U.S. Cl. 260—399

10 Claims

ABSTRACT OF THE DISCLOSURE

Drug lipid conjugates represented by the formulas

In the formulas, R^1 , R^2 and R^3 each is hydrogen, fatty acyl

or $-\text{D}^4$, wherein D^3 and D^4 are remainders of drug moieties, and one of said R^1 , R^2 and R^3 is

or $-\text{D}^4$ and at least one other of said R^1 , R^2 and R^3 is fatty acyl; R^4 is hydrogen or fatty acyl; R^5 and R^6 each is hydrogen or fatty acyl, and at least one of said R^5 and R^6 is fatty acyl; and D^1 and D^2 are remainders of drug moieties.

These compounds exhibit the pharmaceutical utilities of the parent drugs but have enhanced and prolonged activity when orally administered.

This invention relates to drug lipid conjugates and intermediates therefor.

Most orally administered drugs pass into the blood system of the portal vein from which they are immediately passed through the liver. There, a substantial portion of the drug is usually metabolized. The drug dosage must therefore be accordingly increased to compensate for this loss. It is an object of this invention to provide novel compounds which have increased absorption into the lymph system and hence reaches cellular tissue before being passed through the liver.

In summary, the compounds of this invention can be represented by the formulas:

(I)

(II)

(III)

in the above formulas,

R^1 , R^2 and R^3 each is hydrogen, fatty acyl,

or $-\text{D}^4$, wherein D^3 and D^4 each are the remainders of drug moieties, and one of said R^1 , R^2 and R^3 is

or $-\text{D}^4$ and at least one other of said R^1 , R^2 and R^3 is fatty acyl;

R^4 is hydrogen or fatty acyl;

2

R^5 and R^6 each hydrogen or fatty acyl, and at least one of said R^5 and R^6 is fatty acyl; and D^1 and D^2 each are remainders of drug moieties.

The term "fatty acid" and "fatty acyl" group as used herein refer to natural fatty acids and their acyl derivatives. These compounds include saturated fatty acids such as butyric, isovaleric, caproic, caprylic, capric, lauric myristic, palmitic, stearic, arachidic, behenic, lignoceric, cerotic and unsaturated fatty acids such as palmitoleic, oleic, ricinoleic, linoleic, linolenic, eleostearic, and the like. The preferred fatty acyl groups in the compounds of this invention have from 8 to 24 carbons and are saturated. The term "drug moieties" refers to drugs having pharmaceutical utility and having the designated chemical structure as is further exemplified hereinafter.

The compounds of Formula I wherein one of R^1 , R^2 and R^3 is

can be prepared by a procedure represented as follows:

In the above formulas,

D^3 is as previously defined; and

R^{10} , R^{11} , R^{12} and R^{13} each is H, or a fatty acyl group and

Ph is phenyl, and at least one of R^{10} and R^{11} and one of R^{12} and R^{13} is a fatty acyl group.

In the above procedure, the compounds of Formula IV are reacted with oxalyl chloride in a suitable solvent such as diethyl ether to yield the corresponding acyl chlorides of Formula V. The 2,3-acetonides of Formula VI are prepared by reacting the acyl chlorides of Formula V with glycerol acetonide in an inert organic solvent such as chloroform or carbon tetrachloride in the presence of an organic base such as triethylamine or pyridine. The acetonide group of the compounds of Formula VI are cleaved by reaction with triethylborate and boric acid at elevated temperatures to yield the corresponding hydroxy

compounds of Formula VII. The compounds of Formula VIII are prepared by reacting the compounds of Formula VII with the corresponding fatty acyl chloride or chlorides in an inert organic solvent such as chloroform or carbon tetrachloride in the presence of an organic base such as triethylamine or pyridine. Glycerol 2-fatty acylates and glycerol 3-fatty acylates are prepared by reacting the compounds of Formula VII with one molar equivalent of the corresponding fatty acyl chloride or chlorides in an inert organic solvent in the presence of an organic base as described above to yield a mixture of mono- and diesters. The desired monoesters can be separated by chromatography on neutral alumina, eluting with hexane, hexane-benzene and cyclohexanone followed by crystallization. The corresponding 1,2-di(fatty acylates) are prepared using a molar excess of the corresponding fatty acyl chloride or chlorides.

The glycerol 1,3-benzylidene compounds of Formula IX are prepared by reacting the acyl chlorides of Formula V with glycerol 1,3-benzylidene in an inert organic solvent such as chloroform or carbon tetrachloride in the presence of an organic base such as triethylamine or pyridine, as previously described. Cleavage of the 1,3-benzylidene group is obtained by reaction of the compounds of Formula IX with triethylborate and boric acid at elevated temperatures to yield the glycerol compounds of Formula X.

Glycerol 1,3-di(fatty acyl) compounds of Formula XI are prepared by reacting the compounds of Formula X with a molar excess of fatty acyl chloride or chlorides in an inert organic solvent such as chloroform or carbon tetrachloride which can also contain ethyl acetate in the presence of an organic base such as triethylamine or pyridine, as previously described. To obtain the glycerol 1-fatty acylates of Formula XI, the compounds of Formula X are reacted with 1 molar equivalent of the fatty acyl chloride (as previously described) to obtain a mixture of mono- and diesters from which the monoester can be separated by chromatography on neutral alumina, eluting with hexane, hexane-benzene and cyclohexanone followed by crystallization.

Included within Formulas VIII and XI are conjugates of 2-naphthylacetic acid derivatives of Formula IV. The 2-naphthylacetic acid derivatives which are included within Formula IV have been previously described together with methods for their preparation in U.S. patent applications Ser. No. 694,771, filed Dec. 7, 1967 and Ser. No. 810,014, filed Mar. 24, 1969, now abandoned. These compounds can be represented by the following formulas:

In the above formulas,

- 10 each of R¹⁰⁸ (at position 1, 4, 7 or 8) and R¹¹⁹ (at position 1, 7 or 8) is alkyl, trifluoromethyl, fluoro, chloro, hydroxy, conventional hydrolyzable ester, oxyether or thioether;
- 15 R¹⁰⁸ is alkyl, fluoro, chloro, hydroxy, conventional hydrolyzable ester, oxyether or thioether;
- 20 each of R¹⁰⁹ (at position 1, 4, 7 or 8) and R¹²⁰ (at position 1, 7 or 8) is alkyl, fluoro, chloro, hydroxy, conventional hydrolyzable ester, oxyether or thioether, provided that when R¹⁰⁹ is hydroxy, oxyether or thioether, R¹⁰⁹ or R¹²⁰ is the identical group or alkyl, fluoro, chloro or conventional hydrolyzable ester; provided that when one of R¹⁰⁹ or R¹²⁰ is hydroxy, oxyether or thioether, R¹⁰⁸ is the identical group or alkyl, fluoro, chloro, or conventional hydrolyzable ester;
- 25 each of R¹¹² and R¹¹⁵ (at position 1 or 4) is hydroxy, oxyether or thioether;
- 30 each of R¹¹³ (at position 1 or 4) and R¹¹⁴ is alkoxy or alkylthio, provided when R¹¹² or R¹¹⁵ is alkoxy or alkylthio, R¹¹³ or R¹¹⁴ respectively is a different alkoxy or alkylthio group;
- 35 one of R¹¹⁶ and R¹¹⁷ each is hydrogen, methyl, ethyl, difluoromethyl, fluoro or chloro; or R¹¹⁶ and R¹¹⁷ taken together are alkylidene, halomethylene or ethylene;
- 40 R¹¹⁸ is hydrogen, alkyl, cycloalkyl, trifluoromethyl, hydroxymethyl, alkoxyethyl, vinyl, ethynyl, fluoro, chloro, hydroxy, conventional hydrolyzable ester, oxyether, thioether, formyl, carboxy, alkoxy carbonyl, acetyl, cyano or aryl; and R¹²¹ is hydrogen, alkyl, cycloalkyl, trifluoromethyl, fluoro, chloro, hydroxy, conventional hydrolyzable ester, oxyether, thioether or aryl.

In the above Formulas IA-VIIIA, the term "alkyl" and derivations thereof refer to lower molecular weight, branched, or straight chain hydrocarbon groups of up to six carbon atoms, such as methyl, ethyl, propyl, isopropyl, butyl, tertbutyl, pentyl, hexyl, and the like. The term "cycloalkyl" refers to cyclic hydrocarbon groups of three to seven carbon atoms, such as cyclopropyl, cyclopentyl, cyclohexyl and the like.

The term "alkoxy" refers to a straight or branched chain hydrocarbon ether group of six or less carbon atoms, including methoxy, ethoxy, 2-propoxy, butoxy, 3-pentoxy and the like.

The term "alkoxymethoxy" refers to methylether groups substituted with one alkoxy group; typical alkoxy-methoxy groups include methoxymethoxy, ethoxymethoxy, isopropoxymethoxy, and the like.

The term "alkylthio" refers to straight or branched chain hydrocarbon thioether groups of six or less carbon atoms, including methylthio, ethylthio, propylthio, 2-propylthio, 2-butylthio, pentylthio, 3-hexylthio, and the like.

The term "alkylthiomethoxy" refers to methylether groups substituted with an alkylthio group; typical alkylthiomethoxy groups include methylthiomethoxy, 2-propylthiomethoxy, pentylthiomethoxy, and the like.

The term "alkylthiomethylthio" refers to methylthio ether groups substituted with an alkylthio group, including methylthiomethylthio, ethylthiomethylthio, and the like.

The term "alkoxymethylthio" refers to methylthio ether groups substituted with one alkoxy group, such as methoxymethylthio, ethoxymethylthio, 2-propoxymethylthio, and the like.

The term "aryl" refers to unsubstituted and p-mono substituted phenyl derivatives, such as phenyl, p-tolyl, p-fluorophenyl, p-chlorophenyl, p-hydroxyphenyl, p-methoxyphenyl, p-ethylphenyl and the like.

The term "halomethylene" refers to mono- or dihalomethylene groups wherein halo is fluoro or chloro. The preferred halomethylenes include fluoromethylene, difluoromethylene, fluorochloromethylene, and chloromethylene.

The term "conventional hydrolyzable ester" as used with respect to Formulas IA-VIIIA denotes those hydrolyzable ester groups conventionally employed in the art, preferably those derived from hydrocarbon carboxylic acids or their salts. The term "hydrocarbon carboxylic acid" defines both substituted and unsubstituted hydrocarbon carboxylic acids. These acids can be completely saturated or possess varying degrees of unsaturation (including aromatic), can be of straight chain, branched chain, or cyclic structure and, preferably, contain from one to twelve carbon atoms. In addition, they can be substituted by functional groups, for example, hydroxy, alkoxy containing up to six carbon atoms, acyloxy containing up to twelve carbon atoms, nitro, amino, halogeno and the like, attached to the hydrocarbon backbone chain. Typical conventional hydrolyzable esters thus included within the scope of the term and the instant invention are acetate, propionate, butyrate, valerate, caproate, enanthate, caprylate, pelargonate, acrylate, undecenoate, phenoxyacetate, benzoate, phenylacetate, diphenylacetate, diethylacetate, trimethylacetate, t-butylacetate, trimethylhexanoate, methylneopentylacetate, cyclohexylacetate, cyclopentylpropionate, adamantanate, glycolate, methoxyacetate, hemisuccinate, hemi adipate, hemi- β,β -dimethylglutarate, acetoxyacetate, 2-chloro-4-nitrobenzoate, aminoacetate, diethylaminoacetate, piperidinoacetate, β -chloropropionate, trichloroacetate, β -chlorobutyrate, and the like.

The term "oxyether" as used herein denotes those ether groups conventionally employed in the art, preferably those derived from normal chain, branched chain, aromatic hydrocarbons and oxo heterocyclic hydrocarbons. The term "hydrocarbon" defines both saturated and unsaturated hydrocarbons. Those designated hydrocarbons are optionally substituted with groups such as hydroxy, alkoxy, halo, alkylthio, and the like. Preferably the hydrocarbons contain from one to twelve carbon atoms. Typical oxyethers thus include alkoxy, difluoromethoxy, alkoxy-methoxy, alkylthiomethoxy, tetrahydrofuran-2'-yloxy, tetrahydropyran-2'-yloxy, and 4'-alkoxytetrahydropyran-4'-yloxy.

The term "thioether" as used herein denotes those ether groups conventionally employed in the art, preferably those derived from normal chain, branched chain, cyclic and aromatic hydrocarbons. The term "hydrocarbon" defines both substituted and unsubstituted hydrocarbons. These hydrocarbons are optionally substituted with groups such as hydroxy, alkoxy, alkylthio, halo and the like. Preferably the hydrocarbons contain from 1 to 12 carbon atoms. Typical thioethers thus include alkylthio, difluoromethylthio, alkoxy-methylthio, alkylthiomethylthio, and the like.

When one of R¹¹⁶ and R¹¹⁷ is methyl, ethyl, difluoromethyl, fluoro or chloro, the present 2-naphthylacetic acid derivatives have an asymmetric carbon atom, the α -carbon atom of the acetic acid moiety. Accordingly, these compounds can exist as enantiomorphs. Each of the optical isomers of the present 2-naphthylacetic acid derivatives is included within the present invention. In some instances, one enantiomorph exhibits greater anti-inflammatory, analgesic, anti-pyretic and anti-pruritic activity, than the other enantiomorph.

The present 2-naphthylacetic acid derivatives that exist as enantiomorphs can be used as mixtures of enantiomorphs or as resolved enantiomorphs.

The optical isomers can be resolved by conventional means, such as selective biological degradation; or by

the preparation of diastereo-isomer salts of the 2-naphthylacetic acid derivatives with an alkaloid, such as cinchonidine, and the separation of the diastereo-isomers by fractional crystallization. The separated diastereo-isomer salts are acid cleaved to yield the respective optical isomers of the 2-naphthylacetic acid derivatives.

The conjugates of these naphthylacetic acid derivatives have high therapeutic value in the treatment of various inflammatory conditions, such as of the skin, eyes, respiratory tract, bones, and internal organs, contact dermatitis, allergic reactions, and rheumatoid arthritis. In those cases in which the above conditions include pain, pyrexia, and pruritus, coupled with the inflammation, the instant compounds are useful for relief of these associative conditions as well as the principal condition. The instant compounds are in addition, however, useful for treating pain, pyrexia, pruritus, and other syndromes thereof per se, such as those arising from bone fracture, toothache, bacterial and virus infection, contact with poisonous material, neuralgia, neuritis, lacerations, contusions, abrasions, and the like.

The compounds of Formulas IA-VIIIA can be readily prepared from known starting compounds.

One such method by which they can be prepared involves the reaction of an unsubstituted or substituted naphthalene with acetyl chloride in nitrobenzene in the presence of about three molar equivalents of aluminum chloride to afford the corresponding 2-acetylnaphthalene derivative. The resulting derivative is heated with morpholine in the presence of sulfur at 150° C.; the resulting product is refluxed with concentrated hydrochloric acid to furnish the corresponding 2-naphthylacetic acid derivative.

The naphthalenes that are used in the above process can be illustrated by the following formulas:

wherein R¹⁰⁸, R¹⁰⁹ and R¹¹⁸ are as defined above.

The naphthalenes of Formulas A and B are known to the art. Moreover, they can be prepared by conventional means. For example 1,2-dimethoxybenzene is treated with succinic anhydride and aluminum chloride in a hydrocarbon solvent to afford 4-(3',4'-dimethoxyphenyl)-4-oxobutanoic acid. This is reduced by treatment with sodium borohydride, hydrogenolyzed by treating with palladium charcoal catalyst and hydrogen to furnish 4-(3',4'-dimethoxyphenyl) butanoic acid. The corresponding acid chloride is prepared such as by treatment with thionyl chloride, and the acid chloride is treated with aluminum chloride to afford 6,7-dimethoxy-1-tetralone. The tetralone is reduced and hydrogenolyzed by the means described above to furnish 6,7-dimethoxytetralin which is dehydrogenated by treating with palladium charcoal catalyst to afford 2,3-dimethoxynaphthalene. By utilizing 1-methyl-3-fluorobenzene in the above process, 6-methyl-8-fluoro-4-tetralone and 6-fluoro-8-methyl-4-tetralone (as intermediates) and 1-methyl-3-fluoro naphthalene and 1-fluoro-3-methyl naphthalene are prepared. The mixture of naphthalenes are separated by conventional means, such as vacuum distillation.

2-alkyl, 2-cycloalkyl, or 2-aryl substituted naphthalenes, the naphthalenes of Formula A wherein R¹¹⁸ is alkyl or aryl, can be prepared from 2-tetralone by treating the latter with an equivalent of an alkyl, cycloalkyl or aryl

magnesium bromide in an ether to obtain the corresponding 2 - alkyl-, 2 - cycloalkyl-, or 2-aryl-3,4-dihydronaphthalene which is dehydrogenated by heating with palladium charcoal catalyst to afford the corresponding 2-alkyl, 2-cycloalkyl, or 2-aryl naphthalene.

2-vinyl naphthalenes are prepared by refluxing 2-ethyl naphthalenes with a molar equivalent of N-bromosuccinimide in a halo hydrocarbon solvent, such as chloroform, methylene chloride, dichloroethane, carbontetrachloride, 1,4-dichlorobutane, chlorobenzene, chloroethane, chlorocyclohexane, dichlorobenzene, and the like, in light and in the presence of a trace amount of peroxide, such as benzoyl peroxide, t-butylperoxide, peroxyacetic acid, and the like, to afford the corresponding 2-(α -bromoethyl)-naphthalene. The latter is dehydrobrominated by treating with lithium carbonate in dimethylformamide to afford 2-vinyl-naphthalene.

2-ethynylnaphthalene is prepared from 2-vinylnaphthalene by brominating the latter in a halo hydrocarbon solvent and then debrominating the resulting 2-(α , β -dibromoethyl) naphthalene by conventional means, such as by treatment with sodium amide in liquid ammonia, to furnish the 2-ethynylnaphthalene.

2 - cyclopropynaphthalene is prepared from 2-vinyl-naphthalene by refluxing with diiodomethane in the presence of zinc:copper couple.

2-cyclobutynaphthalene is prepared from 2-naphthylmagnesium bromide by treating the latter with cyclobutanone to furnish 2-(1'-hydroxycyclobutyl)-naphthalene, which is hydrogenolyzed with hydrogen in the presence of Raney nickel to furnish 2-cyclobutynaphthalene.

2-cyclopentynaphthalene can be prepared by heating naphthalene with cyclopentyl benzene sulfonate. 2-cyclohexynaphthalene can be similarly prepared by employing cyclohexyl benzene sulfonate.

2-acetylnaphthalene is prepared by treating 2-(α -bromoethyl)-naphthalene, prepared as described above, with sodium acetate in acetic acid to afford 2-(α -ethanoyloxyethyl)-naphthalene which upon base hydrolysis furnishes the 2-(α -hydroxyethyl)-naphthalene. The latter is oxidized with an equivalent of chromium trioxide in glacial acetic acid or 8 N sulfuric acid to furnish 2-acetylnaphthalene.

2-carboxynaphthalene is prepared from 2-acetylnaphthalene by treating the latter with aqueous sodium hypochlorite. The 2-carboxy group is esterified by conventional means, described herein, to furnish 2-alkoxycarbonylnaphthalenes. By treating the latter with one equivalent of an alkali metal hydroxide, treating the resulting product with borane in an ether, such as diglyme, (dimethoxydiethyleneglycol), 2-hydroxymethylnaphthalene is prepared.

The 2-hydroxymethyl group is esterified and etherified by conventional means employed to esterify and etherify primary hydroxy groups.

2-formylnaphthalene is prepared from 2-hydroxymethyl-naphthalene by treating the latter with manganese dioxide in a halo hydrocarbon solvent.

2 - cyanonaphthalenes are prepared by refluxing 2-formylnaphthalene with hydroxylamine hydrochloride and sodium acetate in ethanol to furnish the corresponding oxime which is refluxed with acetic anhydride in the presence of an acid catalyst to furnish 2-cyanonaphthalene.

Alternatively, the above substituents can be introduced on a naphthylacetic acid ester derivative by using an ethyl or vinyl substituted naphthylacetic acid ester derivative as a starting material.

In the preferred embodiment, the starting materials are not substituted with trifluoromethyl, difluoromethoxy, difluoromethylthio, methylmethylenedioxy, alkoxyethylthio, alkylthiomethyloxy, alkylthiomethylthio, tetrahydropyran-2'-yloxy, tetrahydrofuran-2'-yloxy, or 4'-alkoxytetrahydropyran-4'-yloxy groups, but rather, such groups are introduced on the 2-naphthalene acetic acid derivative via one of the final steps.

Another method of preparing these compounds em-

ploys unsubstituted and substituted 1-tetralones and can be illustrated by the following reaction sequence:

50 wherein alkyl and R¹¹⁸ are defined as above.

The 1-tetralones, the compounds of Formula C, are heated with two or more equivalents of a dialkyl carbonate, such as diethyl carbonate, in the presence of one or more equivalents of an alkali metal hydride, such as sodium hydride, potassium hydride, and the like, in a hydrocarbon solvent, such as hexane, cyclohexane, heptane, isoctane, benzene, toluene, xylene, and the like, to afford the corresponding alkoxy carbonyl compounds of Formula D. The latter are treated with an alkali metal hydride in a hydrocarbon solvent; then the resulting products are treated with an α -haloacetic acid ester, such as ethyl α -bromoacetate, methyl α -iodoacetate, and the like, to furnish the corresponding 2-alkoxycarbonyl-2-(alkoxycarbonylmethyl)-1-tetralones, the compounds of Formula E. The latter is hydrolyzed with an acid, such as hydrochloric acid, sulfuric acid, p-toluenesulfonic acid, and the like, to obtain the 2-(carboxymethyl) compounds of Formula F. The latter is reduced with a reducing agent, such as sodium borohydride, lithium borohydride; or with one equivalent of hydrogen in the presence of Adam's catalyst, and the like, to afford the hydroxy compounds of Formula G which are hydrogenolyzed by treatment with an equivalent amount of hydrogen in the presence of a hydrogenation catalyst, such as platinum, palladium, and the like, to furnish the corresponding 1,2,3,4-tetra-

hydro-2-naphthylacetic acid derivatives, the compounds of Formula H. The compounds of Formula H are esterified by conventional means, such as the means described above, to afford the compounds of Formula I; which are dehydrogenated by heating with palladium charcoal catalyst at temperatures of 180° C. and higher to furnish the corresponding 2-naphthylacetic acid ester derivatives, the compounds of Formula J. The latter compounds are hydrolyzed to the corresponding 2-naphthylacetic acid derivatives, the compounds of Formula K, by conventional hydrolysis, such as by treatment with an aqueous methanolic 5 percent sodium hydroxide solution.

Disubstituted tetralones of Formula L are also employed in the above process to prepare the corresponding disubstituted 2-naphthylacetic acid derivatives of Formula M:

wherein R¹⁰⁸ is as defined above and R^{109'} represents the same substituents as R¹⁰⁹, but only at position 4, 7 or 8.

By treating the compounds of Formula D with an alkali metal hydride and then with an α -halocarboxylic acid ester, such as methyl α -bromopropionate and the like, the corresponding 2-alkoxycarbonyl-2-(α -alkoxycarbonylalkyl)-1-tetralones are obtained. These compounds can be hydrolyzed, reduced, hydrogenolyzed, esterified, dehydrogenated and hydrolyzed by the means used to similarly treat compounds of Formula E, to obtain the corresponding 2-naphthyl- α -alkyl acetic acid derivatives.

The 1-tetralones of Formulas C and L are prepared by conventional techniques, for example, such as the process used to make 6,7-dimethoxy-1-tetralone described above.

Alternatively, the 1-tetralones of Formulas C and L can be prepared directly from naphthalenes by conventional means known to the art. For example, the substituted 1-tetralones can be prepared from substituted naphthalenes. The substituted naphthalenes are reduced with two molar equivalents of hydrogen in the presence of a platinum, palladium, nickel catalyst, or the like, to afford the corresponding substituted tetralin (hydrogenation of the unsubstituted ring is favored; when both rings are substituted, two products are obtained with different ring saturation). The substituted tetralin is then oxidized, such as with chromium trioxide in glacial acetic acid or 8 N sulfuric acid, to obtain the substituted 1-tetralone.

The 1-tetralones substituted at positions 6 and 8 of Formulas C and L can also be prepared from the corresponding 4-tetralones (which are intermediates in the above described preparation of naphthalenes substituted at positions 6 and 8) by reducing and hydrogenolyzing the latter with sodium borohydride and hydrogen in the presence of palladium respectively to afford the corresponding tetralins. The tetralins are then oxidized with chromium trioxide in acetic acid to afford the corresponding 1- and 4-tetralones substituted at positions 6 and 8. The tetralones are separated by conventional means, such as fractional crystallization or distillation.

1-substituted and 1,6-disubstituted 2-naphthylacetic acid derivatives also can be prepared from 1-oxo-3,4-dihydro-2-[2H]-naphthylacetic acid derivatives or 1-hydroxy-1,2,3,4-tetrahydro-2-naphthylacetic acid derivatives, the compounds of Formula F or G respectively.

For example, the 1-chloro-2-naphthylacetic acid derivatives are prepared by first esterifying compounds of Formula F by conventional means, such as described above, and then chlorinating the resulting 1-oxo esters by a conventional technique, such as by treatment with phosphorous pentachloride, to furnish the corresponding 1-

chloro-3,4-dihydro compounds. The resulting 1-chloro products are then dehydrogenated by conventional means, preferably by refluxing in a hydrocarbon solvent with 2,3-dichloro-5,6-dicyano - 1,4 - benzoquinone (DDQ) to furnish the corresponding 1-chloro-2-naphthylacetic acid derivatives.

The 1-fluoro-2-naphthylacetic acid ester derivatives are prepared by esterifying the carboxy group of the corresponding 1 - hydroxy-1,2,3,4-tetrahydro-2-naphthylacetic acid derivatives, the compounds of Formula G, and then treating the resulting ester with two or more equivalents of 1-diethylamino-1,2,2-trifluoro-2-chloroethane in a halogenated hydrocarbon solvent to afford the corresponding 1-fluoro derivative. The latter upon treatment with DDQ, as described above, affords the corresponding 1-fluoro-2-naphthylacetic acid ester derivative.

By treating the 1 - oxo-3,4-dihydro-2-[2H]naphthylacetic acid ester derivatives with an alkyl magnesium bromide, such as methyl magnesium bromide, in a non-aqueous ether, such as diethylether, diisopropylether, dioxane, tetrahydrofuran, and the like, hydrolyzing the resulting products under acidic conditions, and then dehydrogenating the resulting 1-alkyl-1,2,3,4-tetrahydro-2-naphthylacetic acid ester derivatives by conventional techniques, such as the techniques described above, the corresponding 1-alkyl-2-naphthylacetic acid derivatives are obtained.

1-alkoxy-2-naphthylacetic acid ester derivatives are prepared by treating 1-oxo-3,4-dihydro-2-[2H]naphthylacetic acid ester derivatives with an alkylorthoformate, such as methylorthoformate, in the presence of an acid catalyst, such as the ones described above, in a hydrocarbon solvent and then dehydrogenating the resulting 1-alkoxy-3,4-dihydro-2-naphthylacetic acid derivatives by conventional means, such as described above.

1-alkylthio-2-naphthylacetic acid ester derivatives can be prepared by hydrolyzing a 1-alkoxy-2-naphthylacetic acid ester derivative to obtain the corresponding 1-hydroxy derivatives and then treating the latter with an alkylmercaptan, such as methylmercaptan, ethylmercaptan, and the like, in an acid environment at about 180° C. under pressure greater than atmospheric pressure for 3 hours or more.

The 1-substituted-2-naphthylacetic acid ester derivatives are hydrolyzed by conventional methods, such as by the means described above, to the free acids.

Another method for the preparation of 4-substituted 2-naphthylacetic acid derivatives involves the treatment of benzene with an equivalent of a 3-halocarbonyl dialkyl glutarate, such as dimethyl 3-chlorocarbonyl glutarate and two or more equivalents of aluminum chloride in a hydrocarbon solvent to afford the corresponding dialkyl benzoyl glutarate, which is reduced and hydrogenolyzed as the oxo-containing compounds above to afford the corresponding dialkyl 3-benzyl glutarate. The latter is hydrolyzed by conventional means and the resulting 3-benzyl glutaric acid is treated with concentrated sulfuric acid to afford the corresponding 1,2-dihydro-4-oxo-2-[3H]naphthylacetic acid derivative. The latter is reduced, halogenated, alkylated, esterified and dehydrogenated by the processes used to reduce, halogenate, alkylate, esterify and dehydrogenate the 1-oxo-3,4-dihydro-2-[2H]naphthylacetic acid derivatives described above, to obtain 4-chloro-, 4-fluoro-, 4-hydroxy-, 4-alkyl, 4-alkoxy-, and 4-alkylthio-2-naphthylacetic acid derivatives. The 4-substituted-6-substituted-2-naphthylacetic acid derivatives are obtained by employing a monosubstituted benzene, such as methoxybenzene, in the above process.

Another method of preparing the 8-substituted 2-naphthylacetic acid derivatives involves treating an ester of phenylacetic acid with two or more equivalents of succinic anhydride and aluminum chloride in a nitrobenzene or carbon disulfide to afford the corresponding alkyl p-(3-carboxy-1-oxopropyl)phenylacetate derivative, which is reduced and hydrogenolyzed by treatment with an alkali borohydride and palladium charcoal catalyst, respective-

11

ly, to afford the ester of *p*-(3-carboxypropyl)-phenylacetic acid. The corresponding acid halide is prepared by treating the latter with a conventional halogenating agent, such as phosphorus tri- or pentabromide or -chloride or thionyl chloride. The resulting ester of *p*-(3-halocarbonylpropyl)phenylacetic acid is treated with three or more equivalents of aluminum chloride in a hydrocarbon solvent to furnish the ester of 8-oxo-5,6-dihydro-2-[7H]-naphthylacetic acid. This compound can be reduced, halogenated, alkylated, esterified and dehydrogenated by the processes described above to obtain the 8-chloro-, 8-fluoro-, 8-hydroxy-, 8-alkyl-, 8-alkoxy- and 8-alkylthio-2-naphthylacetic acid derivatives.

Another method by which the present compounds can be prepared involves the reaction of 2-tetralones with one or more equivalents of a 1-alkoxycarbonylalkylidene triphenyl phosphorane, such as 1-methoxycarbonylethylidene triphenyl phosphorane, to furnish the corresponding 2,2-(1-alkoxycarbonylalkylidene)tetralin. The latter upon heating with palladium charcoal catalyst affords the corresponding 2-naphthylacetic acid ester derivative.

For this purpose, the 1-alkoxycarbonylalkylidene triphenyl phosphorane reactant is conveniently provided upon reaction of triphenylphosphine with a 2-halocarboxylic acid ester in an organic reaction medium followed by reaction with a base.

Thus, for example, by reacting 6-methoxy-2-tetralone with the triphenylphosphorane derived from ethyl 2-halopropionate, 2,2-(1'-carbethoxyeth-1',1'-ylidene)-6-methoxytetralin is prepared. Dehydrogenation thereof provides ethyl 6-methoxynaphthyl- α -methylacetate which upon hydrolysis affords 6-methoxynaphthyl- α -methylacetic acid.

Unsubstituted and substituted 2-tetralones of the following formulas can be utilized in the above process:

wherein R¹⁰⁸, R¹⁰⁹ and R¹¹⁸ are as defined above.

The substituted 2-tetralones of Formulas N and O are prepared by treating the corresponding 1-tetralones with butylnitrite in ether and then esterifying the resulting 2-oximino-1-tetralones with an acid anhydride, such as acetic anhydride, in an organic acid, such as acetic acid, to obtain the substituted 2-acetylmino-2-tetralones. The acetylmino substituents are reduced to acetylamino substituents with hydrogen in the presence of palladium and the like. The keto groups are then reduced to hydroxy groups with sodium borohydride or the like. The substituted 2-acetylamino-1-hydroxytetralins are then treated with glacial acetic acid in the presence of concentrated acid to obtain the corresponding substituted 2-tetralones of Formulas N and O.

The 3,4-dihydro-2-naphthylacetic acid derivatives of Formulas VIA, VIIA and VIIIA are prepared from the corresponding 2-naphthylacetic acid derivatives or the esters thereof by refluxing the latter in an alkanol with two or more equivalents of an alkali metal, such as lithium, potassium, sodium, and the like. Preferably the 2-naphthylacetic acid derivative starting material is not substituted with hydroxy or conventional hydrolyzable ester, but rather, these groups are introduced later by the means described herein.

The addition of an alkyl substituent at the α -position (with respect to the acetic acid chain) to obtain the 2-naphthyl- α -alkylacetic acid derivatives is optional, but when the addition is required, it is carried out following the preparation of the 2-naphthylacetic acid derivatives or the 3,4-dehydro derivatives thereof prepared as de-

12

scribed above. The introduction of the α -alkyl substituents can be illustrated by the following reaction sequence:

wherein

R¹¹⁸ is alkyl, cycloalkyl, trifluoromethyl, vinyl, alkoxy-methyl, fluoro, chloro, conventional hydrolyzable ester, oxyether, thioether, formyl, alkoxycarbonyl, acetyl, cyano or aryl;

Z is a carbon-carbon single bond or a carbon-carbon double bond; provided that when Z is a carbon-carbon double bond, R¹¹⁸ is alkyl, cycloalkyl, trifluoromethyl, fluoro, chloro, oxyether, thioether or aryl.

The 2-naphthylacetic acid derivatives, the compounds of Formula P, are esterified by conventional means, such as being allowed to react with an alkanol in the presence of boron trifluoride, to afford the corresponding esters, the compounds of Formula Q. The compounds of Formula Q are treated with an alkali metal hydride such as sodium hydride, potassium hydride, and the like, in an ether solvent, such as monoglyme, and then with an alkyl halide, such as methyl iodide, to afford the corresponding 2-naphthyl- α -alkylacetic acid ester derivatives, the compounds of Formula R. The latter are hydrolyzed by refluxing in a basic solution to obtain the corresponding 2-naphthyl- α -alkylacetic acid derivatives.

The ethynyl 2-naphthyl- α -alkylacetic acid derivatives are prepared from vinyl 2-naphthyl- α -alkylacetic acid derivatives by brominating and debrominating the latter's vinyl group by the means described above. Oxyether or alkoxy-methyl 2-naphthyl- α -alkylacetic acid derivatives are hydrolyzed to obtain the hydroxy or hydroxymethyl derivatives respectively. Alkoxycarbonyl 2-naphthyl- α -alkylacetic acid derivatives are hydrolyzed to obtain the carboxy derivatives.

2-naphthylacetic acid derivatives substituted at other positions are also employed in the above process.

The α -alkyl substituents are similarly introduced into other 2-naphthylacetic acid derivatives substituted at positions 1,4,7,8 and/or 6. Prior to the above process, hydroxy groups are etherified and carboxy groups are esterified to protect them from attack by reagents used in subsequent elaborations. Such protected groups can be regenerated by hydrolysis after the process.

The introduction of other substituents on the α -carbon atoms of the acetic acid moiety is also optional, but when carried out, is preferably done after the preparation of the 2-naphthylacetic acid derivatives and the esters thereof (including the 3,4-dihydro derivatives).

The α -difluoromethyl group can be introduced by treating the 2-naphthylacetic acid ester derivatives with an alkali metal or alkali metal hydride in a dialkyl carbonate, such as diethyl carbonate, to afford the corresponding α -alkoxycarbonyl derivatives. The latter is

treated with chlorodifluoromethane and an alkali metal alkoxide, such as potassium t-butoxide, in an ether solvent, preferably 1,2-dimethoxyethane to afford the corresponding α -alkoxycarbonyl- α -difluoromethyl derivatives, which are hydrolyzed to furnish the corresponding 2-naphthyl- α -carboxy- α -difluoromethylacetic acid derivatives. The deesterified product is decarboxylated by heating to between 30° C. and 150° C., until the evolution of carbon dioxide ceases to give the corresponding 2-naphthyl- α -difluoromethylacetic acid derivatives.

By treating the above 2-naphthyl- α -alkoxycarbonyl-acetic acid ester derivatives with an equivalent of an alkali metal hydride in a hydrocarbon solvent, then with an alkyl halide, the corresponding 2-naphthyl- α -alkoxy-carbonyl- α -alkylacetic acid ester derivatives are obtained. The latter are hydrolyzed and decarboxylated to furnish the corresponding 2-naphthyl- α -alkylacetic acid derivatives. This is an alternative method of introducing the α -alkyl substituent.

The α -fluoro group is introduced by treating the 2-naphthylacetic acid ester derivatives with two or more equivalents of an alkyl formate, such as ethylformate, and three or more equivalents of an alkali metal or alkali metal hydride in a hydrocarbon solvent to afford the corresponding α -hydroxymethylene derivatives which are treated with an equivalent of an alkali metal hydride and one equivalent of perchloryl fluoride to afford the corresponding α -fluoro- α -formyl derivatives. The latter are oxidized by conventional means, such as with chromium trioxide in glacial acetic acid or 8 N sulfuric acid, to furnish the corresponding α -fluoro- α -carboxy derivatives which are decarboxylated by heating to temperatures of 100° C. or more to afford the corresponding 2-naphthyl- α -fluoroacetic acid ester derivatives. The corresponding α -chloro derivatives are prepared by utilizing chlorine in place of perchloryl fluoride in the above process.

The α,α -difluoromethylene group can be introduced by refluxing 2-naphthyl- α -chloroacetic acid ester derivatives with an alkali metal hydroxide in an alkanol to afford the corresponding 2-naphthyl- α -hydroxyacetic acid derivative. The carboxy groups of the latter are re-esterified by conventional methods and the resulting esters are then oxidized by conventional means, such as described above, to obtain the corresponding α -oxo derivatives, which upon being refluxed with one equivalent of difluoromethylidene triphenylphosphorane in a hydrocarbon solvent, affords the corresponding 2-naphthyl- α,α -difluoromethyleneacetic acid ester derivatives. The corresponding α,α -fluorochloromethylene derivatives are prepared by using chlorofluoromethylidene triphenylphosphorane in place of difluoromethylidene triphenylphosphorane in the above process. The difluoromethylidene triphenylphosphorane is prepared by refluxing sodium chlorodifluoroacetate with triphenylphosphine in dimethylformamide. Similarly, triphenyl chlorofluoromethylidene phosphorane is prepared by employing sodium dichlorofluoroacetate.

The α,α -fluoromethylene group can be introduced by treating 2-naphthyl- α,α -hydroxymethyleneacetic acid ester derivatives with phosphorus pentachloride in a hydrocarbon solvent.

The α,α -fluoromethylene group can be introduced to tosylating 2-naphthyl- α,α -hydroxymethyleneacetic acid ester derivatives with p-toluenesulfonyl chloride in a hydrocarbon solvent and then treating the resulting tosylate with an alkali metal fluoride, such as sodium fluoride. By utilizing the alkali metal chloride in the above process, the corresponding α,α -chloromethylene derivatives are furnished.

The α,α -methylene group is introduced by treating the 2-naphthyl acetic acid ester derivatives with formaldehyde or paraformaldehyde and an alkali metal alkoxide, such as sodium methoxide in dimethylsulfoxide.

The α,α -ethylene group is introduced by refluxing the 2-naphthyl- α,α -methyleneacetic acid ester derivatives with

diiodomethane in the presence of zinc-copper couple in an ether solvent.

In the preferred embodiment of this invention the hydroxy, hydroxymethyl, conventional hydrolyzable ester, 5 alkoxymethoxy, alkylthiomethoxy, tetrahydrofuran-2'-yloxy, tetrahydropyran-2'-yloxy, 4'-alkoxytetrahydropyran-4'-yloxy, alkoxymethythio and alkylthiomethylthio are introduced after the introduction of substituents at the α -position of the 2-naphthyl acetic acid derivatives.

10 Those compounds containing a trifluoromethyl group are preferably prepared from the corresponding methyl substituted 2-naphthylacetic acid ester derivatives by treating the latter with chlorine and phosphorus trichloride in the presence of light to afford the corresponding trichloromethyl derivatives, which, when refluxed with antimony trifluoride in a hydrocarbon solvent, furnish the corresponding trifluoromethyl substituted 2-naphthylacetic acid ester derivatives. In the preferred embodiment of the present invention the trifluoromethyl group is introduced on the 2-naphthylacetic acid derivatives starting material prior to the preparation of the corresponding 3,4-dihydro derivatives by the above described processes.

20 Those compounds containing difluoromethoxy groups are preferably prepared from the corresponding alkoxy substituted 2-naphthylacetic acid ester derivatives by refluxing the latter with 48 percent hydrobromic acid in acetic to furnish the free hydroxy derivatives which, upon treatment with chlorodifluoromethane and an alkali metal hydroxide in aqueous dioxane or tetrahydrofuran, affords the corresponding difluoromethoxy substituted 2-naphthylacetic acid ester derivatives.

25 By utilizing alkylthio 2-naphthylacetic acid ester derivatives in the above process, the corresponding difluoromethythio derivatives are obtained.

30 The hydroxy groups are etherified by conventional methods, for example, by treatment with an alkali metal hydride and then with an alkylhalide, preferably an alkylbromide or iodide; or by treatment with a diazoalkane or an alkanol in the presence of borotrifluoride in an ether solvent, and the like.

35 The alkoxyethoxy groups are introduced by treating the hydroxy substituted 2-naphthylacetic acid derivatives with an alkoxychloromethane in dimethylformamide to afford the corresponding alkoxyethoxy substituted 2-naphthylacetic acid derivatives. The alkylthiomethoxy substituted 2-naphthylacetic acid derivatives are prepared by utilizing an alkylthiochloromethane in the above process.

40 The alkoxymethythio substituted 2-naphthylacetic acid derivatives are prepared by refluxing thio substituted 2-naphthylacetic acid derivatives with an alkoxychloromethane in dimethylformamide. The alkylthiomethythio substituted derivatives are prepared by using an alkylthiochloromethane in place of alkoxychloromethane in the above process.

45 The compounds containing tetrahydrofuran-2'-yloxy, tetrahydropyran-2'-yloxy, or 4'-alkoxytetrahydropyran-4'-yloxy groups are preferably prepared from the corresponding hydroxy 2-naphthyl-acetic acid ester derivative by treatment with dihydrofuran, dihydropyran, or 4'-alkoxy dihydropyran, such as 4'-methoxy dihydropyran, in the presence of an acid catalyst.

50 The 4-alkoxy-2,6-dihydropyrans are prepared by treating 4-oxotetrahydropyran with an alkanol in the presence of an acid catalyst, and then pyrolyzing the resulting 4,4-dialkoxy tetrahydropyran in the presence of acid to afford the corresponding 4-alkoxy-2,6-dihydropyran.

55 The compounds containing hydroxy ester groups are prepared from the hydroxy derivatives by conventional esterification means, such as by heating with an acid anhydride.

60 The foregoing general procedures are useful for the preparation of other naphthylacetic acid derivatives hereof.

15

The preferred 2-naphthylacetic acid conjugates of Formulas VII and XI are derived from 2-naphthylacetic acid compounds within Formula IV represented by the formula:

In the above formula,

R^{130} is methoxy, methylthio, difluoromethoxy, chloro, methyl, ethyl or isopropyl; and
 R^{131} is hydrogen, methyl or difluoromethyl.

The preferred method for preparing these latter compounds involves the reaction of a β -substituted naphthylene with acetyl chloride in nitrobenzene in the presence of at least 3 molar equivalents of an aluminum chloride to yield the corresponding 6-substituted-2-acetylnaphthylene derivative. The resulting derivative is heated with morpholine in the presence of sulfur at about 150° C.; the product is refluxed with concentrated hydrochloric acid to yield the corresponding 2-(6-substituted-2-naphthyl)acetic acid derivative. The addition of the alkyl substituent at the alpha position is carried out by esterifying the 2-(6-substituted-2-naphthyl)acetic acid derivative by conventional methods, such as by treatment with a diazoalkane, such as diazomethane, in ether or with an alkanol such as methanol in the presence of boron trifluoride to yield the corresponding alkyl ester. The ester product is then treated with sodium hydride in an ether solvent such as 1,2-dimethoxyethane, and then treated with a methyl halide such as methyl iodide to yield the corresponding 2-(6'-substituted-2-naphthyl)propionic acid methyl ester. These can be hydrolyzed such as with a base in alcohol to yield the corresponding acids.

Preferably, the difluoromethoxy group at the 6-position of the naphthylene ring is introduced after the introduction of any methyl group at the α -position of the 2-naphthylacetic acid compounds. These compounds are prepared from the corresponding 2-(6-alkoxy-2-naphthyl)acetic acid alkyl ester derivative by refluxing the latter compound with 48 percent hydrobromic acid in acetic acid to furnish the corresponding 6'-hydroxy derivative. The hydroxy derivative is treated with chlorodifluoromethane and an alkali metal hydroxide in aqueous dioxane or tetrahydrofuran to furnish the corresponding 2-(6-difluoromethoxy-2-naphthyl)acetic acid derivative.

The preferred conjugates are those of the d-acids of Formula (IaI).

Representative 2-naphthylacetic acid conjugates of Formulas VIII and XI can be prepared corresponding to the following 2-naphthylacetic acid derivatives of Formulas IA-VIIIA.

TABLE A

6-methoxy-2-naphthylacetic acid,
2-naphthylacetic acid,
6-chloro-2-naphthylacetic acid,
6-fluoro-2-naphthylacetic acid,

3,4-dihydro-6-chloro-2-naphthyl- α -methylacetic acid,
3,4-dihydro-6-fluoro-2-naphthyl- α -methylacetic acid,
3,4-dihydro-6-methyl-2-naphthyl- α -methylacetic acid,
3,4-dihydro-6-difluoromethoxy-2-naphthyl- α -methylacetic acid,
3,4-dihydro-6-methoxy-2-naphthylacetic acid,
3,4-dihydro-6-methylthio-2-naphthylacetic acid,
3,4-dihydro-6-chloro-2-naphthylacetic acid, and
3,4-dihydro-6-methyl-2-naphthylacetic acid.

Also included within the scope of Formulas VIII and XI are conjugates of the 1,2,3,4-tetrahydrophenanthrene, 1,2,3,4,9,10-hexahydrophenanthrene, and 1,2,3,4,9,10,11,12-octahydrophenanthrene acids disclosed in U.S. Pat. 3,476,859. These acids can be represented by the formula:

In the above formula,

R¹⁵⁰ is hydrogen, hydroxy, allyloxy, diethylaminoethoxy, lower alkoxy containing one to four carbon atoms, cyclopentyloxy, tetrahydrofuran-2'-yloxy, tetrahydro-pyran-2'-yloxy, or acyloxy;

R¹⁵¹ is hydrogen, methyl, ethyl or n-propyl;

R¹⁵² is methyl or ethyl;

R¹⁵³ is hydrogen, methyl or ethyl;

R¹⁵⁴ is hydrogen or methyl and is alpha- or beta oriented when Z¹ is a single bond; and

Z¹ and Z² each is a carbon-carbon single bond or carbon-carbon double bond, Z² being a single bond when Z¹ is a single bond.

These conjugates (corresponding to Formulas VIII and XI) can be prepared from the acids of Formula IB (which correspond to Formula IV) by the procedure described above. These conjugates have anti-fertility and estrogenic activity and are accordingly useful in the replacement therapy for estrogen deficiencies, in the control and regulation of fertility, and in the management of menstrual disorders.

Exemplary compounds of Formula IB from which the corresponding conjugates of Formula VIII and XI can be prepared follow:

TABLE B

- d-cis bisdehydrodoisynolic acid and the 7-methyl ester;
l-cis bisdehydrodoisynolic acid and the 7-methyl ester;
d-trans bisdehydrodoisynolic acid;
racemic-cis bisdehydrodoisynolic acid;
racemic-cis 1-ethyl-2-methyl-7-ethoxy-1,2,3,4-tetrahydro-2-phenanthrenecarboxylic acid;

- racemic-cis 1-ethyl-2-methyl-7-methoxy-1,2,3,4-tetrahydro-2-phenanthrenecarboxylic acid;
racemic-cis 1-ethyl-2-methyl-7-allyloxy-1,2,3,4-tetrahydro-2-phenanthrenecarboxylic acid;
5 racemic-cis 1-ethyl-2-methyl-7-n-propoxy-1,2,3,4-tetrahydro-2-phenanthrenecarboxylic acid;
racemic-cis 1-ethyl-2-methyl-7-n-butoxy-1,2,3,4-tetrahydro-2-phenanthrenecarboxylic acid;
racemic-cis 1,2-dimethyl-7-hydroxy-1,2,3,4-tetrahydro-2-phenanthrenecarboxylic acid;
10 racemic-cis 1,2-diethyl-7-hydroxy-1,2,3,4-tetrahydro-2-phenanthrenecarboxylic acid;
racemic-cis 1-ethyl-2-n-propyl-7-hydroxy-1,2,3,4-tetrahydro-2-phenanthrenecarboxylic acid;
15 racemic-cis 7-hydroxy-1,2,3,4-tetrahydro-2-phenanthrenecarboxylic acid;
racemic-cis 1-methyl-7-hydroxy-1,2,3,4-tetrahydro-2-phenanthrenecarboxylic acid;
racemic-cis 1-methyl-7-methoxy-1,2,3,4-tetrahydro-2-phenanthrenecarboxylic acid;
20 racemic-cis 1,2-dimethyl-1-ethyl-7-methoxy-1,2,3,4-tetrahydro-2-phenanthrenecarboxylic acid;
racemic-cis 1,1-diethyl-2-methyl-7-methoxy-1,2,3,4-tetrahydro-2-phenanthrenecarboxylic acid;
25 1-methyl-7-methoxy-1,2,3,4,9,10,11,12-octahydro-2-phenanthrenecarboxylic acid;
1,2-dimethyl-7-methoxy-1,2,3,4,9,10,11,12-octahydro-2-phenanthrenecarboxylic acid;
d-trans 1-ethyl-2-methyl-7-hydroxy-1,2,3,4,9,10,11,12-octahydro-2-phenanthrenecarboxylic acid;
d-cis 1-ethyl-2-methyl-7-hydroxy-1,2,3,4,9,10,11,12-octahydro-2-phenanthrenecarboxylic acid;
30 d1-cis 1-ethyl-2-methyl-7-methoxy-1,2,3,4,9,10,11,12-octahydro-2-phenanthrenecarboxylic acid;
d1-cis 1-ethyl-2-methyl-7-hydroxy-1,2,3,4,9,10,11,12-octahydro-2-phenanthrenecarboxylic acid;
35 d1-cis 1-ethyl-2-methyl-7-methoxy-1,2,3,4,9,10,11,12-octahydro-2-phenanthrenecarboxylic acid;
d1-cis 1-ethyl-2-methyl-7-hydroxy-1,2,3,4,9,10,11,12-octahydro-2-phenanthrenecarboxylic acid;
40 d1-cis 1-ethyl-2-methyl-7-methoxy-1,2,3,4,9,10,11,12-octahydro-2-phenanthrenecarboxylic acid; and
d1-trans 1-ethyl-2-methyl-7-methoxy-1,2,3,4,9,10,11,12-octahydro-2-phenanthrenecarboxylic acid.

Other conjugates included within Formulas VIII and XI are conjugates of the following exemplary drug acids (corresponding to Formula IV in the above preparation procedure). The utility of the conjugates are also indicated.

TABLE C

50	N-p-sulfanillylphenylglycine.....	Antimicrobial.
	2-acetoxybenzoic acid.....	Analgesic, antipyretic, antirheumatic.
	Acetyl salicylic acid.....	Analgesic.
	Actinorhodine.....	Antimicrobial.
	N-(p-[(1-(2,4-diamino-6-pteridinyl)-ethyl]methylamino)benzoyl]-glutamic acid.....	Folic acid antagonist.
55	N-acetyl-L-cysteine.....	Mucolytic agent.
	Agaric acid.....	Anhidrotic.
	4-amino-5-imidazolecarboxamide orotate.....	Treatment of hepatitis, cirrhosis, jaundice.
	Sulfoxalicylic acid compound with sulfanilamide.....	Antimicrobial.
60	p-Aminobenzoic acid.....	Antiricketsial, sunscreen agent.
	β -(4-hydroxy-3,5-diiodophenyl)- β -alanine.....	Iodine therapy in thyrotoxicosis.
	N-(p-[(2,4-diamino-6-pteridylmethyl)-amino]benzoyl)glutamic acid.....	Antimetabolite, folic acid antagonist.
	Diammonium citrate.....	Diuretic.
65	4-chlorophenoxy acetate.....	Anorexigenic.
	D-(2-amino-2-carboxylacetamide)-3,3-dimethyl-7-oxo-4-thia-1-azabicyclo-[3.2.0]heptane-2-carboxylic acid.....	Antimicrobial.
	β -Hydroxymethoxy tricarballylic acid γ -lactone disalicylic acid ester.....	Antipyretic, analgesic.
	N-(p-[(1-(2,4-diamino-6-pteridinyl)-ethyl]amino)benzoyl]glutamic acid.....	Folic acid antagonist.
70	p-Methoxybenzoic acid.....	Antirheumatic.
	p-Stiboxybenzoic acid methyl 1,2,5,6-tetrahydro-1-methylnicotinate.....	Anthelmintic.
	[(p-carbamoylphenyl)-arsylene]-dithio diacetic acid.....	Used in filariasis.
	Bacitracin.....	Antimicrobial.
	5-acetamido-2-ethoxybenzoic acid.....	Sedative, antineuraltic.
	N-benzoyl-p-aminosalicylic acid.....	Antituberculous agent.

TABLE C—Continued

α -N-[2,3-bis(p-chlorophenyl)-1-methyl-propyl]-maleamic acid.	Hypercholesterolemia, gout.
Benzylpenicillinic acid.	Antimicrobial.
p-(benzylsulfonamide)-benzoic acid.	Adjunct in penicillin therapy.
2-(4-biphenyl)-butyric acid.	Hypocholesteremic.
N ⁴ ,N ⁶ -bis(2-chlorophenyl)lysine.	Antimetabolite.
1-(1'-cytosinyl)-4-[L-3'-amino-5'- β -(1'-N-methylguanidino)valeryl-amino]-1,2,3,4-tetra-deoxy- β -D-erthrono-2-enuronic acid.	Antimicrobial.
Bradykinin.	Vascular relaxant, cardiac stimulant.
5-bromosalicylic acid acetate.	Analgesic.
Carreine acetyltryptophanate.	CNS stimulant.
d-Camphorcarboxylic acid.	Antisiphilitic.
4-(o-chlorobenzyl)-5-oxo-4-phenyl-hexanoic acid.	Antiviral agent.
o-(Carbamoylophenoxy)acetic acid.	Antipyretic, analgesic.
3 β -hydroxy-11-oxolean-2-en-30-oic acid hydrogen succinate.	Anti-inflammatory.
2-(3-carboxy-4-hydroxyphenyl)-cinnamic acid.	Antiarthritic.
1-hydroxy-5-oxo-5H-pyrido-[3,2-a]-phenoxyazine 3-carboxylic acid.	Used for treating cataracts.
7-(D-5-amino-5-carboxyvaleramido)-3-(hydroxymethyl)-8-oxo-5-thia-1-azabicyclo[4.2.0]oct-2-ene-2-carboxylic acid acetate.	Antimicrobial.
3-(hydroxymethyl)-8-oxo-7-[2-(2-phenyl)acetamido]-5-thia-1-azabicyclo[4.2.0]oct-2-ene-2-carboxylic acid acetate.	Antimicrobial.
4-(p-[bis(2-chloroethyl)amino]-phenyl)butyric acid.	Antimetabolite.
7-(n-[N,N-bis(2-chloroethyl)-amino]phenyl)propylpenicillin.	Antimicrobial.
3 α ,7 α ,12 α -trihydroxy-5 β -cholanic acid.	Choleretic.
2-phenylcinchoninic acid.	Uricosuric, analgesic.
Citric acid.	Used for Rickets.
Dihydrocodenone O-(carboxymethyl)oxime.	Antitussive.
1-carboxy-4,5-dihydroxy-1,3-cyclohexenylbenzyl-3,4-dihydroxychinamate.	Choleretic.
Cystine.	Used to promote wound healing.
Dimethylaminoethanol acetyl-L-glutamate.	CNS stimulant.
2-(dimethylamino)ethanol p-acetamidoobozate.	Do.
3,7,12-triketoholanic acid.	Choleretic.
N-[D-1-(2-amino-4-hydroxy-6-pteridinyl)ethyl]methyl-amino]benzyl]glutamic acid.	Antimetabolite.
3 α ,12 α -dihydroxy-5 β -cholanic acid.	Choleretic.
3,5-diamino-2-(p-(sulfamoylphenyl)azol)benzoic acid carboxysulfamido-chrysoidine.	Antimicrobial.
4,4'-diazidino)benzamidine diacetate.	Used for trypansomal and babesia infections.
3,5-dibromotyrosine.	Antithyroid agent.
N-(Glycloyacetyl)-DL-serine.	Antimetabolite.
N-[3,5-dichloro-4-((2,4-diamino-6-pteridinyl)methyl)-methylamino]benzyl]glutamic acid.	Folic acid antagonist.
3,4-dichloro- α -methoxybenzyl penicillin.	Antimicrobial.
p-(Diethylsulfamoyl)benzoic acid.	Uricosuric agent.
3,5-diiodotyrosine.	Iodine therapy in hyperthyroidism.
Diisopropylamine dichloroacetate.	Vasodilator, hypotensive agent.
Pteroyl- α -glutamylglutamic acid.	Antimetabolite.
(Ethylenedinitrilo)-tetraacetic acid disodium salt.	Anticoagulant.
2-[α -(2-dimethylaminoethoxy)- α -methylbenzyl]pyridine succinate.	Antihistamine.
[2,3-dichloro-4-(2-methylenebutyryl)phenoxy]acetic acid.	Diuretic.
1,2,3,6-tetrahydro-1,3-dimethyl-2,6-dioxopurine-7-acetic acid piperazine salt.	Cardiotonic, diuretic, smooth muscle relaxant.
2-(1-hydroxyethyl)- β -(hydroxymethyl)-3-methyl-5-benzofuranacrylic acid γ -lactone hydrogen succinate.	Cardiotonic; vasodilator.
1-(5-norbornen-2-yl)ethyl succinic acid ester.	Choleretic.
γ -Oxo-8-fluoranthenebutyric acid.	Hydrocholeretic.
N-(α , α -trifluoro-m-tolyl)anthranilic acid.	Anti-inflammatory agent.
3-fluoro-4-hydroxyphenyl-acetic acid.	Antithyroid agent.
N-[p-((2-amino-4-hydroxy-6-pteridinyl)methyl)benzoyl]glutamic acid.	Folic acid deficiency; megaloblastic anemias not due to B ₁₂ deficiency (pernicious anemia).
N-[p-((2-amino-5-formyl-5,6,7,8-tetrahydro-4-hydroxy-6-pteridinyl)methyl)benzoyl]glutamic acid.	Folic acid deficiency.
4'-formylsuccinilane thiosemicarbazone.	Antituberculous agent.
2,4,6,8-decataenenedioic acid 4-(1,2-epoxy-1,5-dimethyl-4-hexenyl)-5-methoxy-1-oxaspiro[2.5]oct-6-yl ester.	Antimicrobial.
4-chloro-N-furfuryl-5-sulfamoylanthranilic acid.	Diuretic.
11,16-trihydroxy-4,8,10,16-tetramethyl-17-(1'-carboxyisohept-4'-enylidene)cyclopentanoperhydrophenanthrene 16-acetate.	Antimicrobial.

TABLE C—Continued

3,4,5-trihydroxybenzoic acid.	Astringent.
2,5-dihydroxybenzoic acid.	Analgesic, antirheumatic.
4-methoxy-5-methyl-o-phthalaldehyde.	Antifungal, antibiotic.
5-3-carboxylic acid.	Antiarthritic.
D-glucuronic acid.	Used for muscular degeneration or weakness.
N-amidinoglycine.	Used in Addison's disease.
3 β -hydroxy-11-oxolean-12-en-30-oic acid.	Do.
Glycyrrhizic acid.	Antimetabolite.
N-formyl-N-hydroxyglycine.	Antimicrobial.
Helyolic acid.	Antidepressant.
1,3,5,8-tetramethyl-2,4-bis(α -hydroxyethyl)porphine-6,7-dipropionic acid.	Anticoagulant.
Heparin acid.	Sclerosing agent.
2-hexyldecanoic acid.	Antithyroid agent.
β -[3,5-diido-4-(4'-hydroxy-3',5'-di-tert-butylphenoxy)phenyl]propionic acid.	Antileprotic.
11-(2-cyclopenten-1-yl)-undecanoic acid.	Antihistaminic.
α -Hydrazino- β -(5-imidazolyl)propionic acid.	Antidiuretic, uricosuric agent.
3-hydroxy-2-phenyl-4-quino-linecarboxylic acid.	Analgesic, antipyretic, anti-inflammatory agent.
(p-isobutylphenyl)acetic acid.	Anti-inflammatory agent.
2-(4-isobutylphenyl)propionic acid.	Anti-inflammatory agent.
1-(p-chlorobenzyl)-5-methoxy-2-methylindole-3-acetic acid.	Anti-inflammatory, analgesic, antipyretic agent.
2-carboxy-3-carboxymethyl-4-isopropenylpyrrolidine.	Ascaricide.
Lucensomycin.	Antifungal agent.
Lysergic acid.	Serotonin antagonist.
N-(2,3-xylyl)anthranilic acid.	Analgesic, antinflammatory agent.
L-3-[p-[bis(2-chloroethyl)-amino]phenyl]alanine.	Antimetabolite.
[5-acetamido-2]-[2-(2-hydroxyethoxy)carbamoyl]-phenoxo]acetic acid.	Diuretic.
3-(hydroxymercur)-propyl[carbamoyl]-phenoxo]acetic acid.	Do.
N-[3-(hydroxymercur)-2-methoxy-propyl]carbamoyl-succinamic acid.	Do.
[3-[3-(hydroxymercur)-2-methoxypropoxy]saclyldene]-malonic acid δ -lactone.	Diuretic.
3-(3-hydroxymercur)-2-methoxy-propyl[carbamoyl]-1,2,2-trimethyl-cyclopentanecarboxylic acid.	Do.
β -(6-methoxy-2-naphthyl)- α , α -dimethylvaleric acid.	Estrogenic agent.
Methescalin theophylline.	Vascular tonic.
N-[p-((2a,4-Diamino-6-pteridinyl)-methyl)methylamino]benzoyl]glutamic acid. 3-(O-methoxyphenyl)-2-phenylacrylic acid.	Antimetabolite.
L-3-(3,4-dihydroxyphenyl)-2-methylalanine.	Choleretic.
α -Methyl- α -pyrroline.	Antihypertensive agent.
α -Methyl-p-tyrosine.	Inhibitor of catecholamine synthesis.
45 Morpholine salicylate.	Inhibitor of catecholamine synthesis, antihypertensive.
1-Ethyl-1,4-dihydro-7-methyl-4-oxo-1,8-naphthyridine-3-carboxylic acid.	Analgesic, antirheumatic agent.
Narcine.	Antibacterial.
2-(benzhydryloxy)-N,N-dimethyl-ethylamine bis(theophylline 7-acetate).	Analgesic, antitussive.
Nicotinic acid.	Antihistaminic, antiemetic, antiparkinson agent.
Monoethanolamine nicotinate.	Vasodilator.
N-[p-((1-(2-amino-4-hydroxy-6-pteridinyl)ethyl)amino)benzoyl]glutamic acid.	Do.
cis-9-octadecenoic acid.	Antimetabolite.
1,2,3,6-tetrahydro-2,6-dioxo-4-pyrimidinocarboxylic acid.	Choleretic.
Isonicotinic acid hydrazide p-aminosalicylate.	Antituberculous agent.
D-3-mercaptopvaline.	Chelating agent in hepatolenticular degeneration.
Penicillin N.	Antimicrobial.
Penicillin O.	Do.
Penicillin V.	Stimulator of gastric acid secretion.
60 N-[N-[N-(N-tert-butoxycarbonyl- β -alanyl)-L-tryptophanyl]-L-methionyl]-L-aspartyl-L-phenylalanimide.	Iron removal agent.
[(Carboxymethyl)imino]bis(ethyl-enenitrile) tetraacetic acid.	Cathartic.
Phenoltritachlorophthalene.	To treat fatigue.
N-(phenoxyamidino)sarcosine.	Anthelmintic.
1-ethyl-1-methyl-2-propynyl acid phthalate.	Antimicrobial agent.
4'-(Acetyl sulfamyl)phthalanilic acid.	Do.
4'-(2-thiazolylsulfamyl)-phthalanilic acid.	Vasodilator, hypotensive agent.
L-Pyroglyutamyl-L-alanyl-L-aspartyl-L-prolyl-L-asparaginyl-L-lysyl-L-phenylalananyl-L-tryosyl-L-glycyl-L-leucyl-methionamide.	
p-(Dipropylsulfamyl)benzoic acid.	Uricosuric agent in gout, gouty arthritis.
N-[N-(N-pteroyl- γ -glutamyl)-glutamyl]glutamic acid.	Antimetabolite.
3-pyridineacetic acid.	Antihypercholesteremic agent.

TABLE C—Continued

Diacetylpyrocatechol-3-carboxylic acid.	Analgesic, antipyretic.
N,N-diethyl-cis-Δ ⁴ -tetrahydrophthalimide acid salt of 6-methoxy-4-(dimethylaminoethylamino)quinoline.	Antiasthmatic.
5-[p-(4,6-dimethyl-(2-pyrimidinyl)sulfamoyl)-phenylazo]-salicylic acid.	
5-[p-sulfamoylphenylazo]-salicylic acid.	Antimicrobial agent.
5-[p-(2-pyridylsulfamoyl)-phenylazo]-salicylic acid.	In ulcerative colitis.
o-Hydroxybenzoic acid.	Analgesic agent.
5,6-dimethoxyphthalidehydric acid isomericinylhydrazone.	Antituberculous agent.
p-Carboxybenzaldehyde thiosemicarbazone diethanolamine salt.	Antituberculous agent.
Stibocapteate	Antischistosomal agent.
5-amino-6-(7-amino-5,8-dihydro-6-methoxy-5,8-dioxo-2-quinolyl)-4-(2-hydroxy-3,4-dimethoxyphenyl)-3-methylpicolinic acid.	Antimetabolite.
4'-(2-Thiazolylsulfamoyl)-succinianilic acid.	Antimicrobial agent.
4'-sulfenylsuccinianilic acid.	Do.
p-Sulfanilamidosalicylic acid.	Do.
2-[2-(p-chloro- α -methyl- α -phenylbenzyl)-oxyethyl]-1-methyl-pyroridine hydrogen fumarate.	Antihistaminic.
5,6-dihydrobenz[e]acridine-7-carboxylic acid.	Used in certain muscular paralyses.
3,6-dihydro-3,7-dimethyl-2,8-dioxo-1(2H)-purineacetic acid.	Diuretic, myocardial stimulant, vasodilator.
1,2,3,6-tetrahydro-3,3-dimethyl-2,6-dioxopurine-7-acetic acid.	Diuretic, myocardial stimulant.
p-Ureidobenzenearsylene-dithio-di- α -benzoic acid.	Amebicide.
Trans-4-(aminomethyl)cyclohexanecarboxylic acid.	Antifibrinolytic agent.
[4-(4-Hydroxy-3-iodophenoxy)-3,5-di-iodophenyl]acetic acid.	Thyroid replacement therapy.
β -[4-(4-hydroxy-3-iodophenoxy)-3,5-di-iodophenyl]-alanine.	Do.
β -[4-(3'-ido-4'-hydroxyphenyl)-3,5-di-iodophenyl]-propanoic acid.	Cholesteropenic agent.
5-benzylidihydro-6-thioxo-2H-1,3,5-thiadiazine-3(4H)acetic acid.	Antimycotic.
α -Ethyl-1-hydroxy-4-phenyl-cyclohexaneacetic acid.	Choleretic agent.
3-(1,4-dihydro-3-methyl-1,4-dioxo-2-naphthylthio)propionic acid.	Antihemorrhagic agent.
p-[α -Ethoxy-p-phenylphenacyl]amino]benzoic acid.	Antiviral agent.

The compounds of Formula I wherein one of R¹, R² and R³ is —D⁴ can be prepared by a procedure represented as follows:

in the above formulas

D⁶ is the remainder of a ketone drug moiety and D⁷ is the remainder of the enol ether drug moiety corresponding to D⁶ ketone drug moiety or an aromatic drug moiety; and each of R¹⁷⁰, R¹⁷¹, R¹⁷² and R¹⁷³ is hydrogen or a fatty acyl group, and at least one of R¹⁷⁰ and R¹⁷¹ and at least one of R¹⁷² and R¹⁷³ is a fatty acyl group.

In the above illustrated process, the ketones of Formula IC are reacted with methyl orthoformate in dioxane in the presence of p-toluenesulfonic acid to yield the enol ethers of Formula IIC. The compounds are reacted with 1,2-di-O-(fatty acyl)-glycerols in an inert organic solvent such as benzene in the presence of p-toluenesulfonic acid to yield a mixture of the drug enol ethers, i.e. 2',3'-di-O-(fatty acyl)-glycerols of Formula IIIC and 1',3'-di-O-(fatty acyl)-glycerols of Formula IVC. The compounds of Formula IIIC and IVC are isolated from the mixture by conventional chromatography and crystallization.

Included within Formulas IIIC and IVC are conjugates of steroid ethers corresponding to Formula IIC. These steroid ethers which are included within Formula IIC

are, for the most part, derived from ketones which have been described together with methods for their preparation in U.S. patent applications Ser. No. 731,300, filed May 22, 1968, Ser. No. 731,301, filed May 22, 1968 and 5 Ser. No. 731,267, filed May 22, 1968 and U.S. Pats Nos. 3,365,446, 3,067,194 and 3,364,203. Estrogenic steroids conjugated at an aromatic hydroxy group (phenolic group) are prepared from the corresponding ethers described in U.S. patent application Ser. No. 731,301, filed 10 May 22, 1968.

Representative anabolic steroids within Formula IC can be represented by the following formulas:

45 In the above formulas

R²¹⁰, R²¹¹, R²¹³, R²¹⁵, R²²², and R²²³ each is hydrogen or methyl (preferably one of R²²² and R²²³ is methyl); R²¹² is hydrogen or lower alkyl;

50 R²¹⁴ is hydrogen or chloro; R²¹⁶ is hydroxy, or a conventional hydrolyzable ester or ether thereof; R²¹⁷ is methyl or ethyl; R²¹⁹, R²²⁰, and R²²⁵ each is hydrogen, methyl, fluoro, or chloro; and R²²⁰ is not present when Z⁴ is a double bond;

Z⁴ and Z⁶ each is a single bond or a double bond.

The conjugates of the compounds of Formulas ID-VD represented by Formulas IIIC and IVC are anabolic agents with a favorable anabolic:androgenic ratio, also possess anti-estrogenic, anti-gonadotropic, and anti-fibrillatory activities, and can be used in the same manner as testosterone. These compounds are preferably administered orally. However, they can also be administered by other usual routes such as parenterally. In either manner of administration they can be administered either alone or in conjunction with other medicinal agents, or in pharmaceutically acceptable, non-toxic compositions formed by the incorporation of any of the normally employed excipients.

The terms "(lower)alkyl" and derivations thereof appearing in the above and following definitions for steroids denote alkyl groups containing from one to six carbon atoms, inclusive, such as methyl, ethyl, propyl, isopropyl, butyl, isobutyl, t-butyl, pentyl, amyl, hexyl and the like.

The term "conventional hydrolyzable ester" as used therein denotes those hydrolyzable ester groups conventionally employed in the steroid art, preferably those derived from hydrocarbon carboxylic acid or phosphoric acid and their salts. The term "hydrocarbon carboxylic acid" defines both substituted and unsubstituted hydrocarbon carboxylic acids. These acids can be completely saturated or possess varying degrees of unsaturation (including aromatic), can be of straight chain, branched chain, or cyclic structure, and preferably contain from one to 12 carbon atoms. In addition, they can be substituted by functional groups, for example, hydroxy, alkoxy containing up to six carbon atoms, acyloxy containing up to 12 carbon atoms, nitro, amino, halogeno, and the like, attached to the hydrocarbon backbone chain. Typical conventional hydrolyzable esters thus included within the scope of the term and the instant invention are acetate, propionate, butyrate, valerate, caproate, enanthate, caprylate, pelargonate, acrylate, undecanoate, phenoxyacetate, benzoate, phenylacetate, diphenylacetate, diethylacetate, trimethylacetate, t-butylacetate, trimethylhexanoate, methylneopentylacetate, cyclohexylacetate, cyclopentylpropionate, adamantoate, glycolate, methoxyacetate, hemisuccinate, hemiadipate, hemi- β,β -dimethylglutarate, acetoxyacetate, 2 - chloro - 4 - nitrobenzoate, aminoacetate, diethylaminoacetate, piperidinoacetate, β -chloropropionate, trichloroacetate, β -chlorobutyrate, dihydrogen phosphate, dibenzyl phosphate, benzyl hydrogen phosphate, sodium benzyl phosphate, cyclohexylammonium benzyl phosphate, sodium phenyl phosphate, sodium ethyl phosphate, di-p-nitrobenzyl phosphate, sodium o-methoxyphenyl phosphate, cyclohexylammonium p-cyanobenzyl phosphate, sodium phenacyl phosphate, benzyl o-carbome-thoxyphenyl phosphate, and the like. The term "conventional hydrolyzable ethers" include tetrahydropyran-2'-yl, tetrahydrofuran - 2' - yl, and 4' - (lower)alkoxy - 4' - tetrahydrofuran-4'-yl ethers and the like.

By the term "aryl" are included aryl, aralkyl, and alkaryl groups, such as phenyl, p-chlorophenyl, p-methoxyphenyl, benzyl, phenethyl, tolyl, ethylphenyl, and the like. The wavy line(s) designates and includes both the alpha and beta configurations.

Representative anabolic steroid conjugates according to this invention (corresponding to Formulas IIIC and IVC) can be prepared from the following ketones by 45 the above procedure.

TABLE D

19-norandrost-4-en-17 β -ol-3-one,

17 β -hydroxy-6 α -fluoro-17 α -methyl-19-norandrost-4-en-3-one, and
17 β -hydroxy-6 α -fluoro-17 α ,18-dimethyl-19-norandrost-4-en-3-one.

Representative corticoid steroids within Formula IC can be represented by the formula:

In the above formula,

R²³⁰ is hydrogen, methyl, fluoro, or chloro and when Z⁸ is a single bond, R²³⁰ can be either α or β oriented; R²³¹ is hydrogen, chloro, or fluoro; R²³² is keto or

wherein R^{232a} is hydroxy, chloro, or fluoro; R²³³ is hydrogen, methyl, hydroxy, or conventional hydrolyzable esters thereof; R²³⁴ is hydrogen, hydroxy, conventional hydrolyzable esters thereof, or when taken together with R²³³,

R^{235} is hydrogen or alkyl of up to eight carbons;
 R^{236} is hydrogen, alkyl, or an aryl group of up to eight carbons;
 R^{237} is chloro, fluoro, hydroxy, conventional hydrolyzable esters thereof or conventional hydrolyzable ethers thereof;
 Z^1 and Z^2 each is a single bond, double bond, or

each of R^{267} and R^{268} is hydrogen, chloro, or fluoro.

The conjugates of the compounds of Formula IE have corticoid activity and are accordingly useful as anti-inflammatory agents. They are useful for the same purposes as hydrocortisone. These compounds are preferably administered orally. However, they can also be administered parenterally or topically. In any manner of administration, they can be administered either singly, in conjunction with other medicinal agents, or in pharmaceutically acceptable non-toxic compositions formed by the incorporation of any of the normally employed excipients.

Representative corticoid steroid conjugates according to this invention (corresponding to Formula IIIC and IVC) can be prepared from the following ketones by the above procedure:

6α -fluoro-16 α -methylpregna-1,4-diene-11 β ,21-diol-3,20-dione,
 16α -acetoxy pregn-4-ene-11 β ,21-diol-3,20-dione, and
 16β -acetoxy pregn-4-ene-11 β ,21-diol-3,20-dione.

5 Representative estrogenic steroids within Formula IC can be represented by the following Formula IF and representative estrogenic steroids with aromatic methoxy groups within Formula IIIC are represented by the following Formula IIF.

10

20

In the above formulas,

R^{199} and R^{200} each is hydrogen, hydroxy or a conventional hydrolyzable ester thereof, lower alkoxy, lower cycloalkoxy, lower cycloalkenyl, tetrahydrofuran-2'-yloxy, tetrahydropyran-2'-yloxy, or 4'-(lower)alkoxytetrahydropyran-4'-yloxy;

R^{201} is hydrogen, methyl, methoxy, hydroxyl or conventional hydrolyzable esters thereof, or conventional hydrolyzable ethers thereof;

R^{202} is hydrogen or methyl; and when Z^9 is a single bond, R^{202} can be alpha or beta oriented;

R^{203} is hydrogen, hydroxy or conventional hydrolyzable esters thereof (e.g. lower acyloxy or lower cycloacyloxy groups) when Z^9 is a single bond and is hydrogen when Z^9 is a double bond;

R^{205} is hydrogen, a lower alkyl group, such as methyl, ethyl, propyl, and the like, a lower alkenyl group, such as vinyl and the like, or a lower alkynyl (including halo lower alkynyl with a halogen, such as fluoro, chloro or bromo), such as ethynyl, fluoroethynyl, chloroethynyl, bromoethynyl, propynyl, trifluoropropynyl, butynyl, hexynyl, and the like, or

R^{206} is methyl or ethyl; and Z^9 is a single or double bond.

50 The conjugates of the compounds of Formulas IF and IIF corresponding to compounds of Formulas IIIC and IVC have high oral anti-fertility and estrogenic activity. They are preferably administered orally but can be administered parenterally in the same manner and dosage

55 as estradiol and when administered orally are used in the same manner as ethynodiol. The conjugates of this invention can be administered in any of the number of conventional pharmaceutical forms, and particularly in ones suited for oral administration, e.g. in solid form, such as in pills, powders, capsules, tablets, or the like, or in liquid form, such as syrups, emulsions, suspensions, and the like.

Representative estrogenic steroid conjugates according to this invention (of Formulas IIIC and IVC) can be prepared from the following exemplary ketones and aromatic ethers by the above procedure.

TABLE F

- 70 3-methoxyestra-1,3,5(10)-trien-17-one,
 3-methoxyestra-1,3,5(10)-trien-17 β -ol,
 3-methoxy-17 α -ethynylestra-1,3,5(10)-trien-17 β -ol,
 3-methoxy-7 α -methyl-17 α -ethynylestra-1,3,5(10)-trien-17 β -ol,
 75 3-methoxy-17 β -cyclopentoxyestra-1,3,5(10)-trien-

3-methoxyestra-1,3,5(10),7-tetraen-17-one,
3-hydroxyestra-1,3,5(10)-trien-17-one,
3-hydroxy-18-methylestra-1,3,5(10)-trien-17-one,
3-cyclopentoxyestra-1,3,5(10)-trien-17-one,
3-cyclopentoxy-18-methylestra-1,3,5(10)-trien-17-one,
3-acetoxyestra-1,3,5(10)-trien-17-one,
3-tetrahydropyran-2'-yloxyestra-1,3,5(10)-trien-17-one,
and
3-hydroxyestra-1,3,5(10),7-tetraen-17-one.

Representative progestational steroids within Formula IC can be represented by the following formulas:

In the above formulas,

R²¹³ is hydrogen or methyl;
R²¹⁶ is hydroxy or conventional hydrolyzable esters or ethers thereof;
R²¹⁷ is methyl or ethyl;
R²¹⁸ is lower alkenyl, such as vinyl and propenyl, lower alkynyl (including lower haloalkynyl with a halogen, such as fluoro, chloro, or bromo), such as ethynyl, fluoroethynyl, chloroethynyl, propynyl, trifluoropropynyl, and the like, and

wherein

R²¹⁹ and R²²⁰ each is hydrogen, chloro, or fluoro;
R²²¹, R²²², and R²²⁵ each is hydrogen, methyl, fluoro, or chloro;
in Formula IG when Z¹⁰ is a double bond, R²²⁰ is absent; in Formula IVG when Z¹² is a single bond, R²¹⁹ can have either an α or β orientation;
R²³⁶ and R²³⁷ each is hydrogen or, taken together, a methylene group having the formula

wherein

R²³⁸ and R²³⁹ each is hydrogen, chloro, or fluoro;
R²⁴⁰ is keto or

wherein R²⁴¹ is hydrogen, chloro, or hydroxyl; and when R²⁴¹ is hydrogen, R²¹³ and R²⁴² is hydrogen; R²⁴² is hydrogen, chloro, or fluoro;
R²⁴³ is methylene,

wherein R²⁴⁴ and R²⁴⁵ each is hydrogen or methyl, or taken together with R²⁴⁸ is

wherein

- 15 R²⁴⁶ and R²⁴⁷ each is hydrogen, alkyl, or aryl, the latter two groups having up to eight carbons;
R²⁴⁸ is hydrogen, hydroxyl, or conventional hydrolyzable esters thereof;
R²⁴⁹ is hydrogen or fluoro;
20 Z¹⁰ and Z¹¹ each is a single bond or double bond; and Z¹² is a single bond, double bond, or a single bond in combination with a methylene group having the formula

wherein R²⁵¹ and R²⁵² each is hydrogen, chloro, or fluoro.

- 30 The conjugates of the compounds of Formulas IG-IVG, inclusive, corresponding to compounds of Formulas IIIC and IVC are progestational agents useful in the treatment of menstrual disorders and fertility control and can be used in the same manner as 17 α -acetoxy-6-chloropregna-4,6-diene-3,20-dione (chloromadinone acetate). The 16-methylene species are particularly useful in estrus synchronization in domestic animals. These compounds are preferably administered orally but they can also be administered parenterally. In any mode of administration the conjugates can be used either alone or in conjunction with other medicinal agents, or in pharmaceutically acceptable, nontoxic compositions formed by the incorporation of any of the normally employed excipients.

- 45 Representative progestational steroid conjugates according to this invention (of Formulas IIIC and IVC) can be prepared from the following ketones by the above procedure.

TABLE G

- 50 pregn-4-en-3- β -ol-20-one,
6-chloro-17 α -acetoxypregna-4,6-dien-3 β -ol-20-one,
6-chloro-17 α -acetoxy-19-norpregna-4,6-dien-3 β -ol-20-one,

 17 α -ethynyl-17 β -hydroxy-18-methyl-19-norandrost-4,9(10)-dien-3-one,
 17 α -fluoroethynyl-17 β -hydroxy-19-norandrost-4,9(10)-dien-3-one,
 17 α -vinyl-17 β -hydroxy-19-norandrost-4,9(10)-dien-3-one,
 17 α -vinyl-17 β -hydroxy-18-methyl-19-norandrost-4,9(10)-dien-3-one,
 17 α -(2'',2''-difluorocyclopropenyl)-17 β -hydroxy-18-methyl-19-norandrost-4,9(10)-dien-3-one,
 17 α -(2'',2''-difluorocyclopropenyl)-17 β -hydroxy-19-norandrost-4,9(10)-dien-3-one,
 17 α -vinyl-17 β -hydroxy-18-methyl-19-norandrost-4,9(10),11-trien-3-one,
 17 α -ethynyl-17 β -hydroxy-19-norandrost-4,9(10),11-trien-3-one,
 17 α -fluoroethynyl-17 β -hydroxy-18-methyl-19-norandrost-4,9(10),11-trien-3-one,
 17 α -ethynyl-17 β -hydroxy-19-norandrost-4,9(10),11-trien-3-one,
 17 α -fluoroethynyl-17 β -hydroxy-19-norandrost-4,9(10),11-trien-3-one,
 17 α -chloroethynyl-17 β -hydroxy-19-norandrost-4,9(10)-dien-3-one.

50 The preferred steroid conjugates of Formulas IIIC and IVC are derived from steroid ketones represented by the formulas:

In the above formulas,

70 R²⁷⁰ and R²⁷¹ each is hydrogen or methyl;
 OR²⁷² is hydroxy or a conventional hydrolyzable ester thereof; and
 R²⁷³ is hydrogen, lower alkyl, cyclopropyl, lower alkenyl,
 75 lower alkynyl or propadienyl.

31

Other conjugates included within Formulas IIIC and IVC can be prepared from the following exemplary drug ketones and aromatic ethers by the above procedure.

TABLE H

2-Bornanone	Anesthetic, expectorant.
3-diethylcarbamoyl-1-methylpyridinumcamphor sulfonate.	Analeptic, respiratory and circulatory stimulant.
Carbomycin	Antimicrobial.
Cedrin	Antimalarial.
Chlortetracycline	Antimicrobial.
Toximycin	Antimicrobial, antimetabolite.
7-chloro-4-(dimethylamino)-1,4a,5,5a,6,11,12a-penta-hydroxy-N-(hydroxymethyl)-6-methyl-1,11-dioxo-2-naphthacenecarboxamide.	10 Antimicrobial.
Coumingine	Cardiac tonic and stimulant.
7-Chloro-6-demethyltetracycline	Antimicrobial.
Dihydrocodenone	Antitussive, analgesic.
4-(dimethylamino)-1,4a,5,5a,6,11,12a-octahydro-3,5,10,12,12a-penta-hydroxy-6-methyl-1,11-dioxo-2-naphthacenecarboxamide.	15 Antimicrobial.
Erythromycin A	Antimicrobial.
Erythromycin estolate	Do.
Frequentin	Do.
4-methoxy-5-methyl-1- <i>o</i> -phthalaldehyde-3-carboxylic acid.	20 Antifungal antibiotic.
3-hydroxy-11-oxolean-12-en-30-oic acid	Used in treatment of Addison's disease.
Griseofulvin	Antifungal antibiotic.
Isogriseofulvin	Do.
Dihydromorphinone	Analgesic.
Hydrocodene	Do.
14-hydroxycodeineone	Do.
2-(2-hydroxy-1-naphthyl)-cyclohexanone.	25 Antitussive.
1,3,4,6,8,13-Hexahydroxy-10,11-di-methylphenanthrene-1,10,9,8-oxopra]perylene-7,14-dione.	Antidepressant.
5-isopropyl-3-methyl-2-cyclohexene-1-one.	30 CNS stimulant.
5-hydroxy-1,4-naphthoquinone	Antihemorrhagic activity.
4,9-dimethoxy-7-methyl-5-furo [3,2-g] [1]benzopyran-5-one.	Coronary vasodilator, broncho dilator.
2-hydroxy-3-(3-methyl-2-butenyl)-1,4-naphthoquinone.	Antimalarial.
2-hydroxy-3-(9-hydroxy-9-pentyltetradecyl)-1,4-naphthoquinone.	Do.
Lucensomycin	Antifungal agent.
N-lysinoethyltetracycline	Antimicrobial.
2-methyl-1,4-naphthoquinone	Prophylaxis.
Menadione carboxymethoxime ammonium salt.	Do.
4-(dimethylamino)-1,4a,5,5a,6,11,12-octahydro-3,6,10,12,12a-penta-hydroxy-N-[4-(2-hydroxyethyl)-1-piperazinyl]-methyl-6-methyl-1,11-dioxo-2-naphthacenecarboxamide.	35 Antimicrobial.
4-dimethylamino-1,4a,5,5a,6,11,12a-octahydro-3,5,10,12,12a-penta-hydroxy-6-methylene-1,11-dioxo-2-naphthacenecarboxamide.	Do.
Methylidihydromorphonone	Analgesic.
Methymycin	Antimicrobial.
3,3-diethyl-5-methyl-2,4-piperidinedione.	Sedative.
Mikamycin	Antimicrobial.
1-N-allyl-7,8-dihydro-14-hydroxynorphenone.	Narcotic antagonist.
Dihydrohydroxymecidone	Analgesic.
Dihydrohydroxymorphone	Do.
2-hydroxy-3-pinanone	For respiratory insufficiency.
4-(dimethylamino)-1,4a,5,5a,6,11,12a-octahydro-3,5,6,10,12,12a-hexahydro-6-methyl-1,11-dioxo-2-naphthacenecarboxamide.	40 Antimicrobial.
2-(1-cyclopentenyl-1-yl)-2-(2-morpholinoethyl)cyclopentanone.	Antitussive.
Perlivine	Antimetabolite.
Pimarcin	Antimicrobial.
2-(piperidinomethyl)cyclohexanone	Respiratory stimulant.
3,3-diethyl-2,4-dioxopiperidine	Sedative, antitussive.
Prostaglandins (B ₁ , E ₁ , E ₂ , F, PGF etc.)	Smooth muscle stimulant.
3,3',4',5,7-pentahydroxyflavone	Decreases capillary fragility.
N,N-diethylfrimocil B amide	Antimicrobial.
Rifomycin (B, S, O, SB, X, A, G, etc.)	Do.
4-(dimethylamino)-1,4a,5,5a,6,11,12a-octahydro-3,6,10,12,12a-penta-hydroxy-6-methyl-1,11-dioxo-N-(1-pyrrolidinylmethyl)-2-naphthacenecarboxamide.	45 Do.
4-(dimethylamino)-1,4a,5,5a,6,11,12a-octahydro-3,10,12,12a-tetrahydroxy-1,11-dioxo-2-naphthacenecarboxamide.	Do.
Decahydro-4a,7,9-trihydroxy-2-methyl-6,8-bis(methylamino)-4H-pyran[2,3-b] [1,4]benzodioxin-4-one.	50 Do.
Spiramycin (I, II, III, the corresponding acetates, etc.)	Do.
Stepholyomycin (M ₁ , S, etc.)	Do.
Tetracycline	Do.
Thioconchicine	Muscle relaxant.
3-methylcahromone	Antispasmodic, coronary vasodilator.
Viridin	Antifungal agent.
2-methyl-3-phytyl-1,4-naphthoquinone	Prophylaxis.

32

The compounds of Formula II can be prepared by a procedure which can be represented as follows:

In the above formulas, D¹ and R⁴ are as previously defined.

In the above procedure, the ketones of Formula II are reacted with glycerol and dry methyl orthoformate in a suitable inert organic solvent in the presence of perchloric acid to yield the glycerol ketals of Formula III. The latter compounds are then esterified by reaction with a fatty acid in a pyridine solution containing p-toluenesulfonic acid to yield the compounds of Formula III.

Included within Formula III are conjugated ketals of anabolic steroids of Formulas ID, IID, IIID, IVD and 20 VD and exemplary compounds listed in Table D; of corticoid steroids of Formula IE and exemplary compounds listed in Table F supra; and of progestational steroids of Formula IG, IIG, IIIG and IVG and exemplary compounds listed in Table G supra. Also included within 25 Formula III are conjugated ketals of other drug ketones exemplified by the ketones listed in Table H, supra.

The preferred conjugated ketals of steroids of Formula III are derived from steroid ketones (corresponding to Formula II) represented by the formulas by the above procedure.

33

either alone or in conjunction with other medicinal agents or in pharmaceutically acceptable, non-toxic compositions formed by the incorporation of any of the normally employed excipients.

The preferred process for preparing ketal conjugates of 5 ketones of Formula IVJ and certain ketones of Formula VJ can be represented as follows:

34

In the above formulas,

R²⁷⁵, R²⁷⁶, R²⁷⁷ and R²⁷⁸ are as previously defined, and R²⁸³ is a fatty acyl group.

- 20 The 3,3-(3-hydroxymethyl-1,2-propylenedioxy) compounds of Formulas IIK and VK are preferably prepared by reacting the respective 3-keto compounds of Formulas IK and IVK with glycerol and dry methyl orthoformate under nitrogen at room temperature in a suitable inert 25 organic solvent such as diglyme in the presence of perchloric acid. The glycerol ketals of Formulas IIK and VK can be reacted with a fatty acid in a pyridine solution containing p-toluenesulfonic acid to yield the 3,3-[3-(fatty 30 acyloxy)-1,2-propylenedioxy] compounds of Formulas IIIK and VIK.

The other ketal conjugates of ketones of Formula VJ are preferably prepared by a process illustrated as follows:

- 60 in the above formulas,

R²⁷⁹, R²⁸⁰, R²⁸¹, R²⁸², R²⁸³ and Z¹³ are as previously defined.

- 65 The glycerol ketals of Formula VIIIK are prepared by reacting the 3-keto compounds of Formula VIIK with glycerol in a chloroform solution in the presence of p-toluenesulfonic acid at reflux until the reaction is eventually complete, that is, preferably about 36 hours. The glycerol ketals of Formula VIIIK are esterified to form the corresponding fatty esters of Formula IXK by reaction at room 70 temperature with the desired fatty acyl chloride in pyridine which can, if desired, contain additional solvent such as dioxane. Usually from 5 minutes to 1 hour are sufficient 75 for completion of the reaction.

35

The compounds of Formula III can be prepared by a procedure which can be represented as follows:

In the above formulas, D^2 , R^5 and R^6 are as previously defined.

In the above procedure, the compounds of Formula II (suitable protected) are reacted with potassium or sodium isopropylidene glycerate in a mixture of pyridine and a lower alkanol such as ethanol. While the mixture is maintained at a temperature of 0° C. or lower, a solution of p-toluenesulfonyl chloride in pyridine is added, and the mixture is then allowed to warm to room temperature. The compounds of Formula III are then separated from the reaction mixture by conventional techniques such as by diluting the reaction mixture with water to precipitate the product which can be separated by filtration or the like, extraction, crystallization, chromatography and combinations of these techniques.

The isopropylidene ether group is then cleaved by conventional acid treatment such as with a strong mineral or organic acid, e.g. trifluoroacetic acid, to yield the compounds of Formula III.L. These are reacted with the desired fatty acyl chloride or chlorides in an inert organic solvent such as chloroform or carbon tetrachloride in the presence of an organic base such as triethylamine or pyridine followed by conventional purification procedures to yield the compounds of Formula IV.L.

In the above procedure, it may be necessary to protect reactive groups to increase the yield of the desired products, and such conventional procedures can be used as are routinely followed for this purpose.

Included within Formula IVL are conjugates of 2-naphthyl-ethanol derivatives corresponding to Formula IL. Suitable 2-naphthylethanol derivatives which are included within Formula IL have been previously described together with methods for their preparation in U.S. patent application Ser. No. 741,904, filed July 2, 1968. These can be represented by the following formulas:

wherein,

one of R^{302} and R^{303} is hydrogen, the other is hydrogen, methyl, ethyl or difluoromethyl; or R^{302} and R^{303} taken together are methylene, halomethylene or ethylene; R^{304} (at position C-1,4,5,7 or 8) is hydrogen, alkyl, trifluoromethyl, fluoro, chloro, hydroxy, a conventional hydrolyzable ester, oxyether or thioether;

36

R^{305} is alkyl, cycloalkyl, hydroxymethyl, alkoxyethyl, trifluoromethyl, vinyl, ethynyl, fluoro, chloro, hydroxy, a conventional hydrolyzable ester, oxyether, thioether, formyl, acetyl or aryl; and
5 each of R^{306} and R^{307} (at position C-1,4,5,7 or 8) is alkyl, fluoro, chloro, hydroxy, a conventional hydrolyzable ester, oxyether, or thioether; provided that when one of R^{306} and R^{307} is hydroxy, oxyether or thioether, the other is the identical group or alkyl, fluoro, chloro or a conventional hydrolyzable ester.

An especially preferred group of compounds are conjugates of compounds of Formulas IIM, IIM and IIIM including β -[2-naphthyl]-ethanol, β -[2-naphthyl]- β -methylethanol, β -[2-naphthyl]- β -difluoromethyl-ethanol, β -[2-naphthyl]- β,β -methyleneethanol, β -[2-naphthyl]- β,β -difluoromethylenethanol and the C-5, 6- or 7-methyl, -fluoro, -cholo, trifluoromethyl, -methoxy and -methyl thio derivatives thereof.

When one of R^{302} and R^{303} is hydrogen and the other is methyl, ethyl or difluoromethyl, the compounds of Formulas IIM, IIIM and IIIIM can exist as pairs of enantiomorphs. Conjugates of each of the optical isomers thereof are included within the present invention. In some instances, one conjugated enantiomorph exhibits greater antiinflammatory, analgesic, anti-pyretic and/or anti-pruritic activity than the other conjugated enantiomorph. For example, conjugates of the levorotatory form, the 1 or (–) form, of β -(6-methoxy-2-naphthyl)- β -methylethanol exhibits greater anti-inflammatory activity than conjugates of the corresponding dextrorotatory form.

Preferably, the resolved compounds of Formulas IIM, IIIM and IIIIM can be prepared from the corresponding resolved acid starting compounds used to prepare the compounds of Formulas IM, IIM and IIIM. The resolved compounds of Formulas IM-IIIM and their respective resolved starting compounds will not necessarily have the same optical rotation although they will have the same absolute configuration. For example, 1 β -(6-methoxy-2-naphthyl)- β -methyl ethanol is prepared from d 6-methoxy-2-naphthyl- α -methyl acetic acid.

The conjugates of the compounds of Formulas IIM, IIIM and IIIM exhibit anti-inflammatory, analgesic, anti-pyretic and anti-pruritic activity in mammals. These conjugates are useful in the treatment of inflammation of the skin, respiratory tract, muscular skeletal system, joints, internal organs and tissues. Accordingly, these compounds are useful in the treatment of conditions characterized by inflammation, such as contact dermatitis, allergic conditions, burns, rheumatism, contusion, arthritis, bone fracture, post-traumatic conditions and gout. In those cases in which the above conditions include pain, pyrexia, and pruritus, coupled with the inflammation, the instant compounds are useful for relief of these conditions as well as the inflammation. For example, the instant compounds are useful in the treatment of pain associated with post-operative conditions, post-traumatic conditions, post-partum conditions, dysmenorrhea, burns, gout, contusions, neuralgia, neuritis, headaches and rheumatic fever. As stated above, these compounds also exhibit anti-pyretic activity, accordingly, these compounds are useful in the treatment of pyrexia where reduction of a fever is indicated, for example, cases where high fever is associated with diseases such as rheumatic fever, bronchitis, pneumonia, typhoid fever, Hodgkin's disease, and the like. The present compounds are also useful in the treatment of pruritus where the condition exists contemporaneously with inflammation, pain and/or high fever. Moreover, the compounds are useful for treating pruritus per se.

The compounds of Formulas IIM, IIIM and IIIM are prepared from the corresponding 2-naphthyl acetic acid derivatives or esters thereof (described supra Formulas 75

37

IA-VIIIA) via a process which can be illustrated as follows:

In the above formulas,

R³⁰² and R³⁰³ are as defined above and R³¹¹ is hydrogen or alkyl. In the above scheme, the naphthyl moiety of the compounds of Formula VIM, naphthyl acetic acid derivatives and esters thereof, and the naphthyl moiety of the compounds of Formula VIIM, β -[2-naphthyl] ethanol derivatives, can be substituted with an R³⁰³ group at position C-1,4,5,7 or 8; or an R³⁰⁴ group at position C-6 or an R³⁰⁵ group at position C-6 and an R³⁰⁶ group at position C-1,4,5,7 or 8 corresponding to these groups as described with respect to Formulas IM, IIM, and IIIM, supra.

The process is conducted by treating the compound of Formula VIIM with lithium aluminum hydride. If the free carboxylic acid form of the compound of Formula VIM (wherein R³¹¹ is hydrogen) is used as a starting material, at least 0.75 molar equivalents of lithium aluminum hydride are used, and preferably about 1.0 to 2.5 molar equivalents are used. If the ester form of the compound of Formula VIM (wherein R³¹¹ is alkyl) is used as a starting material, at least 0.5 molar equivalents of lithium aluminum hydride are used, and preferably about 0.6 to 2.0 molar equivalents are used. The novel process is carried out in an inert organic ether, such as diethyl ether, dipropyl ether disopropyl ether, dibutyl ether, tetrahydrofuran, or the like. The reaction is carried out at a temperature between 0° C. and the boiling point of the solvent employed, preferably between 15° C. to 35° C.

The compound of Formula VIIM is isolated by destroying the excess lithium aluminum hydride, if any, such as by the addition of excess ethyl acetate, or aqueous solutions of sodium hydroxide or ammonium chloride. The mixture is then diluted with water, filtered and extracted with an inert organic solvent immiscible with water. The compound of Formula VIIM can be further purified by standard techniques, such as crystallization, chromatography, etc.

Alternatively, the compounds of Formula VIM can be reduced by treating them with diborane in tetrahydrofuran at a temperature between about 0° C. and about 65° C.

Certain groups present on the starting compound of Formula VIM are reduced by lithium aluminum hydride or diborane. For example, an acetyl group is reduced to an α -hydroxy ethyl group and a formyl group is reduced to a hydroxy methyl group. These reduced groups are regenerated after completion of the above novel process via an oxidation process using manganese dioxide (active) in an inert organic solvent, such as acetone, petroleum ether, and the like, at about room temperature.

When a resolved enantiomorph of Formula VIM is employed as starting material in the above process, the corresponding resolved enantiomorph of Formula VIIM is obtained. As stated above, although the absolute configuration of the 2-naphthyl acetic acid starting compound and the corresponding β -[2-naphthyl]-ethanol product will be identical, the optical rotation of the starting compound and product will not necessarily be the same.

Representative conjugates of 2-naphthylethanol derivatives of Formula IVL can be prepared as described above from the following exemplary 2-naphthylethanol derivatives corresponding to Formulas IM, IIM and IIIM.

38

- β -(1-methoxy-2-naphthyl) ethanol,
 β -(4-difluoromethylthio-2-naphthyl)- β -methylethanol,
 β -(5-methylthio-2-naphthyl)- β -methylethanol,
 β -(5-chloro-2-naphthyl) ethanol,
5 β -(5-trifluoromethyl-2-naphthyl)- β , β -difluoromethyleneethanol,
 β -(6-fluoro-2-naphthyl)- β -methylethanol,
 β -(6-methyl-2-naphthyl) ethanol,
 β -(6-methoxy-2-naphthyl) ethanol,
10 β -(6-difluoromethoxy-2-naphthyl)- β -difluoromethyleneethanol,
 β -(6-methoxy-2-naphthyl)- β -ethylethanol,
 β -(6-chloro-2-naphthyl)- β -methylethanol,
 β -(7-methoxy-2-naphthyl)- β -methylethanol,
15 β -(7-methylthio-2-naphthyl)- β -ethylethanol,
 β -(7-chloro-2-naphthyl)- β , β -methylenethanol,
 β -(8-trifluoromethyl-2-naphthyl)- β , β -methylenethanol,
 β -(5,6-dimethyl-2-naphthyl)- β -methylethanol,
 β -(5-methoxy-2-naphthyl)- β -methylethanol,
 β -(5-methyl-2-naphthyl)- β -methylethanol,
20 β -(5-fluoro-2-naphthyl)- β -ethylethanol,
 β -(5-methoxy-2-naphthyl) ethanol,
 β -(6-methyl-2-naphthyl)- β -methylethanol,
 β -(6-chloro-2-naphthyl)- β -difluoromethyleneethanol,
25 β -(6-methylthio-2-naphthyl)- β , β -methylenethanol,
 β -(6-trifluoromethyl-2-naphthyl)- β -methylethanol,
 β -(7-methyl-2-naphthyl)- β -methylethanol,
 β -(7-fluoro-2-naphthyl) ethanol,
 β -(7-trifluoromethyl-2-naphthyl)- β -methylethanol,
30 β -(1-chloro-2-naphthyl)- β -ethylethanol,
 β -(4-ethoxy-2-naphthyl)- β , β -ethylenethanol,
 β -(6,7-dimethoxy-2-naphthyl)- β -methylethanol,
 β -(8-hydroxy-2-naphthyl)- β -ethylethanol,
 β -(1-trifluoromethyl-2-naphthyl)- β , β -ethylenethanol,
35 β -(4-acetoxy-2-naphthyl)- β , β -difluoromethyleneethanol,
 β -(5-methoxymethoxy-2-naphthyl)- β -ethylethanol,
 β -(5-isopropyl-2-naphthyl) ethanol,
 β -(6-vinyl-2-naphthyl)- β -methylethanol,
40 β -(6-acetyl-2-naphthyl) ethanol,
 β -(7-acetoxy-2-naphthyl)- β -difluoromethyleneethanol,
 β -(7-ethyl-2-naphthyl)- β -ethylethanol,
 β -[8-(4'-methoxytetrahydropyran-4'-yloxy)-2-naphthyl]- β -methylethanol, and
45 β -(6,7-dimethyl-2-naphthyl)- β -methylethanol.

Included within Formula IVL are conjugates of steroid alcohols corresponding to Formula IL. Suitable steroid alcohols are described together with methods for their preparation in U.S. patent applications Ser. No. 731,300, filed May 22, 1968; Ser. No. 731,301, filed May 22, 1968, and Ser. No. 731,267, filed May 22, 1968, and U.S. Pat. Nos. 3,365,446; 3,067,194 and 3,364,203.

Representative anabolic steroids corresponding to Formula IL can be represented by the following formulas:

TABLE J

1 β -(6-methoxy-2-naphthyl)- β -methylethanol,

75

wherein

R^{410} , R^{411} , R^{413} , R^{415} , R^{422} and R^{423} each is hydrogen or methyl (preferably one of R^{422} and R^{423} is methyl);

R^{412} is hydrogen or lower alkyl;

R^{414} is hydrogen or chloro;

R^{416} is lower alkyl or lower cycloalkyl;

R^{417} is methyl or ethyl;

R^{419} , R^{420} and R^{425} each is hydrogen, methyl, fluoro, or chloro; and R^{420} is not present when Z^{24} is a double bond;

X^3 is keto or α -hydrogen together with β -X, β -hydrogen, or β -hydroxy, and conventional hydrolyzable esters thereof;

X^4 is hydroxy, or conventional hydrolyzable esters thereof; and at least one of X^3 and X^4 is hydroxy; and

Z^{24} and Z^{26} each is a single bond or double bond.

The conjugates of compounds represented by Formulas IN-VIN are anabolic agents with a favorable anabolic: androgenic ratio, also possess anti-estrogenic, anti-gonadotropic, and anti-fibrillatory activities, and can be used for the same purposes as testosterone. These conjugates are preferably administered orally but can be administered by other routes such as parenterally. These conjugates are administered either alone or in conjunction with other medicinal agents, or in pharmaceutically acceptable, non-toxic compositions formed by the incorporation of any of the normally employed excipients.

Representative anabolic steroid conjugates of Formula IVL according to this invention can be prepared from the following exemplary alcohols as described above.

 17 α -ethyl-18-methyl-19-norandrosta-4,9(10),11-triene-3 β ,17 β -diol,
 17 α -ethyl-19-norandrosta-4,9(10),11-triene-3 β ,17 β -diol,
 17 α -propyl-18-methyl-19-norandrosta-4,9(10),11-triene-3 β ,17 β -diol,
 17 α -propyl-19-norandrosta-4,9(10),11-triene-3 β ,17 β -diol,
 17 β -acetoxy-19-norandrosta-4,9(10)-dien-3 β -ol,
 17 α -propyl-17 β -acetoxy-18-methyl-19-norandrosta-4,9(10)-dien-3 β -ol,
 17 β -acetoxy-19-norandrosta-4,9(10)-dien-3 β -ol,

42

17 β -acetoxy-18-methyl-19-norandrosta-4,9(10)-dien-3 β -ol,
 17 α -methyl-17 β -acetoxy-19-norandrosta-4,9(10)-dien-3 β -ol,
 5 17 α ,18-dimethyl-17 β -acetoxy-19-norandrosta-4,9(10)-dien-3 β -ol,
 17 α -ethyl-17 β -acetoxy-19-norandrosta-4,9(10)-dien-3 β -ol,
 10 17 α -ethyl-17 β -acetoxy-18-methyl-19-norandrosta-4,9(10),11-trien-3 β -ol,
 17 β -acetoxy-19-norandrosta-4,9(10),11-trien-3 β -ol,
 17 α -methyl-17 β -acetoxy-19-norandrosta-4,9(10),11-trien-3 β -ol,
 15 17 α ,18-dimethyl-17 β -acetoxy-19-norandrosta-4,9(10),11-trien-3 β -ol.

Representative corticoid steroids corresponding to Formula IIO can be represented by the following formulas:

wherein

R⁴³⁰ is hydrogen, methyl, fluoro, or chloro and when Z²³ is a single bond, R⁴³⁰ can be either α or β oriented;
 R⁴³¹ is hydrogen, chloro, or fluoro;
 R⁴³² is keto or

40 wherein R^{432(a)} is hydroxy, chloro, or fluoro;
 R⁴³³ is hydrogen, methyl, hydroxy, or conventional hydrolyzable esters thereof;
 R⁴³⁴ is hydrogen, hydroxy, conventional hydrolyzable esters thereof, or when taken together with R⁴³³

50 R⁴³⁵ is hydrogen or alkyl of up to eight carbons;
 R⁴³⁶ is hydrogen, alkyl, or an aryl group of up to eight carbons;
 R⁴³⁷ is hydrogen, methyl, phenyl, chlorophenyl, fluoro-
 55 phenyl, methylphenyl, or methoxyphenyl (the substituted phenyls preferably being substituted in the para position);
 Z²² and R²³ each is a single bond, double bond, or

60 65 wherein each of R⁴⁶⁷ and R⁴⁶⁸ is hydrogen, chloro or fluoro.

The conjugates of the compounds represented by Formulas IO and IIO have corticoid activity and are accordingly useful as anti-inflammatory agents. They are useful in the same manner for the same purposes as hydrocortisone. These compounds are preferably administered orally. However, they can be administered by other routes, e.g. parenterally, or topically. They can be administered either alone or in conjunction with other medicinal agents, or in pharmaceutically acceptable non-toxic com-

positions formed by the incorporation of any of the normally employed excipients.

Representative corticoid steroid conjugates corresponding to Formula IVL can be prepared from exemplary alcohols listed in Table E, supra, and from the following alcohols by the above procedure.

TABLE L

9 α -chloro-11 β ,21-dihydroxypregna-4,6-diene-3,20-dione, 1 α ,2 α -methylene-9 α -fluoro-17 α -acetoxy-21-hydroxypregna-4,6-diene-3,20-dione, 1 α ,2 α -fluoromethylene-6 α -methyl-16 α ,17 α -methylphenylmethylenedioxy-21-hydroxypregn-4-ene-3,20-dione, 6,16 α -dimethyl-21-hydroxypregna-4,6-diene-3,20-dione, 6,7-(2'',2''-difluorocyclopropenyl)-21-hydroxypregn-4-en-11 β -ol-3,20-dione, 11 β ,17 α ,21-trihydroxy-4-enol[3,2-c]-2''-(4''-fluorophenyl)-pyrazole-6 α ,9 α -difluoro-16 α -methylpregn-20-one, 11 β ,17 α ,21-trihydroxy-4-enol[3,2-c]-2''-(4''-fluorophenyl)-pyrazole-6 α ,16 α -dimethyl-9 α -fluoropregn-6-en-20-one, 11 β ,17 α ,21-trihydroxy-4-enol[3,2-c]-2''-(4''-fluorophenyl)-pyrazole-9 α -fluoro-16 α -methylpregna-20-one, 11 β ,21-dihydroxy-4-enol[3,2-c]-2''-(4''-fluorophenyl)-pyrazole-6 α ,9 α -fluoro-16 α ,17 α -isopropylidenedioxy-20-one, 11 β ,17 α ,21-trihydroxy-4-enol[3,2-c]-2''-(4''-fluorophenyl)-pyrazole-6 α ,7 α -difluoromethylene-16 α -methylpregna-20-one, and 11 β ,17 α ,21-trihydroxy-4-enol[3,2-c]-2''-phenylpyrazole-6 α -methylpregna-20-one.

Representative estrogenic steroids corresponding to Formula IL can be represented by the following formula:

wherein

R⁴⁰¹ is hydrogen, methyl, methoxy, hydroxyl or conventional hydrolyzable esters thereof;

R⁴⁰² is hydrogen or methyl; and when Z²⁰ is a single bond, R⁴⁰² can be alpha or beta oriented;

R⁴⁰³ is hydrogen, hydroxy or conventional hydrolyzable esters thereof (e.g. lower acyloxy or lower cycloacetyl oxy groups) when Z²⁰ is a single bond and is hydrogen when Z²⁰ is a double bond;

R⁴⁰⁵ is hydrogen, a lower alkyl group, such as methyl, ethyl, propyl, and the like, a lower alkenyl group, such as vinyl and the like, or a lower alkynyl (including halo lower alkynyl with a halogen, such as fluoro, chloro or bromo), such as ethynyl, fluoroethynyl, chloroethynyl, bromoethynyl, propynyl, trifluoropropynyl, butynyl, hexynyl, and the like, or

R⁴⁰⁶ is methyl or ethyl;

X¹ and X² each is hydrogen, hydroxy or conventional hydrolyzable esters thereof, lower alkoxy, lower cycloalkoxy, lower cycloalkenyl, tetrahydropyran-2'-yloxy, 4'-(lower)alkoxytetrahydropyran-4'-yloxy, or X² and R⁴⁰⁵ together can be keto; and at least one of X¹ and X² is hydroxy; and Z²⁰ is a single or double bond.

The conjugates of the compounds of Formula IP of this invention have high oral anti-fertility and estrogenic ac-

tivity. These compounds can also be used parenterally in the same manner and dosage as estradiol, but are preferably administered orally. Then they are used in the same manner as ethylenestradiol. The conjugates of this invention can be administered in any of the number of conventional pharmaceutical forms, and particularly in ones suited for oral administration, e.g. in solid form, such as in pills, powders, capsules, tablets, or the like, or in liquid form, such as syrups, emulsions, suspensions, and the like.

Representative estrogenic steroid conjugates corresponding to Formula IVL can be prepared from the following alcohols by the above procedure.

TABLE M

- 15 estra-1,3,5(10)-trien-3-ol-17 β -one, 3-hydroxy-7 α -methylestra-1,3,5(10)-trien-17 β -one, 3-hydroxy-18-methylestra-1,3,5(10)-trien-17 β -one, 1-methyl-3-hydroxyestra-1,3,5(10)-trien-17 β -one, 3-hydroxyestra-1,3,5(10)-trien-16 α -ol-17 β -one, 20 estra-1,3,5(10)-triene-1,3-diol-17 β -one, estra-1,3,5(10)-7-tetraen-3-ol-17 β -one, estra-1,3,5(10)-triene-3 β ,17 β -diol, estra-1,3,5(10)-7-tetraen-3,17 β -diol, 17 α -methylestra-1,3,5(10)-triene-3,17 β -diol, 25 17 α -methylestra-1,3,5(10)-7-tetraene-3,17 β -diol, 17 α -vinylestra-1,3,5(10)-triene-3,17 β -diol, 17 α -vinylestra-1,3,5(10)-7-tetraene-3,17 β -diol, 17 α -ethynylestra-1,3,5(10)-triene-3,17 β -diol, 17 α -ethynylestra-1,3,5(10)-7-tetraene-3,17 β -diol, 30 17 α -chloroethynylestra-1,3,5(10)-triene-3,17 β -diol, 17 α -chloroethynylestra-1,3,5(10)-7-tetraene-3,17 β -diol, 17 α -(2'',2''-difluorocyclopropenyl)-estra-1,3,5(10)-triene-3,17 β -diol, 17 α -(2'',2''-difluorocyclopropenyl)-estra-1,3,5(10)-7-tetraene-3,17 β -diol, 35 17 α -propadienylestra-1,3,5(10)-triene-3,17 β -diol, 3-methoxy-17 α -propadienylestra-1,3,5(10)-trien-17 β -ol, 18-methylestra-1,3,5(10)-triene-3,17 β -diol, 40 estra-1,3,5(10)-triene-3,16 α ,17 β -triol, 7 α -methylestra-1,3,5(10)-triene-3,17 β -diol, 1-methylestra-1,3,5(10)-triene-3,17 β -diol, estra-1,3,5(10)-triene-1,3,17 β -triol, 3-methoxyestra-1,3,5(10)-triene-17 β -ol, 3-cyclopenoxy-18-methylestra-1,3,5(10)-trien-17 β -ol, 45 estra-1,3,5(10)-triene-3,17 β -diol, 3-tetrahydropyran-2'-yloxyestra-1,3,5(10)-trien-17 β -ol, 3-tetrahydropyran-2'-yloxy-18-methylestra-1,3,5(10)-trien-17 β -ol, 3-acetoxy-17 β -hydroxy-17 α -(2'',2''-difluorocyclopropenyl)-estra-1,3,5(10)-triene, 50 3-acetoxy-17 β -hydroxy-18-methylestra-1,3,5(10)-triene, 3,16 α -diacetoxy-17 β -hydroxyestra-1,3,5(10)-triene, 3-acetoxy-17 β -hydroxy-17 α -ethynylestra-1,3,5(10)-triene, 3-acetoxy-17 β -hydroxy-17 α -ethynyl-18-methylestra-1,3,5(10)-triene, 55 3-acetoxy-7 α -methyl-17 β -hydroxyestra-1,3,5(10)-triene, 17 β -hydroxy-1-methyl-3-acetoxyestra-1,3,5(10)-triene, 1,3-diacetoxy-17 β -hydroxyestra-1,3,5(10)-triene, 60 1,3-diacetoxy-17 β -hydroxy-17 α -ethynylestra-1,3,5(10)-triene, 17 β -hydroxy-3-methoxy-17 α -ethynylestra-1,3,5(10)-triene, 65 17 β -hydroxy-3-methoxyestra-1,3,5(10)-triene, 17 β -hydroxy-3-methoxy-17 α -chloroethynylestra-1,3,5(10)-triene, 3-cyclopentyloxy-17 β -hydroxyestra-1,3,5(10)-triene, 70 3-cyclopentyloxy-17 β -hydroxy-18-methylestra-1,3,5(10)-triene, 3-cyclopentyloxy-17 β -hydroxy-17 α -ethynylestra-1,3,5(10)-triene, 3-cyclopentyloxy-17 β -hydroxy-17 α -ethynyl-18-methylestra-1,3,5(10)-triene,

45

3-benzoyloxy-17 β -hydroxyestra-1,3,5(10)-triene,
3-tetrahydropyran-2'-yloxy-17 β -hydroxyestra-1,3,5(10)-
triene, and
3-tetrahydropyran-2'-yloxy-17 β -hydroxy-18-methylestra-
1,3,5(10)-triene.

Representative progestational steroid corresponding to
Formula IL can be represented by the following formulas:

wherein

R⁴¹³ is hydrogen or methyl;

R⁴¹⁶ is lower alkyl or lower cycloalkyl;

R⁴¹⁷ is methyl or ethyl;

R⁴¹⁸ is lower alkenyl, such as vinyl and propenyl, lower alkynyl (including lower haloalkynyl with a halogen, such as fluoro, chloro, or bromo), such as ethynyl, fluoroethynyl, chloroethynyl, propynyl, trifluoropropynyl, and the like, and

wherein

R⁴¹⁹ and R⁴²⁰ each is hydrogen, chloro, or fluoro;

R⁴²¹, R⁴²² and R⁴²⁵ each is hydrogen, methyl, fluoro, or chloro;

in Formula IIQ when Z²⁴ is a double bond, R⁴²⁰ is absent; in Formula VQ when Z²⁵ is a single bond, R⁴¹⁹ can have either an α or β orientation;

R⁴³⁶ and R⁴³⁷ each is hydrogen or, taken together, a methylene group having the formula

wherein

R⁴³⁸ and R⁴³⁹ each is hydrogen, chloro or fluoro;

R⁴⁴⁰ is keto or

46

wherein R⁴⁴¹ is hydrogen, chloro, or hydroxyl; and when R⁴⁴¹ is hydrogen, R⁴¹³ and R⁴⁴² is hydrogen; R⁴⁴² is hydrogen, chloro, or fluoro; R⁴⁴³ is methylene,

5

wherein R⁴⁴⁴ and R⁴⁴⁵ each is hydrogen or methyl, or taken together with R⁴⁴⁸ is

wherein

R⁴⁴⁶ and R⁴⁴⁷ each is hydrogen, alkyl, or aryl, the latter two groups having up to eight carbons;

R⁴⁴⁸ is hydrogen, hydroxyl, or conventional hydrolyzable esters thereof;

R⁴⁴⁹ is hydrogen or fluoro;

X³ is keto,

20

wherein R⁴⁵⁰ is hydrogen, hydroxy, or conventional hydrolyzable esters thereof;

R⁴⁵¹ is hydroxy, or conventional hydrolyzable esters thereof; and at least one of X³ and X⁴ in Formulas IIQ, IIIQ and IVQ is hydroxy;

Z²⁴ and Z²⁶ each is a single bond or double bond; and Z²⁵ is a single bond, double bond, or a single bond in combination with a methylene group having the formula

30

wherein R⁴⁵¹ and R⁴⁵² each is hydrogen, chloro or fluoro.

The conjugates of the compounds represented by Formulas IQ-VQ, inclusive, are progestational agents useful in the treatment of menstrual disorders and fertility control and can be used for the same purposes as 17 α -acetoxyl-6-chloropregna-4,6-diene - 3,20 - dione (chloromadione acetate). The 16-methylene species are particularly useful in estrus synchronization in domestic animals. These conjugates are preferably administered orally but

they can also be administered by other routes, e.g. parenterally. The conjugates are administered either alone or in conjunction with other medicinal agents, or in pharmaceutically acceptable, non-toxic compositions formed by the incorporation of any of the normally employed excipients.

Representative progestational steroid conjugates corresponding to Formula IVL can be prepared from the following exemplary alcohols by the above procedure:

TABLE N

- 55 3-methoxy-17 α -ethynylandrosta-3,5-dien-17 β -ol,
3-methoxy-17 α -ethynyl-18-methylandrosta-3,5-dien-
17 β -ol,
3-propoxy-17 α -ethynylandrosta-3,5-dien-17 β -ol,
60 3-cyclopropoxy-17 α -ethynylandrosta-3,5-dien-17 β -ol,
3-ethoxy-17 α -ethynylandrosta-3,5-dien-17 β -ol,
3-cyclopentoxy-17 α -ethynylandrosta-3,5-dien-17 β -ol,
3-cyclobutoxy-17 α -ethynylandrosta-3,5-dien-17 β -ol,
3-methoxy-17 α -methylethynylandrosta-3,5-dien-17 β -ol,
65 3-methoxy-17 α -fluoroethynylandrosta-3,5-dien-17 β -ol,
3-methoxy-17 α -chloroethynylandrosta-3,5-dien-17 β -ol,
3-methoxy-17 α -ethynyl-19-norandrosta-3,5-dien-17 β -ol,
3-cyclopentoxy-17 α -ethynyl-19-norandrosta-3,5-dien-
17 β -ol,
70 3-cyclopentoxy-17 α -ethynyl-18-methyl-19-norandrosta-
3,5-dien-17 β -ol,
3-methoxy-17 α -ethynyl-18-methyl-19-norandrosta-
3,5-dien-17 β -ol,
3-ethoxy-17 α -ethynyl-18-methyl-19-norandrosta-
75 3,5-dien-17 β -ol,

3-methoxy-17 α -vinyl-18-methyl-19-norandrosta-3,5-dien-17 β -ol,
3-methoxy-17 α -(2",2"-difluorocyclopropenyl)-18-methyl-19-norandrosta-3,5-dien-17 β -ol,
pregn-4-en-3 β -ol-20-one,

17 α -vinyl-17 β -acetoxy-19-norandrosta-4,9(10),11-trien- β -ol.

Other conjugates corresponding to Formula IVL can be prepared from the following alcohols (corresponding to Formula IL in the above preparation procedure) by the above procedure. The utility of the conjugates are also indicated.

TABLE O

3-(α -acetonyl-p-nitrobenzyl)-4-hydroxycoumarin.	Anticoagulant.
4-acetamido-2-methyl-1-naphthol.	Prophylaxis and treatment of hypoprothrombinemia.
4'-Hydroxyacetanilide.	Analgesic, antipyretic.
N-Acetyl-4-hydroxy-m-arsanilic acid diethylamine salt.	Antisypilitic.
10-[3-(4-(2-hydroxyethyl)-1-piperazinyl-propyl)phenothiazin-2-yl methyl ketone.	Tranquilizer.
9-aminoacridinium 4-hexyl-resorcinolate.	Antimicrobial.
m-Hydroxybenzylidenehydrazide.	Antimycobacterial, in tuberculosis.
Actinorhodine.	Antimicrobial.
Adenosine 5'-triphosphoric acid.	Produces coronary dilation hypotension.
3'-Adenylic acid.	Do.
5'-Adenylic acid.	Do.
Agaricic acid.	Anhidrotic.
Ajmaline.	Hypotensive, tranquilizer, sedative.
L-2-amino-3-(N-nitroso)-hydroxyl-aminopropionic acid.	Antimicrobial.
1H-pyrazolo[3,4-d]pyrimidin-4-ol.	Uricosuric agent.
1-N-allyl-3-hydroxymorphinan.	Narcotic antagonist.
5-allyl-5-(2-hydroxypropyl)-barbituric acid.	For vasomotor headache.
Amicetin.	Antimicrobial.
1-(m-hydroxyphenyl)-2-aminoethanol.	Sympathomimetic vaso-pressor. For iodine therapy in thyrotoxicosis.
β -Amino-4-hydroxy-3,5-diiodohydrocinnamic acid.	Antitrichomonal, antibiotic.
p-Aminosalicylic acid hydrazide.	Antituberculous agent.
Ammonium salicylate.	Anaesthetic, antipyretic.
4-(7-chloro-4-quinolylamino)- α -diethylamino-o-cresol.	Antimalarial.
3-diethylamino-2,2-dimethylpropyl tropate phosphate.	Anticholinergic.
3-ethoxy-N, N-diethyl-4-hydroxybenzamide.	Analeptic.
2,3,3a,3b,4,5,5a,6,10,10a,10b,11,12,12a-tetradecahydro-1,10,12a-tri-methyl-1H-cyclopenta[7,8]-phenanthro[2,3-c]isoxazol-1-ol.	Anabolic agent.
cis-2-methyl-2-butenoic acid.	Sedative.
2-p-methoxyphenylmethyl-3-acetoxy-4-hydroxypyridolide.	Antitrichomonal, antibiotic.
5,10,11,11a-tetrahydro-9,11-dihydroxy-8-methyl-5-oxo-1H-pyrido[2,1-c][1,4]-benzodiazepin-2-acrylamide.	Antimicrobial activity.
1,2,10-anthracenetriol.	Parasiticide.
Apocodeine.	Expectorant, emetic, hypnotic, cathartic.
4-hydroxy-3-methoxyacetophenone.	Used like digitalis.
Apomorphine.	Emetic expectorant.
p-Hydroxyphenyl- β -D-glucopyranoside.	Diuretic, urinary antiseptic
p-Stibonobenzoic acid methyl 1,2,5,6-tetrahydro-1-methylnicotinate.	Anthelmintic.
p-Acetamidobenzeneearsonic acid.	Antisypilitic.
p-Amino benzeneearsonic acid.	Growth stimulator in chicks and turkeys.
4',4'-arsenobis(2-aminophenol) dihydrochloride.	Antisypilitic.
3-acetamido-4-hydroxydithiobenzeneearsonic acid, cyclic(hydroxymethyl) ethylene ester.	Amebicidie.
3'-(5-butyl-2,4-dihydroxy-3,3-dimethyl-6-oxo-1,4-cyclohexadien-1-yl) methyl-2',4'-dihydroxy-6'-methoxy-5'-methylbutyrophene.	Anthelmintic.
2',6'-dihydroxy-4'-methoxy-3'-methyl-1-butyrophene.	Do.
Atranorin.	Antimicrobial.
Atropine.	Anticholinergic.
Atropine N-oxide.	Do.
Aurothioglucose.	Antiarthritic.

TABLE O—Continued

17 β -[3-(dimethylamino)-propyl]methylamino androst 5-en-3 β -ol.	Hypocholesteremic agent.
6-azauridine.	Antimetabolite.
5	Antimicrobial.
D-(-)threo-2-azido-N-[β -hydroxy- α -(hydroxymethyl)-p-nitrophenethyl]acetamide.	Antidiarrheal, sudorific.
5,6,7-Trihydroxyflavone.	Peripheral vasodilator.
α -(Butylamino)methyl-p-hydroxybenzyl alcohol.	Antispasmodic, vasodilator.
8-benzyl-7-[2-[ethyl(2-hydroxyethyl)amino]ethyl]-thiophylline.	Antimalarial.
10	Schistosomicide.
d-Bebeerine.	Analgesic.
1-[2-[ethyl(2-hydroxy-2-methylpropyl)amino]ethyl]-4-methylthio xanthen-9-one.	Thiamine deficiency.
4-(m-hydroxyphenyl)-1-methyl isonipetic acid ethyl ester.	Antituberculous agent.
S-benzyl-1-thiaminemonophosphate.	For increased capillary fragility.
15	Estrogenic hormone therapy.
2-ethyl-3-benzofuranyl 4-hydroxy-3,5-diolophenyl ketone.	Anticholinergic.
3-ethyl-2,4-bis(p-hydroxyphenyl)-hexane.	Coronary vasodilator.
1,1-diethyl-3-hydroxypyrrolidinium bromide benzilate.	Anticholinergic.
2-ethyl-3-benzofuranyl 4-hydroxy-3,5-diolophenyl ketone.	Anticholinergic.
Diethylmethyl(2-N-methylbenzilamidoethyl)ammonium chloride.	Analgesic.
Benzylmorphine.	Amebicidie.
6,6'-diallyl- α , α -bis(dieethylamino)-4,4'-bi-o-cresol.	Antimetabolite.
N,N-bis(2-hydroxyethyl)-p-nitroaniline.	Sedative, thyroid depressant.
25	Diuretic activity.
1,10-dimethoxy-2,9-dihydroxyamorphine.	Vascular relaxant, cardiac stimulant.
Bradykinin.	Sedative.
1-bromo-3-methyl-1-pentyn-3-ol.	Antituberculous agent.
5-bromosalicylylhydroxamic acid.	Used for arthritides.
30	Muscular tremors, vestibular nystagmus.
Bulbocapnine.	Anticonvulsant, tranquilizer.
2-hydroxyethyl benzylcarbamate.	Avian coccidiostat.
4-hydroxy-6,7-disobutoxy-3-quinoline-carboxylic acid ethyl ester.	Ganglion blocking agent, antispasmodic.
N-butylscopolammonium bromide.	Antithyroid agent.
35	Anti-inflammatory agent.
Cafestrol.	Milk fever of cattle.
Calcium diborogluconate.	Hematinic.
Ferrous calcium citrate.	Skeletal muscle relaxant.
Cstrychnotoxin.	As digitalis.
Calotropin.	Analeptic.
N-(β -hydroxy- α -methylphenyl)-N-methyl-10- α -camphorsulfonamide.	Antimicrobial.
41	Analgesic.
1-[2-(2-hydroxyethoxy)ethyl]-4-phenyl-isopropionic acid ethyl ester.	Antimicrobial.
Carbomycin.	Antiarthritic.
2-(3-carboxy-4-hydroxyphenyl)-cynoh-ninic acid.	Tranquilizer.
1-[10-(3-(2-hydroxyethyl)-1-piperazinyl)propyl]phenoxythiazin-2-yl]-1-propanone.	As digitalis.
45	In cataract treatment.
2-p-cymenol; 2-hydroxy-p-cymene.	Anthelmintic.
Cassaine.	Do.
1-hydroxy-5-oxo-5H-pyrido[3,2-a]phenoxazine-3-carboxylic acid.	Antimalarial.
Cedrin.	Antimicrobial.
Celesticetin.	As digitalic.
50	Cardiotonic.
Cerberin.	Antimicrobial, antimycobacterial.
Thevetin B.	Smooth muscle depressant.
Chartreusin.	Antitussive.
Chelidoline.	Antimicrobial.
2-chloro- α -(2-dimethylaminoethyl)benzyl hydroxyl.	As digitalic.
55	Cardiotonic.
2,2,2-trichloro-1,1-ethanediol.	Sedative.
D-(-)threo-2,2-dichloro-N-[β -hydroxy- α -(hydroxymethyl)-p-nitrophenethyl]acetamide.	Antimicrobial.
D(-)threo-2-(dichloroacetamido)-1-(p-nitrophenyl)-3-pantothenyl-1-propanone.	Do.
2,2-Dichloro-N-(2,4-dichlorobenzyl)-N-(2-hydroxyethyl)acetamide.	Used like digitalis.
2-methyl-4-(2,2,2-trichloro-1-hydroxyethoxy)-2-pentanol.	Hypnotic.
1,1,1-trichloro-2-methyl-2-propanol.	Sedative.
3-(p-chlorophenoxy)-2-hydroxypropyl carbamate.	Skeletal muscle relaxant.
7-chloro-4-dimethylamino-1,4a,5,5a,6,11,12a-octahydro-3,6,10,12,12a-penta-hydroxy-6-methyl-1,11-dioxo-2-naphthacene carboxamide.	Antimicrobial.
2-chloro-5-(1-hydroxy-3-oxo-1-isooindolinyl)benzenesulfonamide.	Diuretic, antihypertensive.
5-chloro-2-benzoxazolol.	Skeletal muscle relaxant.
3 α ,7 α ,12 α -trihydroxy-5 β -cholanic acid (2-hydroxyethyl)trimethyl-ammonium saltacate.	Choleretic.
70	Analgesic, antipyretic.
Chromomycin A ₃ .	Antimicrobial.
Cinchonidine.	Antimalarial.
Cinchonine.	Do.
5-chloro-7-[(3-diethylaminopropyl)amino]methyl-8-quinolinol.	Amebicidie.
3-hydroxy-1-methylquinuclidinium bromide benzilate.	Anticholinergic.

TABLE O—Continued

7-chloro-4-(dimethylamino)-1,4,4a,5,5a,6,11,12a-octa-hydro-3,6,10,12,12a-penta-hydroxy-N-(hydroxymethyl)-6-methyl-1,11-dioxo-2-naphth-acenecarboxamide.	Antimicrobial.
4-[3-(2-chlorothioxanthen-9-ylidene)-propyl]-1-piperazine ethanol.	Tranquilizer.
o-Chloro- α -(isopropylaminomethyl)-benzyl alcohol.	Bronchodilator.
Codeine.	Analgesic, antitussive.
7-acetamido-10-hydroxy-1,2,3-trimethoxy-6,7-dihydrobenzo[α]hepten-9(6H)-one.	Acute gout.
Convallatoxin.	As digitalis.
Coriamyrtin.	Stimulant.
5,6,7,8-tetrahydro-4-methoxy-6-methyl-1,3-dioxo[4- β -glisoquinolin-5-ol.	Hemostatic.
Coumingine.	As digitalis.
5-hydroxy-3,4-bis(3,4-methylenedioxybenzyl)-tetrahydrofuran.	Urinary antiseptic.
3,3'-(2-methoxyethylidene)-bis[4-hydroxycoumarin].	Anticoagulant.
3,3,5-trimethylcyclohexyl mandelate.	Antispasmodic peripheral vasodilator.
3-(cyclopropylmethyl)-1,2,3,4,5,6-hexahydro-6,11-dimethyl-2,6-methano-3-benzocin-8-ol.	Analgesic.
2-dimethylaminooethyl-1-hydroxy- α -phenylcyclopentanecetate.	Anticholinergic.
6 β -hydroxy-3,5-cyclopregn-20-one.	Psychotropic agent.
(-)-3-hydroxy-N-cyclopropylmethylmorphinan.	Morphine antagonist.
1-carboxy-4,5-dihydroxy-1,3-cyclohexenebis(3,4-dihydroxyinnamate).	Choleretic.
N-(cyclopropylmethyl)tetrahydro-7 α -(1-hydroxy-1-methylethyl)-6,14-endonororipavine.	Narcotic antagonist.
Diphenyl[2-(4-pyridyl)cyclopropyl]methanol.	Psychotherapeutic agent.
7-chloro-6-methyltetracycline.	Antimicrobial.
N-[p-[(1-(2-amino-4-hydroxy-6-pteridinyl)-ethyl)methylamino]benzoyl]glutamic acid.	Antileukemic agent.
3 α ,12 α -Dihydroxy-5 β -cholanic acid.	Choleretic.
4-[2-(methylamino)ethyl]-pyrocatechol.	Sympathomimetic, vasoconstrictor.
11 β ,17-dihydroxy-21-(4-methyl-1-piperazinyl)pregna-1,4-diene-3,20-hydrochloride.	Antianaphylactic agent.
Deacetyllanatoside C.	As digitalis.
Dihydrodesoxymorphine D.	Analgesic.
[Sulfonylbis(p-phenyleneazo)]dithymol.	Antimycobacterial.
3,5-dibromotyrosine.	Antithyroid.
3-dibutylaminomethyl-4,5,6-trihydroxy-isobenzofuranone.	Antihistaminic.
3,4-dichloro- α -(isopropylaminomethyl)-benzyl alcohol.	Adrenergic blocking activity.
N-(dichloroacetyl)-DL-serine.	Antimetabolite.
2,2'-methylenebis(4-chlorophenol).	Anthelmintic.
(3-amino-4-hydroxyphenyl)-dichloroarsine hydrochloride.	Antiphilic.
2,2'-diethyl-1,3-propanediol.	Skeletal muscle relaxant.
Diethylstilbestrol.	Estrogenic hormone therapy.
Diethylstilbestrol 4,4'-disulfuric ester.	Estrogen replacement therapy.
Digitalin.	As for digitals.
3-O-[2-hydroxy-3-(D-gluc-2,3,4,5,6-pentahydroxyhexyl)mercuri]-propylmannitol.	Mercurial diuretic.
Dihydrocodeine.	Analgesic, antitussive.
Dihydromorphine.	Analgesic.
Dihydrostotomycin.	Antimicrobial.
9,10-secoergosta-5,6,22-trien-3 β -ol.	Maintenance therapy in hypoparathyroidism.
2-methyl-3-phytyl-1,4-naphthoquinone.	Prophylaxis.
5,7-diodo-8-quinolinol.	Amebicide.
3,5-diodo-4-hydroxy- β -phenylalanine.	Hyperthyroidism.
2,2-dichloro-4-hydroxy-N-methylacetanilide.	Amebicide.
2-dimethylaminoethyl diphenylglycolate.	Relief in infectious and allergic rhinitis.
α -Dinitrophenol.	Weight reduction.
Pteroylglutamic acid.	Antimetabolite.
N-ethyl-3,4-dihydroxymorephedrine.	Antitussive.
2-(diphenylmethyl)-1-diperidineethanol.	Anorexigenic.
α , α -Diphenyl-1-piperidinebutanol.	Antiemetic.
α , α -Diphenyl-1-piperidinepropanol.	Antispasmodic, antiparkinson agent.
α , α -Diphenyl-2-piperidinopropanol.	Antitussive.
Bis(p-aronophenylamino)-1,2-ethane disodium.	Amebicide.
2',2'',2'''-(4,8-dipiperidinopyrimido[5,4-d]pyrimidine-2,6-diyl)dinitrilo)-tetraethanol.	Coronary vasodilator.
Disodium 2-(4'-sulfamylphenylazo)-7-acetamido-1-hydroxynaphthalene-3,6-difluonate.	Antimicrobial.
2,6-bis(4-hydroxy-3-methoxybenzylidene)cyclohexanone.	Choleretic.
2-[2-(4-methyl-3-phenothiazin-10-ylpropyl)-1-piperazinyl]ethoxyethanol.	Ataractic.
4-(2-aminoethyl)pyrocatechol.	Antihypotensive agent.
6-deoxy-5-hydroxytetracycline.	Antimicrobial.
7-(2,3-dihydroxypropyl)theophylline.	Smooth muscle relaxant.
Ethy(m-hydroxyphenyl)dimethylammonium bromide.	Parasympathomimetic.

TABLE O—Continued

2,5-dihydroxy-3-undecyl-p-benzoquinone.	Teniacide.
N-(β , β -diethyl-m-methoxyphenethyl)-4-hydroxybutyramide.	Narcotic.
5 Choline bromide α -phenyl-5-norbornene-2-glycolate.	Antispasmodic.
α -[1-(methylamino)ethyl]-benzyl alcohol.	Sympathomimetic, vasoconstrictor anti-allergic.
3,4-dihydroxy- α -(methylamino)-methylbenzyl alcohol.	Sympathomimetic, vasoconstrictor cardiac stimulant.
Ergocristine.	Peripheral vascular disorders.
Ergocryptine.	Do.
10 N-(α -hydroxymethyl)ethyl-D-lysergamide.	Oxytocic.
Ergosta-5,7,22-trien-3 β -ol.	Prophylaxis.
Ergotamine.	Do.
Erythromycin.	Antimicrobial.
Erythromycin propionate lauryl sulfate.	Do.
15 1-N-ethylphedrine d-2,2'-(ethylenedimino)-di-1-butanol.	Sympathomimetic.
N,N-Diethylanilamide.	Antifebrile.
1-lp-(2-Diethylaminoethoxy)phenyl-2-(ρ -methoxyphenyl)-1-phenylethanol.	Estrogen antagonist.
Diethylammonium cyclohexadien-4-ol-1-one-4-sulfonate.	Hemostatic.
1-chloro-3-ethyl-1-penten-4-yn-3-ol.	Hypnotic sedative.
α -Ethylbenzyl alcohol.	Choleretic.
Ethyl bis(4-hydroxycoumarinyl)acetate.	Anticoagulant.
α -Ethyl-1-hydroxycyclohexaneacetic acid.	Choleretic.
3,3'-ethylidenebis(4-hydroxycoumarin).	Anticoagulant.
Ethylmorphine.	Hydrochloride, analgesic, antitussive.
25 α -(1-aminopropyl)-3,4-dihydroxybenzyl alcohol.	Sympathomimetic agent.
α -(Ethylamino)methyl-m-hydroxybenzyl alcohol.	Sympathomimetic circulatory stimulant.
1-Ethyl-3-hydroxypiperidine.	Antispasmodic.
N-ethyl-3-piperidyl phenylcyclopentylglycolate.	Antidepressant.
30 1-ethynylcyclohexanol.	Sedative.
Tetrahydro-7 α -(1-hydroxy-1-methylbutyl)-6,14-endo-ethanooripavine.	Narcotic analgesics.
N-methyl- β -vinylacetonealkamine mandelate.	Mydriatic.
Eulin.	Antifungal antibiotic.
3,5-dihydroxy-4',6,7-trimethoxyflavone.	Emetic.
2-amino-1,2-bis(p-methoxyphenyl)ethanol.	Analgesic, sedative.
Cyclohexylidenebis(p-hydroxyphenyl)methane.	Endocrine properties.
2,4-dihydroxy-3,3-dimethylbutyric acid iron derivative sodium salt.	Hematinic.
40 14-deoxylagostin.	Antifungal antibiotic.
Filicin.	Anthelmintic for cattle, sheep goats.
Isonicotinic acid p-hydroxybenzilidenehydrazide.	Antituberculous agent.
2'-deoxy-5-uridouridine.	Antiviral agent.
3-fluoro-4-hydroxyphenylacetic acid.	Antithyroid agent.
45 4-[3-(2-trifluoromethyl)-thio]xanthen-9-yliidenepropyl-1-piperazineethanol.	Neuroleptic agent.
4-[3-(2-trifluoromethyl)-phenothiazin-10-yl]propyl-1-piperazine ethanol.	Tranquilizer.
N-[p-[(2-amino-4-hydroxy-6-pteridinyl)methyl]amino]-benzoylglutamic acid.	Folic acid deficiency.
N-[p-[(2-amino-5-formyl-5,6,7,8-tetrahydro-4-hydroxy-6-pteridinyl)methyl]amino]glutamic acid.	Folic acid deficiency.
50 7-hydroxy-4'-methoxyisoflavone.	Diuretic.
Frequentin.	Antimicrobial.
3-hydroxy-2-methoxy-5-methyl-p-benzoquinone.	Do.
55 3,11,16-trihydroxy-4,8,10,14-tetra-methyl-17-(1'-carboxynept-4'-enylidene).	Do.
Galanthamine.	Cholinesterase inhibitor.
2,5-dihydroxybenzoic acid.	Analgesic, antirheumatic.
Gitogenin.	As digitalis.
Gitogenin β -lycotetraoside.	Do.
3 β ,14,16 β -trihydroxy-5 β -card-20(22)-enolide.	Do.
60 N-(7-chloro-4-quinolyl)-anthranilic acid 2,3-dihydroxypropyl ester.	Antinflammatory, analgesic.
Gliotoxin.	Antimicrobial.
Gluconic acid.	Antispasmodic.
Glucose.	Prophylaxis.
p,p'-Sulfonyldianiline N,N'-diglycoside disodium disulfonate.	Antimycobacterial in leprosy.
65 D-glycuronic acid.	Antiarthritic.
D-glycofuranuro-6,3-lactone.	Do.
Oxo(hydrogen N-glycoloylarsanilate)bismuth.	Antiprotozoan, antifungal agent.
3-hydroxy-1,1-dimethylpyrrolidinium bromide α -cyclopentylmandelate.	Antichloinergic.
3 β -hydroxy-11-oxoolean-12-en-30-oic acid.	Addison's disease.
70 Glycyrrhetic acid.	Do.
Ethyl 3,5,6-tri- α -benzyl-D-glucofuran-o-side.	Anti-inflammatory, antiallergic.
o-Methoxyphenol.	Expectorant.
Guaiacoline.	Anti-asthmatic.
7-azaguanine.	Antimetabolite.
75 N-formyl-N-hydroxyglycine.	Do.

TABLE O—Continued

4-[4-(p-chlorophenyl)-4-hydroxypiperidino]-4'-fluorobutyrophenone.	Sedative, tranquilizer.
3,4-dihydro-1-methyl-9H-pyrido-[3,4- <i>o</i>]-indol-7-ol.	Antheimintic.
Hellebrigenin glucorhamnoside.	Cardiotonic.
1,3,5,8-tetramethyl-2,4-bis(α -hydroxyethyl)prophene-6,7-dipropionic acid.	Anti-depressant.
6-amino-2-methyl-1,2-heptanol.	Myocardial stimulant.
Hesperidin.	For increased capillary fragility.
3-hydroxy-1,1-dimethylpyrrolidinium-bromide α -phenyl-2-thiopheneglycolate.	Anticholinergic.
Hexamethylolmelamine.	Antimetabolite.
Meso-3,4-bis(p-hydroxyphenyl)-n-hexane.	For estrogen deficiency.
5-(1-cyclohexen-1-yl)-1,5-dimethyl-barbituric acid.	Short duration sedative.
N-(β -cyclohexyl- β -hydroxy- β -phenylethyl)-N ¹ -methylpiperazine methosulfate.	Anticholinergic, antispasmodic.
β -(3,5-diido-4-(4'-hydroxy-3',5'-di-tert-butylphenoxy)-phenyl)propionic acid.	Antithyroid agent.
Mandelyltropine.	Anticholinergic.
p-(2-dimethylaminoethyl)-phenol.	Sympathomimetic.
1-hydroxy-6,7-methylenedioxy-2-methyl-1,2,3,4-tetrahydroisoquinoline.	Mycardial stimulant.
2-(2-[2-(4-(p-chloro- α -phenylbenzyl)-1-piperazinyl]ethoxy)ethanol.	Hypnotic.
Dihydromorphinone.	Narcotic, analgesic.
Dihydroquinine.	Antimalarial.
α -(5,6-dimethylbenzimidazolyl) hydroxocobamide.	Prophylaxis.
p-(2-aminopropyl)phenol.	Sympathomimetic, antihypotensive, nasal, decongestant.
7-chloro-4-[4-(ethyl(2-hydroxyethyl)amino)-1-methylbutylamino]quinolone.	Antimalarial, anti-inflammatory agent.
p-Hydroxy- α -[1-(methylamino)-ethyl]benzyl alcohol.	Sympathomimetic.
2-(hydroxyethyl)dimethyl-1-(1-methyl-2-phenoxyisatin-10-ylethyl)-ammonium chloride.	Antihistaminic.
7-(2-hydroxyethyl)theophylline.	Smooth muscle relaxant.
3-hydroxy-N-methylmorphinan.	Narcotic analgesic.
6-hydroxy-2-methyl-1,4-naphthoquinone.	Brucellosis.
3-pyridinecarboxylic acid hydroxymethylamide.	Cholagogue.
2-(2-hydroxy-1-naphthyl)-cyclohexanone.	Antitussive.
β -Ethyl- β -hydroxyphenethyl carbamic acid ester.	Tranquillizer.
4-butyl-2-(p-hydroxyphenyl)-1-phenyl-3,5-pyrazolidinedione.	Anti-inflammatory agent.
3-hydroxy-2-phenylcinchoninic acid.	Antiduritic, uricosuric agent.
1-(β -hydroxypropyl)theobromine.	Cardiotonic.
2-hydroxy-4,4'-stilbenedicarboxamidine.	Antileishmanial, antitrypanosomal agent.
1-(p-chloro- α -phenylbenzyl)-4-(2-hydroxyethoxyethyl)-piperazine.	Tranquillizer.
3c-tropanyl- <i>s</i> -(—) tropate.	Anticholinergic.
1,3,4,6,8,13-hexahydroxy-10,11-dimethylphenanthro-1,10,9,8-a[<i>grpa</i>]perylene-7,14-dione.	Antidepressant.
o-1,3,4-oxadiazol-2-ylphenol.	Hypnotic.
2'-deoxy-5-iodouridine.	Antiviral agent.
Isonicotinic acid 2-(2-acetamido-2-deoxyglycosyl)-hydrazide.	Antituberculous agent.
Inositol.	Lipotropic agent.
5-iodo-2-thiouracil.	Antithyroid agent.
α -(1-isopropylaminopropyl)-protopro-catechyl alcohol.	Bronchodilator.
1-isonicotinoyl-2-salicylidenehydrazine.	Antituberculous agent.
N-isopropylsalicylamide.	Analgesic.
3,4-dihydroxy- α -(iso-propylamino)-methylbenzyl alcohol.	Bronchodilation, defibrillation.
p-Hydroxy- α -[1-(methyl-2-phenoxyethyl)amino]ethylbenzyl alcohol.	Vasodilator.
5-hydroxy-1,4-naphthoquinone.	Antihemorrhagic activity.
1-[4-(m-hydroxyphenyl)-1-methyl-4-piperidyl]-1-propanone.	Narcotic, analgesic.
Ethyl(2-hydroxyethyl)dimethylammonium chloride benzilate.	Mydriatic.
p-Lactophenetide.	Analgesic, antipyretic.
Lanatoside A.	Cardiotonic.
2-hydroxy-3-(3-methyl-2-butenyl)-1,4-naphthoquinone.	Antimalarial.
2-hydroxy-3-(9-hydroxy-9-pentyltetradecyl)-1,4-naphthoquinone.	Do.
m-Hydroxyphenethyl trimethylammonium.	Neuromuscular blocking agent.
(—)-2-methyl-2-phenylhydrylic acid 3 α -tropanyl ester.	Anticholinergic.
(—)-3-hydroxy-N-phenylaclymorphinan.	Analgesic.
Lincosycin.	Antimicrobial.
Lucensomycin.	Antifungal agent.
Lupulon.	Antimicrobial.
N-[4-(dimethylamino)-1,4,4a,5,5a,6,11,12-octahydro-3,6,10,12,12a-penta-hydroxy-6-methyl-1,11-dioxo-2-naphthacencarboxamido]methyllysine.	Do.
2'-deoxy-5-(methylamino)-uridine.	Antiviral agent.
3-methyl-1-pentyn-3-ol.	Hypnotic sedative.

TABLE O—Continued

N-methyl-3-piperidyl benzilate methyl bromide.	Anticholinergic, antispasmodic agent.
3-(1-tolyl)-1,2-propanediol.	Skeletal muscle relaxant.
3-o-tolyl-1,2-propanediol-1-carbamate.	Do.
5 N-[(4-(2-hydroxyethyl)-1-piperazinyl)methyl]tetracycline.	Antimicrobial.
3-(2-methoxy-4-propionylphenoxy)-1,2-propanediol.	CNS depressant, anticonvulsant.
Merphyrin.	Antimetabolite.
α , α '-Diethyl-4'-methoxy-4-stilbenol.	For estrogen deficiency.
Dihydroxy- α -(isopropylamino)methylbenzyl alcohol.	Bronchodilator.
10 α -(1-aminethyl)-m-hydroxybenzyl alcohol.	Sympathomimetic, vasopressor.
1,2,3,4,6-hexahydro-8-hydroxy-3,6,11-trimethyl-2,6-methano-3-benzazocine.	Analgesic.
6-methylenoxytracycline.	Antimicrobial.
Methesucleotol theophylline.	Vascular tonic.
3-(o-methoxyphenoxy)-1,2-propanediol.	Skeletal relaxant.
15 1-carbamate.	Narcotic analgesic.
Methylidihydromorphinone.	Antihypertensive agent.
L-3-(3,4-dihydroxyphenyl)-2-methylalanine.	Vasoconstrictor.
α -(Dimethylamino)methyl-3,4-dihydroxybenzyl alcohol.	Oxytocic.
20 N-[α -(hydroxymethyl)propyl]-D-lysergamide.	Antimonate.
1-deoxy-1-(methylamino)-D-glucitol.	Inhibitor of catecholamine synthesis.
α -Methyl-3-(m-hydroxyphenyl)alanine.	Inhibitor of catecholamine synthesis.
4-hydroxy- α -methylphenylalanine.	Antimicrobial.
Methylmycin.	Prophylaxis of vascular headache.
25 N-[1-(hydroxymethyl)propyl]-1-methyl-D-lysergamide.	Antimicrobial.
Mikamycin.	Ataractic agent.
p-Fluoro-4-(4'-hydroxy-4'-p-tolyl-piperidino)butyrophorone.	Analgesic.
Morphine.	Analgesic.
1,4-tetrahydroxazine orthoxybenzoate.	Antirheumatic agent.
β -(4-imidazolyl)acrylcholine.	Muscle relaxant.
30 3-carbamoyl-1- β -D-ribofuranosylpyridinium hydroxide 5'-ester with adenosine 5'-pyrophosphate inner salt.	In DPN deficiency.
N-allylnormorphine.	Antidote for acute narcotism from morphine.
1-N-allyl-7,8-dihydro-14-hydroxynormorphinone.	Narcotic antagonist.
35 N-allylnortropine.	Anticholinergic.
2-(2-naphthoxy)ethanol.	Sedative in large animals.
{5-[3-amino-4-hydroxyphenyl]arseno-2-hydroxyanilino}methanol sulfoxylate sodium.	Antisyphilitic.
2',5-dichloro-4'-nitrosalicylanilide.	Anthelmintic teriacide.
1,3,4,6-tetraacetyl-2-furanide 2-(2-hydroxyethyl)semicarbazone.	Peripheral vasodilator.
40 p-Hydroxybenzoic acid (5-nitrofurylidene)hydrazide.	Antibacterial.
N-[p-(1-(2-amino-4-hydroxy-6-pteridinyl)ethyl)amino]benzyl]glutamic acid.	Antimetabolite.
1-diethylamino-3-[2,3-dimethoxy-6-nitro-9-acridinyl]aminopropanol.	Antimicrobial.
5-nitro-2-furaldehyde 2-(2-hydroxyethyl)semicarbazone.	Do.
45 2',5-dichloro-4'-nitrosalicylanilide.	Peripheral vasodilator.
1,3,4,6-tetraacetyl-2-furanide.	Antibacterial.
5-nitro-8-quinolinol.	Bronchodilator.
α -(Cyclobutylamino)-methyl-3,4-dihydroxybenzyl alcohol.	Sympathomimetic.
α -(1-aminoethyl)-3,4-dihydroxybenzyl alcohol hydrochloride.	Sympathomimetic, vasoconstrictor.
50 α -(Aminomethyl)-3,4-dihydroxybenzyl alcohol.	Narcotic.
(—)-3-hydroxymorphinan.	Antimicrobial.
Novobiocin.	Antimicrobial.
p-Hydroxy- α -[1-(1-methyl-3-phenylpropyl)amino]ethylbenzyl alcohol.	Peripheral vasodilator.
α -(Aminomethyl)-p-hydroxybenzyl alcohol.	Sympathomimetic.
Oleandomycin.	Antimicrobial.
55 Oleandrin.	Cardiac insufficiency.
4-[3-(5H-dibenzo[b,f]azepin-5-yl)propyl]-1-piperazineethanol.	Antidepressant, tranquilizer.
G-strophanthidin.	As digitalis.
4'-hydroxysalicylanilide.	Choleretic.
7-chloro-1,3-dihydro-4-hydroxy-5-phenyl-2H-1,4-benzodiazepin-2-one.	Tranquilizer.
60 2-amino-4-arsenosophenohydrochloride.	Syphilis, Vincent's angina.
α -Phenylcyclohexaneglycolic acid 4-(diethylamino)-2-butynyl ester hydrochloride.	Asian relapsing fever.
1-(7-chloro-4-quinolylamino)-3-diethylamino-2-propanol.	Antimalarial agent.
Dihydrohydroxycodeinone.	Narcotic analgesic.
6-tert-butyl-3-(2-imidazolin-2-ylmethyl)2,4-dimethylphenol.	Sympathomimetic, nasal vasoconstrictor.
Dihydrohydroxymorphinone.	Narcotic analgesic.
1,4,5,6-tetrahydro-1-methyl-2-pyrimidinylmethyl- α -phenylcyclohexaneglycolate.	Anticholinergic.
Diethyl(2-hydroxyethyl)methylammonium α -phenylcyclohexaneglycolate bromide.	Do.
70 2-hydroxy-3-pinanone.	Respiratory insufficiency.
Oxytetraacycline.	Antimicrobial.
2-amino-2-methyl-1-propanol 8-bromotheophyllinate.	Diuretic.
Paromomycin.	Antimicrobial.
4'-hydroxypropiophenone.	Pituitary gonadotropic hormone inhibitor.

TABLE O—Continued

Hexahydro-4-[3-[2-(trifluoromethyl)-phenothiazin-10-yl]propyl]-1H-1,4-diazepine-1-ethanol.	Sedative.
Isonicotinic acid hydrazide p-aminosalicylate.	Antituberculous agent.
4-hydroxy-4H-furo[3,2-c]pyran-2(6H)-one.	Antimicrobial.
N-(8'-hydroxy-6'-methyl-trans-trans-cis-dodeca-2',4',6'-triienoyl)-2-pyrrolidone.	Antifungal agent.
Pentaerythritol chloral.	Hypnotic sedative.
2-dimethylallyl-5,9-dimethyl-2'-hydroxybenzomorphan.	Analgesic.
Diethyl(2-hydroxyethyl)methylammonium bromide α -cyclopentyl-2-thiopheneglycolate.	Anticholinergic.
10-[3-(4-hydroxypiperidino)propyl]-phenothiazine-2-carbonitrile.	Tranquilizer.
4-[3-(2-chlorophenothiazin-10-yl)-propyl]-1-piperazineethanol.	Tranquilizer, antiemetic.
4-[3(10H-pyrido[3,2-b][1,4]benzothiazin-10-yl)propyl]-1-piperazineethanol.	Antiemetic.
8-phenacylhomatropinium chloride.	Ganglion blocking agent, anti hypertensive.
2-(p-chlorophenyl)-3-methyl-2,3-butanediol.	Sedative.
1,2,3,4,5,6-hexahydro-6,11-dimethyl-3-phenethyl-2,6-methano-3-benzazocin-8-ol.	Analgesic.
p-Acetamidophenyl salicylate.	Analgesic, "antirheumatic," antipyretic.
3',4'-dihydroxy-2-isopropylamino-propiophenone.	Bronchodilator.
1,3-hydroxy-N-phenethylmorphinan.	Analgesic.
N-(2-thiazolyl)-1-phenol-4-sulfonamide.	Used in polyarthritides.
2-[N-(m-hydroxyphenyl)-p-toluidino-methyl]imidazoline.	Adrenergic blocking agent.
Phenyl aminosalicylate.	Antituberculous agent.
1-m-hydroxy- α -(methylamino)methyl]benzyl alcohol hydrochloride.	Sympathomimetic.
α -(1-aminoethyl)benzyl alcohol hydrochloride.	Sympathomimetic, bronchodilator.
Phenyl salicylate.	Analgesic, antipyretic.
2-(β -hydroxyphenethylamino)-pyridine.	Analgesic.
Phlorhizin.	Antimalarial.
2',4', β '-trihydroxypropiophenone.	Antispasmodic.
3-[2-(4-morpholino)ethyl]morphine.	Antitussive.
p-[2-(methylamino)propyl]phenol.	Sympathomimetic, vasopressor agent.
N-(phenoxyamidine)sarcosine.	To treat fatigue.
Physalaemin.	Vasodilator, hypotensive agent.
Pimariotin.	Antimicrobial.
10-[3-[4-(2-Hydroxyethyl)piperidino]propyl]phenothiazin-2-yl methyl ketone.	Tranquilizer.
α -Diphenyl-2-piperidinemethanol.	CNS stimulant.
2-(hydroxymethyl)-1,1-dimethyl-piperidinium methyl sulfate benzilate.	Antispasmodic, anticholinergic, bronchodilator.
Isonicotinic acid (3-hydroxy-2,2-dimethylpropylidene)hydrazide.	Antituberculous agent.
Podophyllinic acid 2-ethylhydrazide.	Antimetabolite.
1-hydroxy-2-hydroxymethyl-6,7-methylenedioxy-4-(3',4',5'-trimethoxyphenyl)-1,2,3,4-tetrahydronaphthalene-3-carboxylic acid lactone.	Do.
Estradiol phosphate polymer.	Estrogen.
Potassium gluconate.	Prophylaxis.
α -Cyclohexyl- α -phenyl-1-pyrrolidine-propanol.	Cholinergic blocking agent.
α -Phenylcyclohexaneglycolic acid (1-methyl-2-pyrrolidinyl)methyl ester.	Anticholinergic.
4,4'-(1,2-diethylethylene)di-o-cresol.	Estrogenic agent.
α -(Isopropylamino)methyl-2-naphthalenemethanol.	Adrenergic agent.
α -Phenylcyclohexaneglycolic acid 1-methyl-3-piperidyl ester.	Anticholinergic.
1-(isopropylamino)-3-(1-naphthoxy)-2-propanol.	Adrenergic blocking agent.
p-Hydroxybenzoic acid propyl ester.	Prophylaxis.
14-hydroxy-3-(β -aminoxy)-2,22-trienolide.	Cardiotonic.
α -(α -Methyl-3,4-methylenedioxy-phenethylamino)methyl]protopcatechyl alcohol.	Sympathomimetic agent, bronchodilator.
Protoveratrin.	Antihypertensive.
7-(2-hydroxypropyl)theophylline.	Smooth muscle relaxant.
99-D-psicofuranosyladenine.	Antimicrobial.
3'-(α -amino-p-methoxyhydrocinnamido)-3'-dioxo-N,N-dimethyladenosine.	Do.
β -Pyridylcarbinol.	Peripheral vasodilator.
β -[1,3-dimethyl-2,6-(1H,3H)-purinedion-7-yl]ethyl sulfate of 5-hydroxy-6-methyl-3,4-pyridinedimethanol.	Respiratory analeptic, coronary vasodilator.
Pyridoxal 5-monophosphoric acid ester.	Prophylaxis.
Pyridoxine hydrochloride.	Adjunct in prophylaxis.
3-(di-2-pyridylmethylene)- α - α -di-2-pyridyl-1,4-cyclopentadiene-1-methanol.	Antiarhythmic agent.
3,3'-(dithiodimethylene)bis[5-hydroxy-6-methyl-4-pyridinemethanol].	Neurotropic agent.
1,2,3-trihydroxybenzene.	Antimicrobial.

TABLE O—Continued

Bis[6-(dimethylamino)-2-[2-(2,5-dimethyl-1-phenylpyrrol-3-yl)vinyl]-1-methylquinolinium]4,4'-methylenebis(3-hydroxy-2-naphthoate).	Anthelmintic.
5 3,3',4',5',7-pentahydroxyflavone.	To decrease capillary fragility.
Quinidine.	Antimalarial.
Quinine.	Do.
1-azabicyclo[2.2.2]octan-3-ol.	Hypnotic.
14,15-epoxy-3 β -hydroxy-5 β -bufa-20,22-dienolide.	Cardiotonic agent.
10 Resistomycin.	Antimicrobial.
Riboflavin.	Prophylaxis.
N,N-diethylribomycin B amide.	Antimicrobial.
N-(pyrrolidinomethyl) tetracycline.	Do.
Rutin.	To decrease capillary fragility.
5-(p-sulfamoylphenylazo)salicylic acid.	Antimicrobial agent.
o-Hydroxybenzamide.	Analgesic, antipyretic, anti-rheumatic.
15 5-[p-(pyridylsulfonyl) phenylazo]-salicylic acid.	Granulomatous colitis in dogs.
4-salicyloylmorpholine.	Choleretic.
1,2,3,4-tetrahydro-7-methoxy-1-methyl-6-isouinolol.	Antihypertensive.
6-demethyl-6-deoxytetracycline.	Antimicrobial.
20 Scillaren.	Cardiotonic.
33,14-dihydroxybufa-20,22-trienolide.	Anticholinergic.
65,7 β -epoxy-3 α -tropolan S-(α)-tropate.	Do.
Scopolamine aminoxide.	Antitussive.
p-Chloro- α -(2-dimethylamino)-1-methylethyl- α -methylphenethyl alcohol hydrochloride.	Antitussive.
Stigmaric 5-en-3 β -ol.	Cholestral inhibitor.
25 Sodium ascorbate.	In vitamin C deficiency.
Sodium levothyroxine.	Thyroid deficiency.
Sodium salicylate.	Analgesic, antipyretic.
Salanine.	Bronchitis, epilepsy.
p-Carboxybenzaldehyde thiosemicarbazone diethanolamine salt.	Antituberculous agent.
Sorbitol.	Osmotic diuretic.
30 Decahydro-4 α ,7,9-trihydroxy-2-methyl-6,8-bis(methyl amino)-4H-pyran-2,3-bis[1,4]benzodioxin-4-one.	Antibiotic.
Spiramycin.	Antimicrobial.
3-(5-(3-Isobutyl-2,3-dihydroxypropyl)amino)-4-hydroxyphenylarseno)-2-benzoxazolylthio]propionic acid sodium salt.	Antisyphilitic.
35 Staphylocycin.	Antimicrobial.
Sodium p-aminobenzenestilbonate glucoside.	Antiprotozoan.
Streptodidigin.	Antimicrobial.
Streptomycin A.	Antimicrobial, antituberculous agent.
Streptomycin B.	Do.
40 5-amino-6-(7-amino-5,8-dihydro-6-methoxy-5,8-dioxo-2-quinolyl)-4-(2-hydroxy-3,4-dimethoxyphenyl)-3-methylpicolinic acid.	Antimetabolite.
4-sulfanilamido-salicylic acid.	Antimicrobial agent.
4-amino-4'-(β -hydroxyethyl amino)diphenyl sulfone.	Antileprotic, antituberculous agent.
Sulfarsphenamine.	Antisyphilitic.
45 p-Hydroxy- α -(methylamino)methyl]benzyl alcohol.	Sympathomimetic.
Cholic acid.	Choleretic.
3-acetyl-5-sec-butyl-4-hydroxy-3-pyrrolin-2-one.	Antimetabolite.
p-Methane-1,8-diol.	Expectorant.
Tetracycline.	Antimicrobial.
3-hydroxytetrahydrofuran.	Choleretic.
50 α -Vinyl-1-aziridineethanol.	Antimetabolite.
Tetrahydro- β -benzoquinone.	Keloids.
Theophylline isopropanolamine.	Smooth muscle relaxant.
Thiamine disulfide.	In thiamine deficiency.
Thiamine hydrochloride.	Prophylaxis.
Thiamine propyl disulfide.	Do.
Thiamine tetrahydrofurfuryl disulfide.	For thiamine deficiency.
55 Thiamphenicol.	Antimicrobial.
4-(dimethylaminocyclohexyl)di-2-thienylmethanol.	Anticholinergic.
2-amino-6-mercapto-9- β -D-ribofuranosylpurine.	Antimetabolite.
2-mercapto-4-hydroxypyrimidine.	Antithyroid agent, in angina pectoris and in congestive heart failure.
60 4-hydroxy-1,3(2H)-benzoxathiol-2-one.	Antiseborrheic agent.
5-methyl-2-isopropyl-1-phenol.	Anthelmintic.
3-[4-(4-hydroxy-3,5-diodophenoxy)-3,5-diiodophenyl]alanine.	Thyroid deficiency, cholesterol agent.
4-[3-hydroxy-3-phenyl-3-(2-thienyl)propyl]-4-methylmorpholinium iodide.	Anticholinergic and antispasmodic properties.
65 1-(1,2,3,6-tetrahydropyridino)-3-0-tolylolxypropan-2-ol.	Analgesic.
C-toxiferine I.	Skeletal muscle relaxant.
Trichloroethyl phosphate.	Sedative, hypnotic.
5,6-diphenyl-3-(2,2,2-trichloro-1-hydroxyethyl)-4-imidazolidinone.	Ataractic agent.
Bis(2,5-trichlorophenol)piperazine.	Anthelmintic.
70 (3-cyclohexyl-3-hydroxy-3-phenylpropyl) triethylammonium iodide.	Cholinergic blocking agent.
4'-fluoro-4-[4-hydroxy-4-(α , α -trifluoromethyl)phenyl]butyrophene.	Anti-psychotic agent.
[4-(4-hydroxy-3-iodophenoxy)-3,5-diiodophenyl]acetic acid.	Thyroid replacement therapy.
β -[4-(4-hydroxy-3-iodophenoxy)-3,5-diiodophenyl] alanine.	Thyroid replacement.

4-(4-hydroxy-3-iodophenoxy)-3,5-di- iodohydrocinnamic acid.	T.S.H. inhibitor, cholestero- penic agent.
s-Triazine-2,4,6-triyltriamino) trimetha- noi.	Antimetabolite.
1-[p-(2-diethylaminoethoxy)phenyl]-1- (p-tolyl)-2-(p-chlorophenyl)ethanol.	Cholesterol biosynthesis in- hibitor.
2-amino-2-hydroxymethyl-1,3-propane- diol.	Correction of metabolic acidosis.
6-methoxytropine benzilate.	Antispasmodic.
N-ethyl-2-phenyl-N-(4-pyridylmethyl) hydroacrylamide.	Anticholinergic, mydriatic, cyclopelgic.
7,3',4-tris[O-(2-hydroxyethyl)]rutin.	Treatment of venous dis- orders.
Monosodium N-phenylglycaminide-p- arsonate.	Antiprotozoan, trypanosomi- cidal antisypnthetic agent.
4-amino-7-(D-ribofuranosyl)-7H-pyr- rolo[2,3-d]pyrimidine.	Antifungal, antituberculous, antineoplastic properties.
Tubocurarine chloride.	Skeletal muscle relaxant.
4-hydroxyphenethylamine.	Sympathomimetic.
3-(hydroxymethyl)-1-[(5-nitrofuryl- dene)amino]hydantoin.	Urinary-tract antibacterial agent.
Uridine 5'-triphosphate.	Muscular atrophy and dys- trophy.
α -Ethyl-1-hydroxy-4-phenylecyclohex- aneacetic acid.	Choleretic agent.
Vernamycin B.	Antimicrobial properties.
Vinblastine.	Antimetabolite.
Vincamine.	Cerebrovascular disorders.
N-[4-amino-2-methyl-5-pyrimidinyl]- methyl-N-(2-(2-benzoylvinyl)thio)- 4-hydroxy-1-methyl-1-butene)formam- ide.	For thiamine deficiency.
3,7-dimethyl-9-(2,6,6-trimethyl-1-cyclo- hexen-1-yl)-2,4,6,8-nonatetraen-1-ol.	Prophylaxis.
Vitamin B ₁₂ .	Do.
Ergocalciferol.	Do.
Activated 7-dehydrocholesterol.	Do.
2,5,7,8-tetramethyl-2-(4',5',12'-tri- methyltridecyl)-6-chromanol.	Do.
4-amino-2-methyl-1-naphthol.	Do.
7-[2-hydroxy-3-(2-hydroxyethyl)- methylamino]propyl]theophylline.	Peripheral vasodilator.
4-[3-(2-chlorothiophen-9-yl)propyl]- 1-piperazine-propanol.	Psychotherapeutic and anti- nauseant.
1,4-bis(p-hydroxyphenyl)-2,3-diiso- trico-1,3-butadiene.	Antimicrobial.
Querebramine.	Adrenergic blocking agent.

PREPARATION 1

Glycerol 1,3-benzylidene

Glycerol (204 g.) is mixed with benzaldehyde (296 ml.) in a one liter flask fitted with a gas inlet and a stirrer. A stream of dry carbon dioxide-nitrogen is passed through the reaction mixture as it is gradually heated to 155 to 165° C., and the reaction is maintained at this temperature for 2 hours. The reaction mixture is distilled at 0.2 mm. Hg, and the fraction boiling at 132-136° C. is collected. The early portion of this fraction crystallizes and can be separated by filtration. The clear distillate is dissolved in ether (300 ml.), and hexane is added until the solution turns cloudy. Sufficient ether is added to give a clear solution. Dry hydrogen chloride gas is passed into the solution for 20 sec., and the mixture is cooled to -30° C. The crystalline solid which forms is removed by filtration and shaken with one percent aqueous ammonia. The solid melts to form an oil which is washed with water, dried and dissolved in ether (600 ml.). The solution on cooling yields glycerol 1,3-benzylidene.

PREPARATION 2

Glycerol 1,2-di(fatty acylates)

Glycerol 1,2-acetonide (1.43 g.) in pyridine (10 ml.) is treated with trichloroethyl chloroformate (2.74 g., 1.83 ml.). The reaction is cooled to room temperature and stirred for 18 hours. The reaction mixture is then poured onto ice, and the precipitated oil is extracted with ether. The ether phase is washed with water, dried and evaporated to yield glycerol 1,2-acetonide, 3-trichloroethylcarbonate.

The acetonide (0.5 g.) is dissolved in triethylborate (5 ml.) and treated with boric acid (0.75 g.). The mixture is heated on a steam bath for 5 hours, the solvents are evaporated and the residue is diluted with water to which sodium bicarbonate is added. The mixture is extracted with chloroform, and the organic extracts are washed with aqueous sodium bicarbonate water, dried and evaporated to yield glycerol 1-trichloroethylcarbonate.

This compound (1 g.) is dissolved in carbon tetrachloride (10 ml.) and treated at 0° C., and treated with pyridine (0.65 ml.), palmitoyl chloride (2.2 g.), and carbon tetrachloride (2 ml.). The mixture is maintained at room temperature for 18 hours, diluted with diethyl ether in water, and extracted with diethyl ether. The ether extracts are washed with 5 percent hydrochloric acid, aqueous sodium bicarbonate solution, dried and evaporated to yield glycerol 1-trichloroethylcarbonate, 2,3-dipalmitate.

The dipalmitate derivative (0.5 g.) is suspended in diethyl ether (20 ml.) and the solution is cooled to 10° C. Zinc dust (1 g.) and acetic acid (1 ml.) is then added, and the solution is allowed to warm to room temperature. After 30 minutes, the solution is filtered, and the filtrate is extracted with saturated aqueous sodium chloride solution. Ice, and pyridine (1.5 ml.) are added to the mixture. The aqueous layer is removed and the resulting solution is washed with water until any precipitated solids are dissolved. Ethyl acetate (5 ml.) is added, the solution is washed with aqueous sodium chloride solution, dried and evaporated to yield glycerol 1,2-dipalmitate.

Repeating the above procedure but replacing palmitoyl chloride with other fatty acyl chlorides yields the corresponding glycerol 1,2-di(fatty acylates) e.g., glycerol 1,2-dioleate, and the like.

This invention is further illustrated by the following specific but not limiting examples.

EXAMPLE 1

Glycerol 1-[2-(6-methoxy-2-naphthyl)propionate]

2-(6-methoxy-2-naphthyl)propionic acid (25 g.) is slurried with dry diethyl ether (250 ml.) and oxalyl chloride (10 ml.) is added. The solution is stirred at room temperature overnight. Another portion of oxalyl chloride (10 ml.) is added, the solution is refluxed for 5 hours using a dry cold trap. The solution is then evaporated to dryness, and the residue extracted with hot hexane. The filtered solution is allowed to cool, the precipitated solids are separated, and the mother liquors are concentrated to yield 2-(6-methoxy-2-naphthyl)propionyl chloride.

Glycerol acetonide (6.0 g.) is dissolved in carbon tetrachloride (100 ml.) and 10 ml. of pyridine is added. To this solution is added a solution of 2-(6-methoxy-2-naphthyl)propionyl chloride in carbon tetrachloride, and the mixture is allowed to stand overnight. This solution is filtered, extracted with sodium bicarbonate and water, and evaporated to dryness to yield glycerol 2,3-acetonide 1-[2-(6-methoxy-2-naphthyl)propionate]. This is dissolved in triethylborate (15 ml.), and boric acid (2.0 g.) is added. The resulting solution is heated on a steam bath for 3 hours in a slow stream of nitrogen, poured into aqueous sodium bicarbonate solution, and extracted with ethyl acetate. The organic layer is dried and evaporated to dryness. The residue is slurried with diethyl ether, and the product is filtered from the suspension to yield glycerol 1-[2-(6-methoxy-2-naphthyl)propionate].

EXAMPLE 2

Other glycerol 1-(6-substituted-2-naphthyl)acetates

Repeating the procedure of Example 1 but replacing 2-(6-methoxy-2-naphthyl)propionic acid with other 6-substituted-2-naphthylacetic acids such as 2-(6-substituted-2-naphthyl)propionic acids having at the C-6 position of the naphthalene ring, methylthio, difluoromethoxy, chloro, methyl, ethyl, and isopropyl groups yields the corresponding 2-(6-substituted-2-naphthyl)propionyl chloride intermediates and the glycerol 1-(6-substituted-2-naphthyl)acetates, e.g., glycerol 1-[2-(6-methylthio-2-naphthyl)propionate], glycerol 1-[2-(6-difluoromethoxy-2-naphthyl)-propionate], glycerol 1-[2-(6-chloro-2-naphthyl)propionate],

61

glycerol 1-[2-(6-methyl-2-naphthyl)propionate],
glycerol 1-[2-(6-ethyl-2-naphthyl)propionate],
glycerol 1-[2-(6-isopropyl-2-naphthyl)propionate].

EXAMPLE 3

Glycerol 2,3-di(fatty acylate) 1-[2-(6-methoxy-2-naphthyl)propionate]

The product of Example 1 (2.6 g.) is dissolved in ethyl acetate-carbon tetrachloride and 10 ml. of pyridine is added. To this solution is added a solution of 7.0 g. of palmitoyl chloride in carbon tetrachloride (20 ml.), and the solution is allowed to stand overnight. Then water (3 ml.) is added, and the solution is allowed to stand for 15 minutes. The solution is extracted with water, aqueous sodium bicarbonate solution, and dried with magnesium sulfate. The solution is then filtered, and any polar material is removed by chromatographic filtration. The solution is then evaporated, and the residue is chromatographed on silica gel to yield glycerol 2,3-dipalmitate-1-[2-(6-methoxy-2-naphthyl)propionate].

Repeating the above procedure with other fatty acyl chlorides having from 8 to 24 carbons, e.g., oleoyl chloride, yields the corresponding glycerol 2,3-di(fatty acylate) 1-[2-(6methoxy-2-naphthyl)propionates], e.g. glycerol 2,3-dioleate 1-[2-(6-methoxy - 2 - naphthyl)propionate].

EXAMPLE 4

Other glycerol 2,3-di(fatty acylate) 1-(6-substituted-2-naphthyl)acetates

Repeating the procedures of Example 3 with the products of Example 2 yields the corresponding glycerol 2,3-di(fatty acylate) 1 - (6-substituted-2-naphthyl)-acetates such as the glycerol 2,3-dipalmitate 1-[2-(6-substituted-2-naphthyl)propionate] wherein the substituent at the C-6 position of the naphthalene ring is methylthio, difluoromethoxy, chloro, methyl, ethyl, isopropyl and the like.

EXAMPLE 5

Glycerol 2-[2-(6-methoxy-2-naphthyl)propionate]

The 2-(6-methoxy-2-naphthyl)propionyl chloride produced in Example 1 (11.0 g.) and glycerol 1,3-benzylidene (9.5 g.) is dissolved in carbon tetrachloride, and triethylamine (18 ml.) is slowly added to the solution which has been previously cooled to about 0° C. The solution is allowed to warm up to room temperature and stand overnight. The solvent is evaporated under reduced pressure, and the residual oil is dissolved in diethyl ether. The solution is extracted four times with water (50 ml.), and the ether solution is dried over magnesium sulfate. The solvent is evaporated to yield glycerol 1,3-benzylidene 2-[2-(6-methoxy-2-naphthyl)propionate].

A portion of this product (3.4 g.) is mixed with powdered boric acid (1.0 g.) and triethyl borate (10.0 ml.). The mixture is warmed until a clear solution is obtained and then heated to 100-110° C. for 15 minutes under 5.0 mm. Hg pressure. After cooling, the residue is digested with water and diethyl ether, and the water layer is extracted with diethyl ether. The ether extracts are combined, dried and evaporated to dryness. The residue is dissolved in benzene to which hexane is added dropwise until a white solid separates. The solid is separated and recrystallized from benzene to yield glycerol 2-[2-(6-methoxy-2-naphthyl)propionate].

EXAMPLE 6

Glycerol 2-(6-substituted-2-naphthylacetate)

Repeating the procedure of Example 5 with other 6-70 substituted-2-naphthylacetyl chlorides such as 2-(6-substituted-2-naphthyl)-propionyl chlorides having at the C-6 position of the naphthalene ring, methylthio, difluoromethoxy, chloro, methyl, ethyl, or isopropyl groups yields the corresponding glycerol 2-(6-substituted-2-naphthyl-

62

acetates) such as the corresponding glycerol 2-[2-(6-substituted-2-naphthyl)propionates], e.g.,

glycerol 2-[2-(6-methylthio-2-naphthyl)propionate],
glycerol 2-[2-(6-difluoromethoxy-2-naphthyl)-

propionate],
glycerol 2-[2-(6-chloro-2-naphthyl)propionate],
glycerol 2-[2-(6-methyl-2-naphthyl)propionate],
glycerol 2-[2-(6-ethyl-2-naphthyl)propionate],
glycerol 2-[2-(6-isopropyl-2-naphthyl)propionate].

EXAMPLE 7

Glycerol 1,3-di(fatty acylate) 1-[2-(6-methoxy-2-naphthyl)propionate]

Repeating the procedure of Example 3 with the product of Example 6 yields the corresponding glycerol 2-[2-(6-methoxy-2-naphthyl)propionate] 1,3-dipalmitate and other 1,3-di(fatty acylates) such as 1,3-dioleates.

EXAMPLE 8

Other glycerol 2,3-di(fatty acylate) 1-(6-substituted-2-naphthylacetates)

Repeating the procedure of Example 4 with the products of Example 6 yields the corresponding glycerol 2,3-di(fatty acylate) 1 - (6 - substituted-2-naphthylacetates) wherein the substituents at the C-6 position of the naphthalene ring include methylthio, trifluoromethoxy, chloro, methyl, ethyl, and isopropyl.

EXAMPLE 9

Glycerol 2,3-di(fatty acylate)-1-(cis bisdehydrodoisynolate)

Repeating the procedures of Examples 1 and 3 but replacing 2-(6-methoxy-2-naphthyl)propionic acid with cis bisdehydrodoisynolic acid yields the corresponding glycerol 2,3-dipalmitate-1-(cis bisdehydrodoisynolate) and corresponding other 2,3-di(fatty acylates).

EXAMPLE 10

Repeating the procedure of Example 9 with other 1,2,3,4-tetrahydrophenanthrene, 1,2,3,4,9,10 - hexahydrophenanthrene and 1,2,3,4,9,10,11,12 - octahydrophenanthrene acids of Formula 1B such as those listed in Table B i.e.

45 racemic-cis 1-ethyl-2-methyl-7-ethoxy-1,2,3,4-tetrahydro-2-phenanthrenecarboxylic acid,
racemic-cis 1-ethyl-2-methyl-7-methoxy-1,2,3,4-tetrahydro-2-phenanthrenecarboxylic acid, and
1-methyl-7-methoxy-1,2,3,4,9,10,11,12-octahydro-2-phenanthrenecarboxylic acid; and the like

50 yields the corresponding

glycerol 2,3-di(fatty acylate)-1-(1,2,3,4-tetrahydro-phenanthrene acid,
1,2,3,4,9,10-hexahydrophenanthrene acid, and
1,2,3,4,9,10,11,12-octahydrophenanthrene acid esters) e.g.
glycerol 23-dipalmitate-1-(racemic-cis 1-ethyl-2-methyl-7-ethoxy-1,2,3,4-tetrahydro-2-phenanthrene-
carboxylate),
glycerol 2,3-dioleate-1-(racemic-cis 1-ethyl-2-methyl-7-methoxy-1,2,3,4-tetrahydro-2-phenanthrene-
carboxylate),
glycerol 2,3-dipalmitate-1-(1-methyl-7-methoxy-
1,2,3,4,9,10,11,12-octahydro-2-phenanthrene-
carboxylate), etc.

EXAMPLE 11

Glycerol 1,3-di(fatty acylate)-2-(racemic cis bisdehydrodoisynolate)

Repeating the procedures of Examples 1, 5 and 7 but replacing 2-(6-methoxy-2-naphthyl)propionic acid with racemic cis-bisdehydrodoisynolic acid yields the corresponding glycerol 1,3-dipalmitates-2-(racemic cis-bisdehy-

drodoisynolate) and the other corresponding 1,3-di(fatty acylates).

EXAMPLE 12

Repeating the procedure of Example 11 with other 1,2,3,4-tetrahydrophenanthrene, 1,2,3,4,9,10 - hexahydrophenanthrene and 1,2,3,4,9,10,11,12 - octahydrophenanthrene acids represented by Formula IB such as those listed in Table B, i.e.

racemic-cis 1-ethyl-2-methoxy-7-ethoxy-1,2,3,4-tetrahydro-2-phenanthrenecarboxylic acid,
racemic-cis 1,1-diethyl-2-methyl-7-methoxy-1,2,3,4-tetrahydro-2-phenanthrenecarboxylic acid,
1-methyl-7-methoxy-1,2,3,4,9,10,11,12-octahydro-2-phenanthrenecarboxylic acid, and the like
yields the corresponding glycerol 1,3-di(fatty acylates)-2-(1,2,3,4-tetrahydrophenanthrene acids, 1,2,3,4,9,10-hexahydrophenanthrene acid, and 1,2,3,4,9,10,11,12-octahydrophenanthrene acid esters), e.g.
glycerol 1,3-dipalmitate-2-(racemic-cis 1-ethyl-2-methoxy-7-ethoxy-1,2,3,4-tetrahydro-2-phenanthrene-carboxylate),
glycerol 1,3-dioleate-2-(racemic-cis 1,1-diethyl-2-methyl-7-methoxy-1,2,3,4-tetrahydro-2-phenanthrene-carboxylate),
glycerol 1,3-dipalmitate-2-(1-methyl-7-methoxy-1,2,3,4,9,10,11,12-octahydro-2-phenanthrenecarboxylate), etc.

EXAMPLE 13

Other glycerol 2,3-di(fatty acylate)-1-(drug carboxylates)

Repeating the procedure of Example 9 with the carboxylic acids listed in Table C such as N-p-sulfonylphenylglycine, 2-acetoxybenzoic acid, acetylsalicylsalicylic acid, and the like yields the corresponding glycerol 2,3-di(fatty acylate)-1-drug carboxylates.

EXAMPLE 14

Other glycerol 1,3-di(fatty acylate)-2-(drug carboxylates)

Repeating the procedure of Example 11 with the drug acids listed in Table C such as

D-(2-amino-2-phenylacetamide)-3,3-dimethyl-7-oxo-4-thia-1-azaciclo[3.3.0]heptane-2-carboxylic acid,
7-(D-5-amino-5-carboxyvaleramide)-3-(hydroxymethyl)-8-oxo-5-thia-1-azabicyclo[4.2.0]oct-2-ene-2-carboxylic acid acetate,
penicillin and the like,

yields the corresponding glycerol 1,3-di(fatty acylate)-2-(drug carboxylates).

EXAMPLE 15

1'-O-(17 β -acetoxy-17 α -ethynylestr-3,5-dien-3-yl)-2',3'-di-O-palmitoyl-glycerol and 2'-O-(17 β -acetoxy-17 α -ethynylestr-3,5-dien-3-yl)-1',3'-di-O-palmitoyl-glycerol

17 β -acetoxy-17 α -ethynylestr-4-en-3-on (10.0 g.) is dissolved in dioxane (425 ml.), and methylorthoformate (10 ml.) is added to the mixture. The solution is flushed with nitrogen for 10 minutes. Then p-toluenesulfonic acid (0.5 g.) is added to the solution. The mixture was maintained at room temperature for 30 minutes, and then was heated for 10 minutes at 75-80°C., continuing to flush the solution with nitrogen. The solution is cooled; pyridine (2 ml.) and then water (25 ml.) is added. The solution is concentrated by solvent evaporation, is mixed with ice water (100 ml.), and the oily phase is separated from the water. The oil is mixed with methanol, and the solid which forms is separated, washed with methanol, water, and then recrystallized from acetone-water to yield 17 β -acetoxy-17 α -ethynyl-3 β -methoxyestra-3,5-diene.

The enol ether (3.54 g.) is dried and dissolved in anhydrous benzene. This solution is mixed with an anhydrous solution of glycerol 1,2-dipalmitate (7.4 g.) and p-toluenesulfonic acid (50 mg.), the reaction mixture is main-

tained at room temperature for 1 hour, and the reaction mixture is concentrated in vacuo. The residue is chromatographed to yield 1'-O-((17 β -acetoxy-17 α -ethynylestra-3,5-dien-3-yl)-2',3'-di-O-palmitoyl-glycerol and 2'-O-(17 β -acetoxy-17 α -ethynyl-estra-3,5-dien-3-yl)-1',3'-di-O-palmitoyl-glycerol.

EXAMPLE 16

Other 1'-O-(17 β -acetoxy-17 α -ethynylestr-3,5-dien-3-yl)-2',3'-di-O-(fatty acyl)glycerols and 2'-O-(17 β -acetoxy-17 α -ethynylestr-3,5-dien-3-yl)-1',3'-di-O-(fatty acyl)glycerols

Repeating the procedure of Example 15 with other glycerol 1,2-di(fatty acylates) having from 8 to 24 carbons such as glycerol 1,2-dioleate, glycerol 1,2-dilaurate and the like yields the corresponding

1'-O-(17 β -acetoxy-17 α -ethynylestr-3,5-dien-3-yl)-2',3'-di-O-(fatty acyl)-glycerols, and
2'-O-(17 β -acetoxy-17 α -ethynylestr-3,5-dien-3-yl)-1',3'-di-O-(fatty acyl)-glycerols, e.g.,
1'-O-(17 β -acetoxy-17 α -ethynylestr-3,5-dien-3-yl)-2',3'-di-O-oleoyl-glycerol,
1'-O-(17 β -acetoxy-17 α -ethynylestr-3,5-dien-3-yl)-2',3'-di-O-lauroyl-glycerol,
2'-O-(17 β -acetoxy-17 α -ethynylestr-3,5-dien-3-yl)-1',3'-di-O-oleoyl-glycerol,
2'-O-(17 β -acetoxy-17 α -ethynylestr-3,5-dien-3-yl)-1',3'-di-O-lauroyl-glycerol, etc.

EXAMPLE 17

Other 1'-O-(steroid-3-yl)-2',3'-di-O-(fatty acyl)glycerols and 2'-O-(steroid-3-yl)-1',3'-di-O-(fatty acyl)glycerols

Repeating the procedure of Example 15 but replacing 17 β -acetoxy-17 α -ethynylestr-4-en-3-one with other steroids of Formulas ID-VD, IE, IF, IIF and IG-IVG (representative steroids listed in Tables D, E, F and G), supra, e.g.

17 β -acetoxyandrost-4-en-3-one,
17 β -acetoxy-17 α -methylandrost-4-en-3-one,
17 β -acetoxy-17 α -ethylandrost-4-en-3-one,
17 β -acetoxy-17 α -ethynyl-18-methylandrost-4-en-3-one,
17 β -acetoxy-17 α -propynylandrost-4-en-3-one,
17 β -acetoxy-17 α -propynyl-18-methylandrost-4-en-3-one,
17 β -acetoxy-17 α -cyclopropylandrost-4-en-3-one,
17 β -acetoxy-17 α -cyclopropyl-18-methylandrost-4-en-3-one,
17 β -acetoxy-17 α -propadienylandrost-4-en-3-one,
17 β -acetoxy-18-methyl-17 α -propadienylandrost-4-en-3-one,
17 β -acetoxyest-4-en-3-one,
17 β -acetoxy-17 α -methylestr-4-en-3-one,
17 β -acetoxy-17 α -ethylestr-4-en-3-one,
17 β -acetoxy-17 α -ethynyl-18-methylestr-4-en-3-one,
17 β -acetoxy-17 α -propynylestr-4-en-3-one,
17 β -acetoxy-17 α -propynyl-18-methylestr-4-en-3-one,
17 β -acetoxy-17 α -cyclopropylestr-4-en-3-one,
17 β -acetoxy-17 α -cyclopropyl-18-methylester-4-en-3-one,
17 β -acetoxy-17 α -propadienylestr-4-en-3-one,
17 β -acetoxy-18-methyl-17 α -propadienylestr-4-en-3-one,
pregn-4-ene-3,20-ione, and
19-norpregn-4-ene-3,20-diones yields the corresponding steroid ethers, e.g.
1'-O-(17 β -acetoxyandrost-3,5-dien-3-yl)-2',3'-di-O-palmitoyl-glycerol,
1'-O-(17 β -acetoxy-17 α -methylandrost-3,5-diene-3-yl)-2',3'-di-O-palmitoyl-glycerol,
1'-O-(17 β -acetoxy-17 α -ethylandrost-3,5-diene-3-yl)-2',3'-di-O-palmitoyl-glycerol,
1'-O-(17 β -acetoxy-17 α -ethynyl-17-methylandrost-3,5-dien-3-yl)-2',3'-di-O-palmitoyl-glycerol,
1'-O-(17 β -acetoxy-17 α -propynylandrost-3,5-diene-3-yl)-2',3'-di-O-palmitoyl-glycerol,
1'-O-(17 β -acetoxy-18-methyl-17 α -propynylandrost-3,5-dien-3-yl)-2',3'-di-O-palmitoyl-glycerol,

- 1'-O-(17 β -acetoxy-17 α -cyclopropyl androst-3,5-dien-3-yl)-2',3'-di-O-palmitoylglycerol,
 1'-O-(17 β -acetoxy-17 α -cyclopropyl-18-methyl androst-3,5-dien-3-yl)-2',3'-di-O-palmitoylglycerol,
 1'-O-(17 β -acetoxy-17 α -propadienyl androst-3,5-dien-3-yl)-2',3'-di-O-palmitoylglycerol,
 1'-O-(17 β -acetoxy-17-methyl-17 α -propadienyl androst-3,5-dien-3-yl)-2',3'-di-O-palmitoylglycerol,
 1'-O-(17 β -acetoxy-3,5-dien-3-yl)-2',3'-di-O-palmitoylglycerol,
 1'-O-(17 β -acetoxy-17 α -methylene-3,5-dien-3-yl)-2',3'-di-O-palmitoylglycerol,
 1'-O-(17 β -acetoxy-17 α -ethylestra-3,5-dien-3-yl)-2',3'-di-O-palmitoylglycerol,
 1'-O-(17 β -acetoxy-17 α -ethynyl-18-methylene-3,5-dien-3-yl)-2',3'-di-O-palmitoylglycerol,
 1'-O-(17 β -acetoxy-17 α -propynylestra-3,5-dien-3-yl)-2',3'-di-O-palmitoylglycerol,
 1'-O-(17 β -acetoxy-17 α -cyclopropyl-18-methylene-3,5-dien-3-yl)-2',3'-di-O-palmitoylglycerol,
 1'-O-(17 β -acetoxy-17 α -cyclopropyl-18-methylene-3,5-dien-3-yl)-2',3'-di-O-palmitoylglycerol,
 1'-O-(17 β -acetoxy-17 α -propadienylestra-3,5-dien-3-yl)-2',3'-di-O-palmitoylglycerol,
 1'-O-(17 β -acetoxy-18-methyl-17 α -propadienylestra-3,5-dien-3-yl)-2',3'-di-O-palmitoylglycerol,
 1'-O-(pregna-3,5-dien-20-one-3-yl)-2',3'-di-O-palmitoylglycerol,
 1'-O-(19-norpregna-3,5-dien-20-one-3-yl)-2',3'-di-O-palmitoylglycerol, and the like.

The corresponding (2'-O-steroid-3-yl)-1',3'-di-O-palmitoylglycerols are also obtained in the above procedure.

Repeating the above procedure with other glycerol 1,2-di(fatty acylates) yields the corresponding 1'-O-(steroid-3-yl)-2',3'-di-O-fatty acyl glycerols and 2'-O-(steroid-3-yl)-1',3'-di-O-(fatty acyl) glycerols.

EXAMPLE 18

Repeating the procedures of Examples 15, 16 and 17 with the corresponding 17 β -hydroxy compounds yields the corresponding 1'-O-(steroid-3-yl)-2',3'-di-O-(fatty acyl) glycerols and 2'-O-(steroid-3-yl)-1',3'-di-O-(fatty acyl) glycerols having 17 β -hydroxy groups.

EXAMPLE 19

1'-O-(17 β -acetoxy-17 α -ethynylestr-3,5-dien-3-yl)-2',3'-O-isopropylidene glycerol

To an anhydrous solution of p-toluenesulfonic acid (80 mg.) in benzene (200 ml.) is added an anhydrous solution of glycerol acetonide (4.3 g.) in benzene (150 ml.). The mixture is refluxed for 36 hours, the solution is evaporated in vacuo, and the residue is chromatographed to yield 1'-O-(17 β -acetoxy-17 α -ethynylestr-3,5-dien-3-yl)-2',3'-O-isopropylidene glycerol.

EXAMPLE 20

Other 1'-O-(steroid-3-yl)-2',3'-O-isopropylidene glycerols

Repeating the procedure of Example 19 with other steroids of Formulas ID-VD, IE, IF, IIF and IG-IVG (representative steroids listed in Tables D, E, F and G) supra, e.g.

- 17 β -acetoxy-3 β -methoxy androst-3,5-diene,
 17 β -acetoxy-3 β -methoxy-17 α -methyl androst-3,5-diene,
 17 β -acetoxy-17 α -methyl-3 β -methoxy androst-3,5-diene,
 17 β -acetoxy-17 α -ethynyl-3 β -methoxy androst-3,5-diene,
 17 β -acetoxy-17 α -ethynyl-3 β -methoxy-18-methyl androst-3,5-diene,
 17 β -acetoxy-3 β -methoxy-17 α -propynyl androst-3,5-diene,
 17 β -acetoxy-3 β -methoxy-18-methyl-17 α -propynyl androst-3,5-diene,
 17 β -acetoxy-17 α -cyclopropyl-3 β -methoxy androst-3,5-diene,

- 3 β -acetoxy-17 α -cyclopropyl-3 β -methoxy-17-methyl androst-3,5-diene,
 17 β -acetoxy-3 β -methoxy-17 α -propadienyl androst-3,5-diene,
 17 β -acetoxy-3 β -methoxy-18-methyl-17 α -propadienyl androst-3,5-diene,
 17 β -acetoxy-3 β -methoxyestra-3,5-diene,
 17 β -acetoxy-3 β -methoxy-17 α -methylestra-3,5-diene,
 17 β -acetoxy-17 α -ethyl-3 β -methoxyestra-3,5-diene,
 17 β -acetoxy-17 α -ethynyl-3 β -methoxy-18-methylestra-3,5-diene,
 17 β -acetoxy-3 β -methoxy-17 α -propynylestra-3,5-diene,
 17 β -acetoxy-3 β -methoxy-18-methyl-17 α -propynylestra-3,5-diene,
 3 β -methoxypregna-3,5-diene-20-one, and
 3 β -methoxy-19-norpregna-3,5-dien-20-one yields the corresponding steroid ethers, e.g.
 1'-O-(17 β -acetoxy-17 α -propynyl androst-3,5-diene-3-yl)-2',3'-O-isopropylidene glycerol,
 1'-O-(17 β -acetoxy-18-methyl-17 α -propynyl androst-3,5-dien-3-yl)-2',3'-O-isopropylidene glycerol,
 1'-O-(17 β -acetoxy-17 α -cyclopropyl androst-3,5-dien-3-yl)-2',3'-O-isopropylidene glycerol,
 1'-O-(17 β -acetoxy-17 α -cyclopropyl-18-methylandrost-3,5-dien-3-yl)-2',3'-O-isopropylidene glycerol,
 1'-O-(17 β -acetoxy-17 α -propadienyl androst-3,5-dien-3-yl)-2',3'-O-isopropylidene glycerol,
 1'-O-(17 β -acetoxy-18-methyl-17 α -propadienyl androst-3,5-dien-3-yl)-2',3'-O-isopropylidene glycerol,
 1'-O-(17 β -acetoxy-17 α -cyclopropylestra-3,5-dien-3-yl)-2',3'-O-isopropylidene glycerol,
 1'-O-(17 β -acetoxy-17 α -methylestra-3,5-dien-3-yl)-2',3'-O-isopropylidene glycerol,
 1'-O-(17 β -acetoxy-17 α -ethylestra-3,5-dien-3-yl)-2',3'-O-isopropylidene glycerol,
 1'-O-(17 β -acetoxy-17 α -ethynylestr-3,5-dien-3-yl)-2',3'-O-isopropylidene glycerol,
 1'-O-(17 β -acetoxy-17 α -ethynylestr-3,5-dien-3-yl)-2',3'-O-isopropylidene glycerol,
 1'-O-(17 β -acetoxy-17 α -cyclopropylestra-3,5-dien-3-yl)-2',3'-O-isopropylidene glycerol,
 1'-O-(17 β -acetoxy-17 α -cyclopropyl-17-methylestra-3,5-dien-3-yl)-2',3'-O-isopropylidene glycerol,
 1'-O-(17 β -acetoxy-17 α -propadienylestra-3,5-dien-3-yl)-2',3'-O-isopropylidene glycerol,
 1'-O-(17 β -acetoxy-18-methyl-17 α -propadienylestra-3,5-dien-3-yl)-2',3'-O-isopropylidene glycerol,
 1'-O-(17 β -acetoxy-17 α -cyclopropylestra-3,5-dien-3-yl)-2',3'-O-isopropylidene glycerol,
 1'-O-(17 β -acetoxy-17 α -cyclopropyl-17-methylestra-3,5-dien-3-yl)-2',3'-O-isopropylidene glycerol,
 1'-O-(17 β -acetoxy-17 α -propadienylestra-3,5-dien-3-yl)-2',3'-O-isopropylidene glycerol,
 1'-O-(17 β -acetoxy-17 α -ethynyl-18-methylandrost-3,5-dien-3-yl)-2',3'-O-isopropylidene glycerol.

EXAMPLE 21

- 1'-O-(drug enyl)-2',3'-di-O-(fatty acyl) glycerols and 2'-O-(drug enyl)-1',3'-di-O-(fatty acyl) glycerols
- Repeating the procedure of Examples 15 and 16 with drug ketones and repeating the procedure of Example 16 with drug enol ethers and aromatic ethers of Table H, supra, e.g. 2-boranone, carbomycin, tetracycline, erythro-

67

mycin A, griseofulvin and the like yields the corresponding

1'-O-(drufi enyl)-2',3'-di-O-(fatty acyl)glycerols and 2'-O-(drug enyl)-1',3'-di-O-(fatty acyl)glycerols, the term drug enyl referring to the presence of carbon-carbon double bond involving the drug carbon atom, i.e. an enol ether linkage.

EXAMPLE 22

17 β -acetoxy-17 α -ethynyl-3,3-(3-hydroxy-1,2-propylenedioxy)estr-5-ene

17 β -acetoxy-17 α -ethynylestr-4-en-3-one (25.0 g.), glycerol (25 ml.) in diglyme (250 ml.), and dry methyl orthoformate (28 ml.) under nitrogen is treated with 30 drops of a solution of perchloric acid (1 drop) in diglyme (40 drops), and is maintained at room temperature for 2 hours. One ml. of pyridine is added to the reaction mixture. The reaction mixture is mixed with water, filtered, and the filtered solids are dissolved in ether, dried and chromatographed on silica gel to yield 17 β -acetoxy-17 α -ethynyl-3,3'-(3-hydroxy-1,2-propylenedioxy)estr-5-ene.

EXAMPLE 23

Other 3,3-(3-hydroxy-1,2-propylenedioxy)- Δ^5 -steroids

Repeating the procedure of Example 22 with

17 β -acetoxy-17 α -ethynylestr-4-en-3-one,
 17 β -acetoxy-17 α -ethyl-18-methylestr-4-en-3-one,
 17 β -acetoxy-17 α -ethynyl-18-methylestr-4-en-3-one,
 17 β -acetoxy-17 α -propadienylestr-4-en-3-one,
 17 β -acetoxy-18-methyl-17 α -propadienylestr-4-en-3-one,
 17 β -acetoxy-18-methyl-17 α -propynylestr-4-en-3-one,
 17 β -acetoxy-17 α -ethylandrost-4-en-3-one,
 17 β -acetoxy-17 α -ethyl-18-methylandrost-4-en-3-one,
 17 β -acetoxy-17 α -ethynyl-18-methylandrost-4-en-3-one,
 17 β -acetoxy-17 α -propadienyl-18-methylandrost-4-en-3-one,
 17 β -acetoxy-18-methyl-17 α -propadienyl-18-methylandrost-4-en-3-one, and
 17 β -acetoxy-18-methyl-17 α -propynyl-18-methylandrost-4-en-3-one, yields the corresponding
 17 β -acetoxy-17 α -ethyl-3,3-(3-hydroxy-1,2-propylenedioxy)estr-5-ene,
 17 β -acetoxy-17 α -ethyl-3,3-(3-hydroxy-1,2-propylenedioxy)-18-methylestr-5-ene,
 17 β -acetoxy-17 α -ethynyl-3,3-(3-hydroxy-1,2-propylenedioxy)-18-methylestr-5-ene,
 17 β -acetoxy-3,3-(3-hydroxy-1,2-propylenedioxy)-17 α -propadienylestr-5-ene,
 17 β -acetoxy-3,3-(3-hydroxy-1,2-propylenedioxy)-18-methyl-17 α -propadienylestr-5-ene,
 17 β -acetoxy-3,3-(3-hydroxy-1,2-propylenedioxy)-18-methyl-17 α -propynylestr-5-ene,
 17 β -acetoxy-17 α -ethyl-3,3-(3-hydroxy-1,2-propylenedioxy)androst-5-ene,
 17 β -acetoxy-17 α -ethyl-3,3-(3-hydroxy-1,2-propylenedioxy)-18-methylandrost-5-ene,
 17 β -acetoxy-17 α -ethynyl-3,3-(3-hydroxy-1,2-propylenedioxy)-18-methylandrost-5-ene,
 17 β -acetoxy-3,3-(3-hydroxy-1,2-propylenedioxy)-17 α -propadienyl-18-methylandrost-5-ene,
 17 β -acetoxy-3,3-(3-hydroxy-1,2-propylenedioxy)-18-methyl-17 α -propadienyl-18-methylandrost-5-ene, and
 17 β -acetoxy-3,3-(3-hydroxy-1,2-propylenedioxy)-18-methyl-17 α -propynyl-18-methylandrost-5-ene.

EXAMPLE 24

17 β -acetoxy-17 α -ethynyl-3,3-(3-palmitoyloxy-1,2-propylenedioxy)estr-5-one

The product of Example 22 (1.8 g.) and palmitic acid (1.35 g.) in 10 ml. of pyridine is treated with p-toluene-

68

sulfonic acid (2.0 g.) in pyridine (10 ml.). The reaction mixture is maintained at room temperature for 18 hours, diluted with water, and the solids are recrystallized from methanol to yield 17 β -acetoxy-17 α -ethynyl-3,3-j(3-palmitoyloxy-1,2-propylenedioxy)ester-5-ene.

EXAMPLE 25

Other 3,3-(3-fatty acyloxy-1,2-propylenedioxy)- Δ^5 -steroids

10 Repeating the procedure of Example 24 with the products of Example 23 yields the corresponding

17 β -acetoxy-17 α -ethyl-3,3-(3-palmitoyloxy-1,2-propylenedioxy)estr-5-ene,
 15 17 β -acetoxy-17 α -ethyl-3,3-(3-palmitoyloxy-1,2-propylenedioxy)-18-methylestr-5-ene,
 17 β -acetoxy-17 α -ethynyl-3,3-(3-palmitoyloxy-1,2-propylenedioxy)-18-methylestr-5-ene,
 20 17 β -acetoxy-3,3-(3-palmitoyloxy-1,2-propylenedioxy)-17 α -propadienylestr-5-ene,
 17 β -acetoxy-3,3-(3-palmitoyloxy-1,2-propylenedioxy)-18-methyl-17 α -propadienylestr-5-ene,
 17 β -acetoxy-3,3-(3-palmitoyloxy-1,2-propylenedioxy)-18-methyl-17 α -propynylestr-5-ene,
 25 17 β -acetoxy-17 α -ethyl-3,3-(3-palmitoyloxy-1,2-propylenedioxy)androst-5-ene,
 17 β -acetoxy-17 α -ethyl-3,3-(3-palmitoyloxy-1,2-propylenedioxy)-18-methylandrost-5-ene,
 17 β -acetoxy-17 α -ethynyl-3,3-(3-palmitoyloxy-1,2-propylenedioxy)-18-methylandrost-5-ene,
 30 17 β -acetoxy-17 α -ethynyl-3,3-(3-palmitoyloxy-1,2-propylenedioxy)-17 α -propadienyl-18-methylandrost-5-ene,
 17 β -acetoxy-17 α -ethynyl-3,3-(3-palmitoyloxy-1,2-propylenedioxy)-18-methylandrost-5-ene,
 35 17 β -acetoxy-3,3-(3-palmitoyloxy-1,2-propylenedioxy)-18-methyl-17 α -propadienyl-18-methylandrost-5-ene, and
 17 β -acetoxy-3,3-(3-palmitoyloxy-1,2-propylenedioxy)-18-methyl-17 α -propynyl-18-methylandrost-5-ene.

40 Repeating the above procedure with other fatty acids yields the corresponding 3,3-[3-(fatty acyloxy)-1,2-propylenedioxy] compounds.

EXAMPLE 26

45 Repeating the procedures of Examples 22 and 24 with pregn-4-ene-3,20-dione and 19-norpregn-4-ene-3,20-dione yields the corresponding

3,3-(3-hydroxy-1,2-propylenedioxy)pregn-5-en-20-one,
 3,3-(3-hydroxy-1,2-propylenedioxy)-19-norpregn-5-en-20-one,
 50 3,3-(3-palmitoyloxy-1,2-propylenedioxy)pregn-5-en-20-one, and
 3,3-(3-palmitoyloxy-1,2-propylenedioxy)-19-norpregn-5-en-20-one.

EXAMPLE 27

17 α -acetoxy-6-chloro-3,3-(3-hydroxy-1,2-propylenedioxy)pregna-4,6-dien-20-one

60 17 α -acetoxy-6-chloro-16 β -methylpregna-4,6-diene-3,20-dione (2.0 g.) in chloroform is mixed with glycerol (0.5 g.), and the mixture is refluxed for 36 hours. The reaction mixture is then washed with aqueous sodium bicarbonate solution, dried, evaporated, and the residue is recrystallized from diethyl ether to yield 17 α -acetoxy-6-chloro-3,3-(3-hydroxy-1,2-propylenedioxy)pregna-4,6-dien-20-one.

EXAMPLE 28

Other 3,3-(3-hydroxy-1,2-propylenedioxy)- Δ^4 -steroids and - $\Delta^{4,6}$ -steroids

70 75 Repeating the procedure of Example 27 with

17 α -acetoxy-6-chloro-16 β -methylpregna-4,6-diene-3,20-dione,
 17 α -acetoxy-6-chloro-16-methylenepregna-4,6-diene-3,20-dione,
 6-chloro-17 α -hydroxypregna-4,6-diene-3,20-dione,

69

6-chloro-17 α -hydroxy-16 β -methylpregna-4,6-diene-3,20-dione,
 6-chloro-17 α -hydroxy-16-methylenepregna-4,6-diene-3,20-dione,
 17 α -acetoxy-6-fluoropregna-4,6-diene-3,20-dione,
 17 α -acetoxy-6-fluoro-16 β -methylpregna-4,6-diene-3,20-dione,
 17 α -acetoxy-6-fluoro-16-methylenepregna-4,6-diene-3,20-dione,
 6-fluoro-17 α -hydroxypregna-4,6-diene-3,20-dione,
 6-fluoro-17 α -hydroxy-16 β -methylpregna-4,6-diene-3,20-dione,
 6-fluoro-17 α -hydroxy-16-methylenepregna-4,6-diene-3,20-dione,
 17 α -acetoxy-6-methylpregna-4,6-diene-3,20-dione,
 17 α -acetoxy-6,16 β -dimethylpregna-4,6-diene-3,20-dione,
 17 α -acetoxy-16-methylene-6-methylpregna-4,6-diene-3,20-dione,
 17 α -hydroxy-6-methylpregna-4,6-diene-3,20-dione,
 17 α -hydroxy-6,16 β -dimethylpregna-4,6-diene-3,20-dione,
 17 α -hydroxy-16-methylene-6-methylpregna-4,6-diene-3,20-dione,
 17 α -acetoxy-6 β -chloro-6 α ,17 α -difluoromethylenepregn-4-ene-3,20-dione,
 17 α -acetoxy-6 β -chloro-6 α ,7 α -difluoromethylen-16-methylenepregn-4-ene-3,20-dione,
 6 β -chloro-6 α ,7 α -difluoromethylen-17 α -hydroxypregn-4-ene-3,20-dione,
 6 β -chloro-6 α ,7 α -difluoromethylen-17 α -hydroxy-16 α -methylenepregn-4-ene-3,20-dione,
 17 α -acetoxy-6 β -fluoro-6 α ,7 α -difluoromethylenepregn-4-ene-3,20-dione,
 17 α -acetoxy-6 β -fluoro-6 α ,7 α -difluoromethylen-16-methylenepregn-4-ene-3,20-dione,
 6 β -fluoro-6 α ,7 α -difluoromethylen-17 α -hydroxypregn-4-ene-3,20-dione, and
 6 β -fluoro-6 α ,7 α -difluoromethylen-17 α -hydroxy-16-methylenepregn-4-ene-3,20-dione yields the corresponding
 17 α -acetoxy-6-chloro-3,3-(3-hydroxy-1,2-propylenedioxy)-pregna-4,6-dien-20-one,
 17 α -acetoxy-6-chloro-3,3-(3-hydroxy-1,2-propylenedioxy)-16 β -methylpregna-4,6-dien-20-one,
 17 α -acetoxy-6-chloro-3,3-(3-hydroxy-1,2-propylenedioxy)-16-methylenepregna-4,6-dien-20-one,

 17 α -acetoxy-6-fluoro-3,3-(3-hydroxy-1,2-propylenedioxy)-pregna-4,6-dien-20-one,
 17 α -acetoxy-6-fluoro-3,3-(3-hydroxy-1,2-propylenedioxy)-16 β -methylpregna-4,6-dien-20-one,
 17 α -acetoxy-6-fluoro-3,3-(3-hydroxy-1,2-propylenedioxy)-16-methylenepregna-4,6-dien-20-one,
 6-fluoro-17 α -hydroxy-3,3-(3-hydroxy-1,2-propylenedioxy)-pregna-4,6-dien-20-one,
 6-fluoro-17 α -hydroxy-3,3-(3-hydroxy-1,2-propylenedioxy)-16 β -methylpregna-4,6-dien-20-one,
 17 α -acetoxy-3,3-(3-hydroxy-1,2-propylenedioxy)-6-methylpregna-4,6-dien-20-one,
 17 α -acetoxy-3,3-(3-hydroxy-1,2-propylenedioxy)-6,16 β -dimethylpregna-4,6-dien-20-one,
 17 α -acetoxy-3,3-(3-hydroxy-1,2-propylenedioxy)-16-methylen-6-methylpregna-4,6-dien-20-one,
 17 α -hydroxy-3,3-(3-hydroxy-1,2-propylenedioxy)-6-methylpregna-4,6-dien-20-one,
 17 α -hydroxy-3,3-(3-hydroxy-1,2-propylenedioxy)-6,16 β -dimethylpregna-4,6-dien-20-one,

70

17 α -hydroxy-3,3-(3-hydroxy-1,2-propylenedioxy)-16-methylene-6-methylpregna-4,6-dien-20-one,
 17 α -acetoxy-6 β -chloro-6 α ,7 α -difluoromethylen-3,3-(3-hydroxy-1,2-propylenedioxy)-pregna-4-en-20-one,
 5 17 α -acetoxy-6 β -chloro-6 α ,7 α -difluoromethylen-3,3-(3-hydroxy-1,2-propylenedioxy)-16-methylenepregn-4-en-20-one,
 6 β -chloro-6 α ,7 α -difluoromethylen-17 α -hydroxy-3,3-(3-hydroxy-1,2-propylenedioxy)-pregn-4-en-20-one,
 10 6 β -chloro-6 α ,7 α -difluoromethylen-17 α -hydroxy-3,3-(3-hydroxy-1,2-propylenedioxy)-16-methylenepregn-4-en-20-one,
 17 α -acetoxy-6 β -fluoro-6 α ,7 α -difluoromethylen-3,3-(3-hydroxy-1,2-propylenedioxy)-pregn-4-en-20-one,
 15 17 α -acetoxy-6 β -fluoro-6 α ,7 α -difluoromethylen-3,3-(3-hydroxy-1,2-propylenedioxy)-16-methylenepregn-4-en-20-one,
 6 β -fluoro-6 α ,7 α -difluoromethylen-17 α -hydroxy-3,3-(3-hydroxy-1,2-propylenedioxy)-pregn-4-en-20-one, and
 20 6 β -fluoro-6 α ,7 α -difluoromethylen-17 α -hydroxy-3,3-(3-hydroxy-1,2-propylenedioxy)-16-methylenepregn-4-en-20-one,
 respectively.

EXAMPLE 29

25 17 α -acetoxy-6-chloro-3,3-(3-palmitoyloxy-1,2-propylenedioxy)-pregna-4,6-dien-20-one

17 α -acetoxy-6-chloro-3,3-(3-hydroxy-1,2-propylenedioxy)-pregna-4,6-dien-20-one (200 mg.) in pyridine
 30 (1.5 ml.) is mixed with a solution of palmitoyl chloride (120 mg.) in dioxane (0.5 ml.) and the reaction mixture is maintained at room temperature for 30 minutes. The reaction mixture is then mixed with water, extracted with hexane, and the hexane phase is washed with water, dried, and evaporated to dryness and the residue is chromatographed on silica gel, eluting with hexane: ethyl acetate to yield 17 α -acetoxy-6-chloro-3,3-(3-palmitoyloxy-1,2-propylenedioxy)pregna-4,6-dien-20-one.

EXAMPLE 30

Other 3,3-(3-fatty acyloxy-1,2-propylenedioxy)- Δ^4 -steroids and $\Delta^{4,6}$ -steroids

Repeating the procedure of Example 29 with the products of Example 28 yields the corresponding:

45 17 α -acetoxy-6-chloro-3,3-(3-palmitoyloxy-1,2-propylenedioxy)-pregna-4,6-dien-20-one,
 17 α -acetoxy-6-chloro-16 β -methyl-3,3-(3-palmitoyloxy-1,2-propylenedioxy)pregna-4,6-dien-20-one,
 50 17 α -acetoxy-6-chloro-16-methylene-3,3-(3-palmitoyloxy-1,2-propylenedioxy)pregna-4,6-dien-20-one,
 6-chloro-17 α -hydroxy-3,3-(3-palmitoyloxy-1,2-propylenedioxy)-pregna-4,6-dien-20-one,
 6-chloro-17 α -hydroxy-16 β -methyl-3,3-(3-palmitoyloxy-1,2-propylenedioxy)pregna-4,6-dien-20-one,
 55 6-chloro-17 α -hydroxy-16-methylene-3,3-(3-palmitoyloxy-1,2-propylenedioxy)pregna-4,6-dien-20-one,
 17 α -acetoxy-6-fluoro-3,3-(3-palmitoyloxy-1,2-propylenedioxy)-pregna-4,6-dien-20-one,
 60 17 α -acetoxy-6-fluoro-16 β -methyl-3,3-(3-palmitoyloxy-1,2-propylenedioxy)pregna-4,6-dien-20-one,
 17 α -acetoxy-6-fluoro-16-methylene-3,3-(3-palmitoyloxy-1,2-propylenedioxy)pregna-4,6-dien-20-one,
 65 17 α -acetoxy-6-fluoro-16 β -methyl-3,3-(3-palmitoyloxy-1,2-propylenedioxy)pregna-4,6-dien-20-one,
 6-fluoro-17 α -hydroxy-16 β -methyl-3,3-(3-palmitoyloxy-1,2-propylenedioxy)pregna-4,6-dien-20-one,
 70 17 α -acetoxy-6-methyl-3,3-(3-palmitoyloxy-1,2-propylenedioxy)pregna-4,6-dien-20-one,
 17 α -acetoxy-6,16 β -dimethyl-3,3-(3-palmitoyloxy-1,2-propylenedioxy)pregna-4,6-dien-20-one,
 17 α -acetoxy-16-methylene-6-methyl-3,3-(3-palmitoyloxy-1,2-propylenedioxy)pregna-4,6-dien-20-one,

75

71

17 α -hydroxy-6-methyl-3,3-(3-palmitoyloxy-1,2-propylenedioxy)pregna-4,6-dien-20-one,
 17 α -hydroxy-6,16 β -dimethyl-3,3-(3-palmitoyloxy-1,2-propylenedioxy)pregna-4,6-dien-20-one,
 17 α -hydroxy-16-methylene-6-methyl-3,3-(3-palmitoyloxy-1,2-propylenedioxy)pregna-4,6-dien-20-one,
 17 α -acetoxy-6 β -chloro-6 α ,7 α -difluoromethylene-3,3-(3-palmitoyloxy-1,2-propylenedioxy)pregna-4-en-20-one,
 17 α -acetoxy-6 β -chloro-6 α ,7 α -difluoromethylene-16-methylene-3,3-(3-palmitoyloxy-1,2-propylenedioxy)pregna-4-en-20-one,
 6 β -chloro-6 α ,7 α -difluoromethylene-17 α -hydroxy-3,3-(3-palmitoyloxy-1,2-propylenedioxy)-pregn-4-en-20-one,
 6 β -chloro-6 α ,7 α -difluoromethylene-17 α -hydroxy-16-methylene-3,3-(3-palmitoyloxy-1,2-propylenedioxy)pregn-4-en-20-one,
 17 α -acetoxy-6 β -fluoro-6 α ,7 α -difluoromethylene-3,3-(3-palmitoyloxy-1,2-propylenedioxy)pregn-4-en-20-one,
 17 α -acetoxy-6 β -fluoro-6 α ,7 α -difluoromethylene-16-methylene-3,3-(3-palmitoyloxy-1,2-propylenedioxy)pregn-4-en-20-one,
 6 β -fluoro-6 α ,7 α -difluoromethylene-17 α -hydroxy-3,3-(3-palmitoyloxy-1,2-propylenedioxy)pregn-4-en-20-one,
 and
 6 β -fluoro-6 α ,7 α -difluoromethylene-17 α -hydroxy-16-methylene-3,3-(3-palmitoyloxy-1,2-propylenedioxy)pregn-4-en-20-one,
 respectively.

Repeating the above procedure with other fatty acyl chlorides yields the corresponding compounds having 3,3-[3-(fatty acyloxy)-1,2-propylenedioxy] groups.

EXAMPLE 31

Other 3-(fatty acyloxy)-1,2-propylenedioxy steroids

Repeating the procedure of Examples 27 and 29 with other ketones of Formulas ID-VD, IE, IF, IIF, and IG-IVG (representative steroids listed in Tables D, E, F and G) supra yields the corresponding 3-(fatty acyloxy)-1,2-propylenedioxy steroids.

EXAMPLE 32

Other 3-(fatty acyloxy)-1,2-propylenedioxy (monoglyceride ketal) drug derivatives

Repeating the procedure of Examples 27 and 29 with drug ketones such as those listed in Table H yields the corresponding 3'-(fatty acyloxy)-1',2'-propylenedioxy (monoglyceride ketal) drug compounds.

EXAMPLE 33

3-(2,3-dipalmitoyloxy-1-propionyloxy)estr-1,3,5(10)-trien-17 β -ol

A mixture of 17 β -trifluoroacetoxyestra-1,3,5(10)-trien-3-ol (100 mg.) and potassium isopropylidene glycerate (65 mg.) in pyridine (1.5 ml.) and p-toluenesulfonyl chloride (140 mg.) at -10° C. is allowed to come to room temperature. The reaction mixture is mixed with water at 0° C. and the isopropylidene glycerate of 17 β -trifluoroacetoxyestra-1,3,5(10)-trien-3-ol is separated therefrom by filtration. The 17 β -trifluoroacetate group is removed by treating the product in acetone with an excess of acetic acid and sodium acetate in ethanol for 18 hours at room temperature followed by diluting with water and extracting with ether. The ether phase is evaporated to dryness, and the residue chromatographed to yield 3-(isopropylidene glyceroyloxy)-estra-1,3,5(10)-trien-17 β -ol.

The latter compound is mixed with anhydrous trifluoroacetic acid for 5 minutes at room temperature, and the acid evaporated off with carbon tetrachloride. The residue is recrystallized from isopropyl ether to yield 3-glyceroyloxy-estra-1,3,5(10)-trien-17 β -ol.

The compound (2.6 g.) is dissolved in ethyl acetate-carbon tetrachloride, and 10 ml. of pyridine is added. To

this solution is added a solution of 7.0 g. of palmitoyl chloride in carbon tetrachloride (20 ml.), and the solution is allowed to stand overnight. Water (3 ml.) is then added, and the solution is allowed to stand for 15 minutes. The solution is extracted with water, aqueous sodium bicarbonate solution and dried with magnesium sulfate. The solution is then filtered, and any polar material is removed by chromatographic filtration. The solution is evaporated and the residue chromatographed on silica gel to yield 3-(2,3-dipalmitoyloxy-1-propionyloxy)estra-1,3,5(10)-trien-17 β -ol.

EXAMPLE 34

3-(2,3-di(fatty acyloxy)-1-propionyloxy)estra-1,3,5(10)-trien-17 β -ols

Repeating the procedure of Example 33 with other fatty acyl chlorides yields the corresponding 3-(2,3-di(fatty acyloxy)-1-propionyloxy)estr-1,3,5(10)-trien-17 β -ol.

EXAMPLE 35

1,2-(6-methoxy-2-naphthyl)propanol 2',3'-di(fatty acyl) glycerates

Repeating the procedure of Example 33 but replacing 17 β -trifluoroacetoxyestra-1,3,5(10)-trien-3-ol with 1,2-(6-methoxy-2-naphthyl)propanol yields the corresponding 1,2-(6-methoxy-2-naphthyl)propanol 2',3'-dipalmitoylglycerate.

Repeating the procedure of Example 34 with 1,2-(6-methoxy-2-naphthyl)propanol yields the corresponding 1,2-(6-methoxy-2-naphthyl)propanol 2',3'-di(fatty acyl) glycerates.

EXAMPLE 35

Other 2-(6-substituted-2-naphthyl)propanol 2',3'-di(fatty acyl)-glycerates

Repeating the procedures of Example 33 and 34 with other 2-(6-substituted-2-naphthyl)propanols having at the C-6 position of the naphthalene ring, methylthio, difluoromethoxy, chloro, methyl, ethyl or isopropyl groups yields the corresponding 2-(6-substituted-2-naphthyl)propanol 2',3'-di(fatty acyl) glycerates, e.g.

2-(6-methylthio-2-naphthyl)propanol 2',3'-dipalmitoylglycerate,
 2-(6-difluoromethoxy-2-naphthyl)-propanol 2',3'-dipalmitoylglycerate,
 2-(6-chloro-2-naphthyl)propanol 2',3'-dipalmitoylglycerate,
 2-(6-methyl-2-naphthyl)propanol 2',3'-dipalmitoylglycerate,
 2-(6-ethyl-2-naphthyl)propanol 2',3'-dipalmitoylglycerate,
 2-(6-isopropyl-2-naphthyl)propanol 2',3'-dipalmitoylglycerate, and the like.

EXAMPLE 37

Other 2',3'-di(fatty acyloxy)-1'-propionyloxy steroids

Repeating the procedure of Examples 33 and 34 with steroid alcohols of Formulas IN-VIN, IO, IIO, IP, and IQ-IVQ (examples listed in Tables K, L, M, N), supra, yields the corresponding 2',3'-di(fatty acyloxy)-1'-propionyloxy steroids, e.g.

17 β -(2,3-dipalmitoyloxy-1-propionyloxy)-5 α ,19-norandrost-3-one,
 9 α -chloro-11 β -hydroxy-21-(2,3-dipalmitoyloxy-1-propionyloxy)-pregna-4,6-diene-3,20-dione,
 17 β -(2,3-dipalmitoyloxy-1-propionyloxy)estra-1,3,5(10)-trien-3-ol,
 3-methoxy-17 α -ethynyl-17 β -(2,3-dipalmitoyloxy-1-propionyloxy)androst-3,5-diene,
 and the like.

73

EXAMPLE 38

Other drug alcohol 2',3'-di(fatty acyl) glycerates

Repeating the procedures of Examples 33 and 34 with other drug alcohols such as those listed in Table O, supra, yields the corresponding drug 2',3'-di(fatty acyl) glycerates, e.g.

4-acetamido-2-methyl-1-naphthol 2',3'-dipalmitoyloxy-glycerate,
4"-hydroxyacetanilide 2',3'-dipalmitoylglycerate,
oxytetracycline 2',3'-dipalmitoylglycerate,
5-chloro-2-benzoxazolol 2',3'-dipalmitoylglycerate,
6-deoxy-5-hydroxytetracycline 2',3'-dipalmitoylglycerate,
and the like.

I claim:

1. A compound selected from the group of compounds represented by the formula:

wherein

R^1 , R^2 and R^3 each is hydrogen, fatty acyl having at least 4 carbon atoms or

and one of said R^1 , R^2 and R^3 isat least one of other of said R^1 , R^2 and R^3 is said fatty acyl; and

is selected from the group of compounds represented by the formula:

wherein one of R^{116} and R^{117} is hydrogen and the other is hydrogen, methyl, ethyl, difluoromethyl, fluoro or chloro; or R^{116} and R^{117} taken together are methylene, halomethylene or ethylene; and R^{118} is hydrogen, alkyl having up to 6 carbon atoms, cycloalkyl having from 3 to 7 carbon atoms, trifluoromethyl, hydroxymethyl,

74

alkoxymethyl having up to 7 carbon atoms, vinyl, ethynyl, fluoro, chloro, alkoxy having up to 6 carbon atoms, difluoromethoxy, alkoxy methoxy having up to 7 carbon atoms, alkylthiomethoxyloxy having up to 7 carbon atoms, alkylthio having up to 6 carbon atoms, difluoromethylthio, alkoxy methylthio having up to 7 carbons, alkylthiomethylthio having up to 7 carbon atoms, phenyl, p-tolyl, p-fluorophenyl, p-chlorophenyl, p-hydroxyphenyl, p-methoxyphenyl and p-ethylphenyl.

2. A compound of claim 1 wherein

is selected from the groups represented by the formula:

wherein

R^{130} is methoxy, methylthio, difluoromethoxy, chloro, methyl, ethyl or isopropyl; and

25 R^{131} is hydrogen, methyl or difluoromethyl.3. A compound of claim 2 wherein R^{131} is methyl.4. A compound of claim 3 wherein R^{130} is methoxy.5. A compound of claim 3 wherein at least one of R^1 , R^2 and R^3 is a palmityl group.

30 6. As a compound of claim 5, glycerol 2,3-dipalmitate-1-[2-(6-methoxy-2-naphthyl)propionate].

7. A compound of claim 3 wherein R^{130} is methylthio.8. A compound of claim 3 wherein R^{130} is methyl.9. A compound of claim 3 wherein R^{130} is difluoromethoxy.35 10. A compound of claim 3 wherein R^{130} is ethyl.
